UNITED STATES PATENT OFFICE

2,340,554

TELEPHONE SYSTEM

Edward S. Peterson, Elmwood Park, Ill., assignor
to Automatic Electric Laboratories, Inc., a corporation of Delaware

Application April 30, 1942, Serial No. 441,113

17 Claims. (Cl. 179—27)

The present invention relates to telephone systems and more particularly to improvements in automatic switching apparatus of the all-relay type adapted for use in automatic exchanges serving the subscribers of small communities.

A community automatic exchange or C. A. X of this type frequently includes automatic switching apparatus of the all-relay link type and trunking facilities to nearby central exchanges of both the manual and the automatic types.

In a conventional C. A. X of the type noted local calls, incoming and outgoing central exchange trunk calls and inter-central exchange trunk calls are set up by way of the all-relay links therein. While this trunking arrangement for setting up the inter-central exchange calls by way of the all-relay links in the C. A. X is entirely satisfactory in operation, a greater number of all-relay links in the C. A. X is required than is desirable.

Accordingly it is an object of the present invention to provide in a C. A. X of the all-relay type an improved arrangement of by-pass selectors of the all-relay type, whereby inter-central exchange trunk calls may be routed directing without employing the all-relay links in the C. A. X.

Another object of the invention is to provide an improved by-pass selector of the all-relay type.

Another object of the invention is to provide in C. A. X of the all-relay type an improved arrangement of dial-back repeaters for setting up trunk calls to central exchanges which are not directly accessible to the all-relay links in the C. A. X.

Another object of the invention is to provide an improved dial-back repeater comprising associated selectors for setting up the calls therethrough, which selectors are of the all-relay type. A further object of the invention is to provide an improved distributor arrangement for connecting dial-back repeaters to idle trunks in a loop extending to a control operator position. A further object of the invention is to provide an improved repeater arrangement for trunking loops between two automatic exchanges.

Further features of the invention pertain to a particular arrangement of the circuit elements of the system, whereby the above-outlined additional operating features are attained. The invention both as to its organization and method of operation, together with further objects and advantages thereof, will best be understood by reference to the following specification taken in connection with the accompanying

drawings, in which Figures 1 and 2, taken together, illustrate the general arrangement of a telephone system embodying the present invention; Figs. 3 to 28, inclusive, taken together, illustrate the details of a system having incorporated therein the features of the invention, as briefly outlined above; and Fig. 29 illustrates the mode of combining Figs. 3 to 28, inclusive, of the drawings to form a unified system.

10 *Description of the apparatus incorporated in the system*

Referring now more particularly to Figs. 1 and 2 of the drawings, the telephone system there illustrated comprises four manual exchanges 30, 31, 32 and 33 and two automatic exchanges 34 and 35, the manual exchange 33 constituting a toll center and the automatic exchange 35 constituting a tandem exchange for the system, as explained more fully hereinafter. The manual exchange 30 and the automatic exchange 35 are interconnected by three trunks; the first and second trunks include physical circuits and the third trunk includes a phantom circuit on the two physical circuits, the first trunk being indicated at 131.

15 The manual exchange 31 and the automatic exchange 35 are interconnected by a single trunk indicated at 141. The manual exchange 32 and the automatic exchange 35 are interconnected by three trunks; the first and second trunks include physical circuits and the third trunk includes a phantom circuit on the two physical circuits, the first trunk being indicated at 142.

20 The manual exchange 33 and the automatic exchange 35 are interconnected by three toll lines; the first and second toll lines include physical circuits and the third toll line includes a phantom circuit on the two physical circuits, the first toll line being indicated at 143. The automatic exchange 34 and the automatic exchange 35 are interconnected by three trunks; the first and second trunks include physical circuits and the third trunk includes a phantom circuit on the two physical circuits, the first trunk being indicated at 165.

25 The manual exchanges 30, 31 and 32 comprise conventional equipment, each including a manual operator position having access to the trunk or trunks mentioned; the manual exchange 33 comprises conventional equipment including a toll position having access to the toll lines mentioned; the automatic exchange 34 comprises conventional equipment including automatic switching apparatus having access to the trunks mentioned; while the automatic exchange 35 serves a number of local sub-

scriber substations including the subscriber substation T.

The three trunks extending between the manual exchange 30 and the automatic exchange 35 are of the two-way type and terminate in composite equipment, not shown, provided in the manual exchange 30 and in composite equipment 40 provided in the automatic exchange 35. Also the single trunk 141 extending between the manual exchange 31 and the automatic exchange 35 is of the two-way type. Further the three trunks extending between the manual exchange 32 and the automatic exchange 35 are of the two-way type and terminate in composite equipment, not shown, provided in the manual exchange 32 and in composite equipment 42 provided in the automatic exchange 35. Similarly, the three toll lines extending between the manual exchange 33 and the automatic exchange 35 are of the two-way type and terminate in composite equipment, not shown, provided in the manual exchange 33 and in composite equipment 43 provided in the automatic exchange 35. Finally the three trunks extending between the automatic exchange 34 and the automatic exchange 35 are of the two-way type and terminate in composite equipment, not shown, provided in the automatic exchange 34 and in composite equipment 44 provided in the automatic exchange 35.

The three trunks extending between the manual exchange 30 and the automatic exchange 35 and terminating in the composite equipment 40 are provided with three by-pass selectors individual thereto in the automatic exchange 35, the by-pass selector 50 being individual to the first trunk 131. The single trunk 141 extending between the manual exchange 31 and the automatic exchange 35 is provided with a by-pass selector 51 individual thereto in the automatic exchange 35. Also the three trunks extending between the manual exchange 32 and the automatic exchange 35 and terminating in the composite equipment 42 are provided with three by-pass selectors individual thereto in the automatic exchange 35, the by-pass selector 52 being individual to the first trunk 142. The three toll lines extending between the manual exchange 33 and the automatic exchange 35 and terminating in the composite equipment 43 are provided with three toll line circuits individual thereto in the automatic exchange 35, the toll line circuit 60 being individual to the first toll line 143. Also each of the toll line circuits is connected by a trunk to an incoming selector individual thereto in the automatic exchange 35, the toll line circuit 60 being connected by the trunk 146 to the incoming selector 153 individual thereto. Finally the three trunks extending between the automatic exchange 34 and the automatic exchange 35 and terminating in the composite equipment 44 are provided with three automatic repeaters individual thereto in the automatic exchange 35, the automatic repeater 62 being individual to the first trunk 165. Also each of the repeaters is connected by a trunk to a line circuit individual thereto in the automatic exchange 35, the automatic repeater 62 being connected by the trunk 113 to the line circuit 81 individual thereto.

Each of the by-pass selectors in the group of three, including the by-pass selector 50, is provided with an incoming trunk individual thereto, the by-pass selector 50 being provided with the incoming trunk 105 individual thereto; also this group of by-pass selectors is provided with a trunk group allotter 70 which is operative to allot

idle trunks to the manual exchange 30, in a manner more fully explained hereinafter. Also the by-pass selector 51 is provided with an incoming trunk 125 individual thereto. Similarly, each of the by-pass selectors in the group of three, including the by-pass selector 52, is provided with an incoming trunk individual thereto, the by-pass selector 52 being provided with the incoming trunk 130 individual thereto; also this group of by-pass selectors is provided with a trunk group allotter 72 which is operative to allot idle trunks to the manual exchange 32, in a manner more fully explained hereinafter.

Each of the toll line circuits in the group of three is provided with an incoming trunk individual thereto, the toll line circuit 60 being provided with the incoming trunk 150 individual thereto. Also the automatic exchange 35 comprises three dial-back repeaters, including the dial-back repeater 61, having access to the three incoming trunks 150 etc., extending to the three toll line circuits 60 etc. Each of the dial-back repeaters is connected by a trunk to an incoming selector individual thereto in the automatic exchange 35, the dial-back repeater 61 being connected by the trunk 155 to the incoming selector 54 individual thereto. Further each of the dial-back repeaters in the group of three is provided with an incoming trunk individual thereto, the dial-back repeater 61 being provided with the incoming trunk 121 individual thereto; also this group of dial-back repeaters is provided with a repeater allotter 73 which is operative to allot idle dial-back repeaters, in a manner more fully explained hereinafter. Finally each of the automatic repeaters in the group of three is provided with an incoming trunk individual thereto, the automatic repeater 62 being provided with the incoming trunk 166 individual thereto; also this group of automatic repeaters is provided with a trunk group allotter 74 which is operative to allot idle trunks to the automatic exchange 34, in a manner more fully explained hereinafter.

Each of the by-pass selectors 50, 51, 52 etc. has access to a local trunk individual thereto which terminates in an individual line circuit in the automatic exchange 35; for example, the by-pass selector 50 has access to a local trunk 134 individual thereto which terminates in an individual line circuit 80. Similarly each of the incoming selectors 53, 54 etc. has access to a local trunk individual thereto which terminates in an individual line circuit in the automatic exchange 35; for example, the incoming selector 53 has access to a local trunk 156 individual thereto which terminates in an individual line circuit, not shown.

Finally each subscriber substation in the automatic exchange 35 has a subscriber line extending thereto which terminates in a line circuit individual thereto in the automatic exchange 35; for example, the subscriber substation T has a subscriber line 163 extending thereto which terminates in the line circuit 82 individual thereto. Further each subscriber substation is provided with conventional substation equipment including a telephone instrument, a calling device or dial and a ringer.

Finally the automatic exchange 35 comprises a local switch train including a number of links, a call allotter 90 and a link allotter 91. The first link is indicated at 92 and comprises a finder 93 and a connector 94. The call allotter 90 is operatively associated with each of the line circuits 80, 81, 82 etc. and is adapted to mark calls

successively to the link allotter 81; while the link allotter 81 is operative to select idle ones of the links successively by way of the cable 85 and to repeat the marking of a call to the finder of a selected link.

Each of the by-pass selectors in the group of three, including the by-pass selector 50, has access to the local trunk individual thereto; to the group of three incoming trunks, including the incoming trunk 130; to the incoming trunk 125; to the group of three incoming trunks, including the incoming trunk 130; and to the group of three incoming trunks, including the incoming trunk 121. The by-pass selector 51 has access to the local trunk individual thereto; to the group of three incoming trunks, including the incoming trunk 130; to the group of three incoming trunks, including the incoming trunk 105; and to the group of three incoming trunks, including the incoming trunk 121. Each of the by-pass selectors in the group of three, including the by-pass selector 52, has access to the local trunk individual thereto; to the incoming trunk 125; to the group of three incoming trunks, including the incoming trunk 105; and to the group of three incoming trunks, including the incoming trunk 121.

Each of the incoming selectors in the group of three, including the incoming selector 53, and each of the incoming selectors in the group of three, including the incoming selector 54, have access to the local trunks individual thereto; to the group of three incoming trunks, including the incoming trunk 130; to the incoming trunk 125; and to the group of three incoming trunks, including the incoming trunk 105. The finder of each link has access to each of the line circuits 80, 81, 82 etc.; while the connector of each link has access to each of the subscriber lines 163 etc.; to the incoming trunk 125; to the group of three incoming trunks, including the incoming trunk 166; and to the group of three incoming trunks, including the incoming trunk 121.

Further it is noted that the connector of each link comprises restricted service facilities which are so connected and arranged that, when a call is extended therover from the automatic exchange 34, it is blocked against access to the incoming trunk 125; to the group of three incoming trunks, including the incoming trunk 105; and to the group of three incoming trunks, including the incoming trunk 121. Also the connector of each link comprises restricted service facilities which are so connected and arranged that, when a call is extended therover from the automatic exchange 35, it is blocked against access to the group of three incoming trunks, including the incoming trunk 105.

Preferably the composite equipment 40, 42, 43 and 44 terminating the various groups of trunks and toll lines in the automatic exchange 35 are substantially identical. For example, the composite equipment 40, shown in Fig. 5, comprises apparatus terminating the group of three trunks extending to the manual exchange 30, including a repeater 570 terminating the first trunk 131; the composite equipment 43, shown in Fig. 12, comprises apparatus terminating the group of three toll lines extending to the manual exchange 33, including a repeater 1270 terminating the first toll line 143; and the composite equipment 44, shown in Fig. 24, comprises apparatus terminating the group of three trunks extending to the automatic exchange 34, including a repeater 2470, terminating the first trunk 165.

Preferably the by-pass selectors 50, 51, 52 etc. are substantially identical. For example, the by-pass selector 50, shown in Figs. 5 to 10, inclusive, comprises a relay group, including a timing relay R510, a ring start slave relay R520, a ring start relay R530, a tone cutoff relay R540, a seizure relay R550, an impedance element I555, a lock relay R610, a reverse battery relay R620, a hold relay R630, a switch relay R640, an answer relay R650, a supervisory relay R660, an impulse relay R670, a ring relay R710, a shunt relay R720, a dial relay R730, a splash relay R740, two dial slave relays R750 and R770, a switch-through relay R760, a busy relay R810, a test relay R820, three trunk select relays R830, R840 and R850, a connect slave relay R860, a connect relay R870, ten counting relays R910, R920, R930, R940, R950, R960, R1010, R1020, R1030 and R1040, and three cycle relays R1050, R1060 and R1070; and a control network connected and arranged in a manner more fully explained hereinafter. Also timing and alarm equipment 800, indicated in Fig. 8, is commonly associated with the by-pass selectors 50, 51, 52 etc.

Preferably the incoming selectors 53, 54 etc. are substantially identical. For example, the incoming selector 53, shown in Figs. 13 to 16, inclusive, comprises a relay group including a control relay R1310, a switch-through relay R1320, a line relay R1330, a hold relay R1340, a dial relay R1350, a dial slave relay R1410, a busy relay R1420, a test relay R1430, three trunk select relays R1440, R1450 and R1460, a connect slave relay R1470, a connect relay R1480, ten counting relays R1510, R1520, R1530, R1540, R1550, R1560, R1610, R1620, R1630 and R1640, three cycle relays R1650, R1660 and R1670 and a series relay R1680; and a control network connected and arranged in a manner more fully explained hereinafter.

Preferably each of the toll line circuits is identical to the toll line circuit 60, connected by way of the repeater 1270 in the composite equipment 43 to the first toll line 143 extending to the manual exchange 33 and connected by way of the trunk 146 to the incoming selector 53. The toll line circuit 60, shown in Fig. 12, comprises a relay group including a dial relay R1210, an answer relay R1220, a switching relay R1230, an impulse relay R1240, a hold relay R1250 and a busy relay R1260; and a control network connected and arranged in a manner more fully explained hereinafter.

Preferably each of the dial-back repeaters is identical to the dial-back repeater 61 connected by way of the trunk 150 to the toll line circuit 60 and connected by way of the trunk 155 to the incoming selector 54. The dial-back repeater 61, shown in Figs. 17 to 20, inclusive, comprises a trunk distributor 1700 which is operative to connect thereto idle ones of the trunks 150 etc., respectively extending to the toll line circuits 60 etc., in a predetermined order. The trunk distributor 1700 comprises a first relay group including a lockout relay R1710, a busy relay R1720, a select relay R1730 and a connect relay R1740 individual to the first trunk 150; a second relay group, not shown, individual to the second trunk; and a third relay group including a lockout relay R1750, a busy relay R1760, a select relay R1770 and a connect relay R1780 individual to the third trunk. Also the trunk distributor 1700 comprises a common reset relay

R1790 and a control network connected and arranged in a manner more fully explained hereinafter. Further the dial-back repeater 61 comprises a relay group including a toll connect relay R1810, a signal slave relay R1820, a signal relay R1830, two hold relays R1840 and R2020, a supervisory relay R1850, a dial relay R1860, an impulse relay R1870, a bridge relay R1880, a release relay R1890, a shunt relay R1920, three control relays R1930, R1970 and R2010, an answer relay R1940, a selector connect relay R1950, a local call relay R1960, a timer relay R1980, a lock relay R1990, a tone stop relay R2030, an impedance element I2040, a seizure relay R2050, a trunk call relay R2060, a reverse battery relay R2070 and an alarm relay R2080. Also the dial-back repeater 61 includes a repeater 615 and a control network connected and arranged in a manner more fully explained hereinafter. Also timing and alarm equipment 2100, indicated in Fig. 21, is commonly associated with the dial-back repeaters 61 etc.

Preferably each of the automatic repeaters is identical to the automatic repeater 62, shown in Figs. 24 to 27, inclusive, which comprises a relay group including two impulse relays R2410 and R2520, a hold slave relay R2420, two hold relays R2430 and R2730, a cutoff relay R2440, a reverse battery relay R2450, a bridge relay R2510, a tone relay R2530, two shunt relays R2540 and R2550, a number of control relays R2560, R2610, R2640, R2650, R2740 and R2750, a seizure relay R2610, two answer relays R2620 and R2630, two supervisory relays R2660 and R2770, a repeat relay R2670, two pulse relays R2710 and R2720, and a busy relay R2760. Also the automatic repeater 62 comprises a transformer 2460 and a control network connected and arranged in a manner more fully explained hereinafter.

Preferably the trunk group alloters 70, 72, 74 etc. are substantially identical. For example, the trunk group allotter 70, shown in Figs. 3 and 4 and associated with the group of three by-pass selectors, including the by-pass selector 50, and consequently with the group of three trunks, including the trunk 131, extending to the manual exchange 30 comprises a relay group including three marking relays R310, R330 and R350, three select relays R320, R340 and R360, a number of sets of select slave relays and a reset relay R370; and a control network connected and arranged in a manner more fully explained hereinafter. One of the sets of select slave relays includes the three select slave relays R410, R420 and R430; and another of the sets of select slave relays includes the three select slave relays R440, R450 and R460.

The repeater allotter 73, shown in Figs. 22 and 23, comprises a relay group including three marking relays R2210, R2230 and R2250, three select relays R2220, R2240 and R2260, a number of sets of select slave relays and a reset relay R2270; and a control network connected and arranged in a manner more fully explained hereinafter. One of the sets of select slave relays includes the three select slave relays R2310, R2320 and R2330; and another of the sets of select slave relays includes the three select slave relays R2340, R2350 and R2360.

Preferably the line circuits 80, 81, 82 etc. are substantially identical and are of conventional connection and arrangement.

Preferably the call allotter 90, the link allotter 91 and each of the links 92 etc. are of the all-relay connection and arrangement disclosed in

the copending application of Edward S. Peterson, Serial No. 384,889, filed March 24, 1941.

A better understanding of the connection and arrangement of the telephone system will be facilitated from a consideration of the detailed operation of the various pieces of apparatus incorporated therein incident to the completion of the various calls between the exchanges illustrated, as will appear hereinafter.

10 *Call from the manual exchange 30*

Considering the extension of a call from the manual exchange 30 the operator at the manual position therein first selects an idle cord circuit and inserts the calling plug thereof into the jack terminating an idle trunk extending to the automatic exchange 35, such, for example, as the trunk 131, whereby ground potential is applied to the line conductor C132 of the trunk 131 and consequently to the dial conductor C568 extending to the composite equipment 40. The application of ground potential to the dial conductor C568 completes a circuit, including the contacts 714, the resistor 665 and the contacts 662, for energizing the upper winding of the impulse relay R670, thereby to cause the latter relay to operate. Upon operating, the impulse relay R670 completes, at the contacts 672, an obvious circuit for energizing the winding of the hold relay R630, thereby to cause the latter relay to operate. Upon operating, the hold relay R630 completes, at the contacts 631, an obvious circuit for energizing the winding of the reverse battery relay R620, thereby to cause the latter relay to operate. Upon operating, the reverse battery relay R620 completes, at the contacts 625, an obvious circuit for energizing the winding of the lock relay R610, thereby to cause the latter relay to operate.

Upon operating, the lock relay R610 completes, at the contacts 612, an obvious path, including the contacts 761, for applying ground potential to the tone start conductor C187, thereby to initiate operation of the timing and alarm equipment 800, for a purpose more fully explained hereinafter. Also the lock relay R610 completes, at the contacts 617, an obvious path, including the contacts 526, for applying ground potential to the control conductor C108 of the trunk 105, thereby to mark the by-pass selector 50 as busy to the switches having access thereto. Also the application of ground potential to the control conductor C108 of the trunk 105 completes an obvious circuit for energizing the winding of the marking relay R310 in the trunk group allotter 70, thereby to cause the latter relay to operate, for a purpose more fully explained hereinafter. Further the lock relay R610 completes, at the contacts 618, an obvious circuit for energizing the upper winding of the tone cutoff relay R540 and an obvious multiple circuit, including the contacts 528, for energizing the winding of the switch relay R640, thereby to cause the latter relays to operate. Upon operating, the switch relay R640 completes, at the contacts 641, an obvious circuit for energizing the upper winding of the answer relay R650, thereby to cause the latter relay to operate, the answer relay R650 being of the differential type. Upon operating, the answer relay R650 completes, at the contacts 651, an obvious circuit for energizing the winding of the supervisory relay R660, thereby to cause the latter relay to operate. Upon operating, the supervisory relay R660 completes, at the contacts 661, an alternative circuit, including the

dial conductor C568, the contacts 714 and the resistor 665, for energizing in series the upper and lower windings of the impulse relay R670; and interrupts, at the contacts 662, the previously traced original circuit, including the dial conductor C568, for energizing the upper winding of the impulse relay R670. The application of battery potential by way of the upper and lower windings of the impulse relay R670 in series and the resistor 665 to the dial conductor C568 is effective to give the operator at the manual position in the manual exchange 30 supervision indicating that the by-pass selector 50 has been seized and is in readiness to receive the first digit.

The operator at the manual position in the manual exchange 30 then proceeds to dial the first digit, whereby the impulse relay R670 follows the first digit in an obvious manner. Upon the first restoration of the impulse relay R670 there is interrupted, at the contacts 672, the previously mentioned circuit for energizing the winding of the hold relay R630; however, the latter relay does not restore during impulsing as it is of the slow-to-release type. Also, at the contacts 673, there is completed a circuit, including the contacts 632, 765 and 817, for energizing the winding of the dial relay R730 and a multiple circuit, including the contacts 1071, 1061 and 1051, for energizing the winding of the first counting relay R1040, thereby to cause the relays mentioned to operate. Upon operating, the dial relay R730 completes, at the contacts 732, a path for short-circuiting the lower winding of the answer relay R650 in series with the winding 574 of the repeater 570 in the composite equipment 40; this circuit extending from one terminal of the lower winding of the answer relay R650 by way of the contacts 643, the winding 574 of the repeater 570, the line conductor C106 of the trunk 105, the contacts 732 and the resistors 664 and 663 to the other terminal of the lower winding of the answer relay R650; thereby to improve impulsing over the trunk 131. Also the dial relay R730 completes, at the contacts 731, an obvious circuit for energizing the winding of the dial slave relay R750, thereby to cause the latter relay to operate. Upon operating, the dial slave relay R750 completes, at the contacts 752, an obvious circuit for energizing the lower winding of the dial slave relay R770, thereby to cause the latter relay to operate. Upon operating, the first counting relay R1040 completes, at the contacts 1043, a path for short-circuiting the winding of the first cycle relay R1050, this path extending from ground by way of the contacts 632, 673, 765, 817, 1071, 1061, 1051 and 1043, the winding of R1050, the contacts 1063 and 615 to ground. Also the first counting relay R1040 prepares, at the contacts 1044 etc., connections to the trunk in the first group in the event the last-mentioned trunk is utilized in the system.

Upon the first reoperation of the impulse relay R670 there is completed, at the contacts 672, the previously mentioned circuit for energizing the winding of the hold relay R630, and there is interrupted, at the contacts 673, the previously traced multiple circuits for energizing the windings of the dial relay R730 and the first counting relay R1040, and also the previously traced path for short-circuiting the winding of the first cycle relay R1050. At this time a holding circuit is completed for energizing in series the windings of the first counting relay R1040 and the first cycle relay R1050, this circuit extending from

ground by way of the contacts 615 and 1063, the winding of R1050, the contacts 1043 and the winding of R1040 to battery. When this holding circuit is completed the first counting relay R1040 is retained in its operated position and the first cycle relay R1050 operates. Also it is noted that, when the previously traced circuit for energizing the winding of the dial relay R730 is thus interrupted, the latter relay does not restore immediately as it is of the slow-to-release type. More particularly, the dial relay R730 remains operated during impulsing, thereby to retain operated the dial slave relays R750 and R770 in an obvious manner. Upon operating, the first cycle relay R1050 interrupts, at the contacts 1051, a further point in the previously traced original circuit for energizing the winding of the first counting relay R1040, and prepares, at the contacts 1052, a circuit substantially identical to that previously traced and including the contacts 1042 for energizing the winding of the second counting relay R1030.

The impulse relay R670 then restores and re-operates following the second impulse of the first 25 digit, whereby the second counting relay R1030 is operated, in an obvious manner, and a holding circuit is completed, at the contacts 1033, for energizing the winding thereof in series with the winding of the second cycle relay R1060. This 30 circuit extends from ground by way of the contacts 615 and 1073, the winding of R1060, the contacts 1033 and the winding of R1030 to battery. When this holding circuit is completed the second counting relay R1030 is retained in its 35 operated position and the second cycle relay R1060 operates. Upon operating, the second cycle relay R1060 interrupts, at the contacts 1061, a further point in the previously mentioned original circuit for energizing the winding of the 40 second counting relay R1030, and prepares, at the contacts 1062, a circuit substantially identical to that previously traced and including the contacts 1032 for energizing the winding of the third counting relay R1020. Also the second cycle relay R1060, at the contacts 1063, the previously traced holding circuit for energizing the winding of the first counting relay R1040 in 45 series with the winding of the first cycle relay R1050, thereby to cause the latter relays to restore. In view of the foregoing explanation of the mode of operation of the counting relays R1040 and R1030 in conjunction with the cycle relays R1050 and R1060, it will be understood that the 50 counting relays R1040, R1030, R1020, R1010 etc. are operated successively in accordance with the number of impulses included in the first digit; that, as each counting relay operates, a holding circuit is completed for energizing the winding thereof in series with the winding of the corresponding one of the cycle relays; and that, as each cycle relay operates, it effects the restoration of the preceding cycle relay and the counting relay preceding the last operated counting relay.

At the conclusion of the first digit the impulse 55 relay R670 is retained in its operated position, thereby to retain completed, at the contacts 672, the previously mentioned circuit for energizing the winding of the hold relay R630 and to retain interrupted, at the contacts 673, the previously traced circuit for energizing the winding of the dial relay R730. Shortly thereafter the dial relay R730 restores, the latter relay being of the slow-to-release type, as previously noted. Upon restoring, the dial relay R730 interrupts, at the contacts 732, the previously traced path for short-

circuiting the lower winding of the answer relay R850 in series with the winding 574 of the repeater 570; and interrupts, at the contacts 731, the previously mentioned circuit for energizing the winding of the dial slave relay R750. The dial slave relay R750, being of the slow-to-release type, does not immediately restore. Also the dial relay R730 completes, at the contacts 734, an obvious circuit, including the contacts 751, for energizing the winding of the connect relay R870, thereby to cause the latter relay to operate. Further the dial relay R730 completes, at the contacts 734, a circuit for energizing one of the trunk select relays R830, R840 or R850, depending upon the numerical value of the first digit and whether the corresponding group of trunks selected comprises one or three trunks, in a manner more fully explained hereinafter.

For purpose of illustration, assume that the first digit was 3, whereby the third counting relay R1020 and the third cycle relay R1010 occupy their operated positions. In this event, upon restoring, the dial relay R730 completes, at the contacts 734, a circuit for energizing the winding of the first trunk select relay R850; the third group of trunks comprising only one trunk. The last-mentioned circuit extends from ground by way of the contacts 734, 751 and 1021, C136 and the winding of R850 to battery, whereby the latter relay operates. Upon operating, the connect relay R870 completes, at the contacts 871, an obvious holding circuit, including the contacts 815, for energizing the lower winding thereof; and completes, at the contacts 872, an obvious circuit for energizing the winding of the connect slave relay R860, thereby to cause the latter relay to operate. Upon operating, the first trunk select relay R850 prepares, at the contacts 852, 853 and 854, a connection traced hereinafter to the single trunk in the third group; and completes, at the contacts 851, a path for short-circuiting the winding of the test relay R820. The last-mentioned path extends from ground by way of the contacts 815, the winding of R820, the contacts 851, C136, the contacts 1021, 751 and 734 to ground.

Shortly following the restoration of the dial relay R730 the dial slave relay R750 restores in order to interrupt, at the contacts 752, the previously mentioned circuit for energizing the winding of the dial slave relay R770. However, the dial slave relay R770 does not immediately restore as it is of the slow-to-release type. Also the dial slave relay R750 interrupts, at the contacts 751, the previously traced path for short-circuiting the winding of the test relay R820, whereupon a holding circuit is completed for energizing the winding of the first trunk select relay R850 in series with the winding of the test relay R820. This circuit extends from ground by way of the contacts 815, the winding of R820, the contacts 851 and the winding of R850 to battery. When this holding circuit is completed the first trunk select relay R850 is retained in its operated position and the test relay R820 operates.

During the time interval following the restoration of the dial relay R730 and prior to the restoration of the dial slave relay R750 and the consequent operation of the test relay R820, the idle or busy condition of the single trunk in the third group is tested. More particularly, during this time interval, battery potential is connected by way of the upper winding of the busy relay R810, the contacts 822, 854 and 863, C883 and the contacts 1026 to the control conductor of the single trunk in the third group. In the event the

last-mentioned trunk is busy, ground potential appears upon the control conductor thereof; and, in the event the last-mentioned trunk is idle, battery potential appears upon the control conductor thereof.

First assuming that the single trunk in the third group is busy, the presence of ground potential upon the control conductor thereof completes an obvious circuit substantially identical to that traced above for energizing the upper winding of the busy relay R810, thereby to cause the latter relay to operate. Upon operating, the busy relay R810 completes, at the contacts 814, a holding circuit, including the contacts 619 and 529, for energizing the lower winding thereof. Also the busy relay R810 interrupts, at the contacts 813, a circuit traced hereinafter for energizing the winding of the switch-through relay R760; and interrupts, at the contacts 817, a further point in the previously traced pulsing circuit for operating the counting relays R1040, R1030 etc. Further the busy relay R810 completes, at the contacts 811 and 812, a circuit for returning busy tone current over the trunk 131 extending to the manual position in the manual exchange 30. The last-mentioned circuit extends from ground by way of the contacts 812, the condenser 785, the line conductor C107 of the trunk 105, the winding 573 of the repeater 570, the condenser 575, the winding 574 of the repeater 570, the line conductor C108 of the trunk 105, the condenser 786 and the contacts 811 to the busy tone conductor C873. The busy tone current traversing the windings 573 and 574 of the repeater 570 induces busy tone voltage in the windings 571 and 572 thereof, whereby busy tone current is returned from the windings 571 and 572 of the repeater 570 by way of the condensers 576 and 577 and the line conductors C132 and C133 of the trunk 131 to the manual position in the manual exchange 30 in order to indicate to the operator thereat that the single trunk in the third group is busy at this time. Upon receiving busy tone the operator at the manual position in the manual exchange 30 effects the release of the by-pass selector 50 in a manner more fully explained hereinafter.

Now assuming that the single trunk in the third group is idle, battery potential appearing upon the control conductor thereof completes a path substantially identical to that previously traced for short-circuiting the upper winding of the busy relay R810, thereby positively to prevent operation of the latter relay at this time. Shortly thereafter the test relay R820 operates in order to arrest the testing of the idle or busy condition of the single trunk in the third group, in the manner previously explained. Upon operating, the test relay R820 interrupts, at the contacts 822, the previously traced connection between the upper winding of the busy relay R810 and the control conductor of the single trunk in the third group. Also, upon restoring, the dial slave relay R750 completes, at the contacts 753, a circuit, including the contacts 771 and 816, for energizing the winding of the switch-through relay R760 due to the fact that the busy relay R810 occupies its restored position at this time. When thus energized the switch-through relay R760 operates to interrupt, at the contacts 761, the previously mentioned path for applying ground potential to the tone start conductor C787, thereby to arrest further operation of the timing and alarm equipment 800 at this time. Also the switch-through relay R760 completes,

at the contacts 764, a holding circuit, including the contacts 618 and 625, for energizing the winding thereof; and interrupts, at the contacts 765, a further point in the previously traced pulsing circuit for operating the counting relays R1040 etc. Further the switch-through relay R760 completes, at the contacts 762 and 763, an operative connection between the repeater 570 and the single trunk in the third group. More particularly, one of the line conductors of the single trunk in the third group is connected by way of the contacts 1024, C881, the contacts 861, 852, 762, 671 and 646, C186, the winding 574 of the repeater 570, the contacts 643, the lower winding of the answer relay R650, the resistor 663, the contacts 645, the winding 573 of the repeater 570, C107, the contacts 647, 763, 853 and 862, C882 and the contacts 1025 to the other line conductor of the single trunk in the third group. When this connection is completed the lower winding of the answer relay R650 is energized in a direction opposite to that of the upper winding thereof, whereby the latter relay restores, the answer relay R650 being of the differential type. Also, at this time, the windings 573 and 574 of the repeater 570 included in the previously traced connection extending to the single trunk in the third group are inductively coupled to the windings 571 and 572 of the repeater 570 included in the previously traced connection extending by way of the trunk 131 to the manual position in the manual exchange 30. Hence, at this time, the manual position in the manual exchange 30 is operatively connected to the single trunk in the third group.

Upon restoring, the answer relay R650 interrupts, at the contacts 651, the previously mentioned circuit for energizing the winding of the supervisory relay R660, thereby to cause the latter relay to restore. Upon restoring, the supervisory relay R660 interrupts, at the contacts 661, the previously traced circuit for energizing in series the upper and lower windings of the impulse relay R670; and completes, at the contacts 662, the previously traced original circuit for energizing the upper winding of the impulse relay R670. The consequent reduction in the resistance interposed between battery and the dial conductor C568 is effective to signal the operator at the manual position in the manual exchange 30 that the desired connection is now completed to the single trunk in the third group.

The operator at the manual position in the manual exchange 30 proceeds to dial the second and subsequent digits over the trunk 131, whereby the impulse relay R670 follows the digits mentioned, in the manner previously explained, repeating the digits mentioned at the contacts 671 over the single trunk in the third group to the succeeding switching stages.

In the foregoing explanation of the mode of operation of the by-pass selector 50, it was assumed that the connection was to be extended to the single trunk in the third group; however, the connection might have been extended to the single trunk in any other group or to an idle trunk in any group comprising three trunks. For example, the connection might have been extended to an idle one of the three trunks in the tenth group; in which event the first digit 0 would have been dialed by the operator at the manual position in the manual exchange 30 into the by-pass selector 50 after seizure thereof, in the manner previously explained. Now assuming that the operator at the manual position in the manual exchange 30 has seized the by-pass se-

lector 50 and that the first digit 0 has been dialed thereinto, in the manner previously explained, the tenth counting relay R810 and the first cycle relay R1050 occupy their operated positions. In the

6 present example, shortly following the first digit 0, the dial relay R130 restores in the manner previously explained, thereby to complete, at the contacts 734, a path, including the contacts 751 and 811, for applying ground potential to the 10 group marking conductor C140 extending to the repeater allotter 73, the repeater allotter 73 being associated with the three dial-back repeaters 61 etc. accessible to the incoming trunks 121 etc. in the tenth group.

15 Before continuing with the detailed operation of the by-pass selector 50, reference is had to the repeater allotter 73 and it is pointed out that, when the first dial-back repeater 61 and the incoming trunk 121 extending thereto are 20 idle, the first marking relay R2210 in the repeater allotter 73 occupies its restored position; the incoming trunk 121 being the first of the three comprising the tenth group. The restored first marking relay R2210 in the repeater allot-

25 ter 73 originally completed, at the contacts 2211, a circuit, including the contacts 2271, 2263, 2243 and 2223, for energizing the winding of the first select relay R2220; whereby the latter relay operated to complete, at the contacts 2225, a holding 30 circuit including the contacts 2245, 2265 and 2271 for energizing the winding thereof. The operated first select relay R2220 marks the first incoming trunk 121 of the three constituting the 35 tenth group as idle to the switches having access thereto. More particularly, the operated first select relay R2220 completes, at the contacts 2222, a connection between the group marking conductor C117 and the individual marking conductor C118 extending to the first link 92 in the automatic exchange 35, for a purpose more fully explained hereinafter. Also the first select relay R2220 completes, at the contacts 2227, obvious 40 multiple circuits for energizing the first select slave relays R2310, R2340 etc. in the various sets 45 of three, whereby the latter relays are retained in their operated positions. The operated first select slave relay R2310 retains completed, at the contacts 2311, an obvious connection between the group marking conductor C140 and the individual 50 marking conductor C136. Accordingly, at this time, the repeater allotter 73 has preselected the first incoming trunk 121 of the three constituting the tenth group as the next trunk selectable by the various switches having access thereto.

55 Continuing now with the operation of the by-pass selector 50 it is pointed out that the application of ground potential to the group marking conductor C140 causes ground potential to be returned over the individual marking conductor

60 C136 due to the operated position of the first select slave relay R2310 in the repeater allotter 73, as previously noted. The application of ground potential to the individual marking conductor C136 completes the previously traced circuit for

65 energizing the winding of the first trunk select relay R850, thereby to cause the latter relay to operate in the manner previously explained, whereby an operative connection is ultimately completed between the repeater 570 and the first 70 incoming trunk 121 of the three constituting the tenth group. More particularly, in the present example, ground potential is applied by way of the impedance element I2040 in the dial-back repeater 61, the winding 1919 of the repeater

75 1915 and the contacts 2074 to the line conductor

C123 of the trunk 121; and battery potential is applied by way of the winding of the seizure relay R2050 in the dial-back repeater 61, the winding 1918 of the repeater 1915 and the contacts 2072 to the line conductor C122 of the trunk 121. One of the line conductors of the trunk 121 is connected by way of the contacts 814, C881', the contacts 861, 852, 762, 671, 646, C106, the winding 574 of the repeater 570, the contacts 843, the lower winding of the answer relay R650, the resistor 663, the contacts 845, the winding 573 of the repeater 570, C107, the contacts 847, 763, 853 and 862, C882' and the contacts 815 to the other line conductor of the trunk 121. Accordingly, at this time, the answer relay R650 restores in the manner previously explained. Hence, at this time, an operative connection is completed between the manual position in the manual exchange 30 and the first trunk 121 of the three constituting the tenth group.

Furthermore, at this time, ground potential is applied by way of the contacts 825, 818, 764, 813, 821, 854 and 863, C883' and the contacts 916 to the control conductor C124 of the trunk 121. This application of ground potential to the control conductor C124 of the trunk 121 completes an obvious circuit for energizing the winding of the first marking relay R2210 in the repeater allotter 73, thereby to cause the latter relay to operate. Upon operating, the first marking relay R2210 interrupts, at the contacts 2211, the previously traced original circuit for energizing the winding of the first select relay R2220; and completes, at the contacts 2212, a circuit, including the contacts 2271, 2263, 2243, 2223 and 2231, for energizing the winding of the second select relay R2240 in the event the second dial-back repeater, not shown, is idle at this time, whereby the latter relay operates. Upon operating, the second select relay R2240 completes, at the contacts 2246, a holding circuit, including the contacts 2265 and 2271, for energizing the winding thereof; interrupts, at the contacts 2243, a further point in the previously traced original circuit for energizing the winding of the first select relay R2220; and prepares, at the contacts 2244, a circuit substantially identical to that previously traced for energizing the winding of the third select relay R2260 upon the subsequent operation of the second marking relay R2230. Further the second select relay R2240 interrupts, at the contacts 2245, the previously traced holding circuit for energizing the winding of the first select relay R2220, thereby to cause the latter relay to restore. Upon restoring, the first select relay R2220 interrupts, at the contacts 2222, the previously traced connection between the group marking conductor C117 and the individual marking conductor C118 extending to the first link 92 in the automatic exchange 35. Also the first select relay R2220 interrupts, at the contacts 2227, the previously traced multiple circuits for energizing the windings of the first select slave relays R2310, R2340, etc., in the various sets, thereby to cause the latter relays to restore. Upon restoring, the first select slave relay R2310 interrupts, at the contacts 2311, the previously mentioned connection between the group marking conductor C140 and the individual marking conductor C136, whereby the first trunk 121 of the three in the tenth group is marked as busy to the subsequent use of the by-pass selector 50.

Also, upon operating, the second select relay R2240 completes, at the contacts 2241, obvious multiple circuits for energizing the windings of the second select slave relays R2320, R2350, etc., in the different sets, thereby to effect operation of the relays mentioned. Upon operating, the second select slave relay R2320 completes, at the contacts 2321, an obvious connection between the group marking conductor C140 and the individual marking conductor C137, thereby to mark the second trunk of the three in the tenth group as idle to the subsequent use of the by-pass selector 50.

Again referring to the operation of the by-pass selector 50 it is noted that, in the event the second trunk of the three constituting the tenth group had been preselected by the repeater allotter 73, the by-pass selector 50 would have operated to select the last-mentioned trunk 20 instead of the first trunk 121 in this group. More particularly, in this event, the group marking conductor C140 would have been connected by way of the contacts 2321 to the individual marking conductor C137 in the repeater allotter 25 73, in the manner explained above. Accordingly, in this event, the application of ground potential to the group marking conductor C140 would have been effective to cause ground potential to be applied to the individual marking conductor C137, whereby the second trunk 30 select relay R840 in the by-pass selector 50 would have operated in order to effect the seizure of the second trunk of the three constituting the tenth group, in an obvious manner.

Continuing now with the operation of the repeater allotter 73 it is pointed out that subsequently, when the second trunk of the three constituting the tenth group is taken for use, the second marking relay R2230 operates in order 35 to effect the restoration of the second select relay R2240 and the second select slave relays R2320, R2350, etc., and to effect operation of the third select relay R2260 and the third select slave relays R2330, R2360, etc., all in the manner previously explained. When the third select relay R2260 and the third select slave relays R2330, R2360, etc., occupy their operated positions the third trunk of the three constituting the tenth group is preselected to the use of the switches 50 having access thereto. Subsequently, when the third trunk of the three constituting the tenth group is taken for use the third marking relay R2250 is operated, in the manner previously explained. Upon operating, the third marking relay R2250 interrupts, at the contacts 2251, a previously completed holding circuit, including the contacts 2264 and 2271, for energizing the winding of the third select relay R2260. However, the latter relay does not restore at this time due to 55 the previous completion of an alternative holding circuit, including the contacts 2271 and 2266, for energizing the winding thereof. Further the third marking relay R2250 prepares, at the contacts 2252, a circuit for energizing the winding 60 of the reset relay R2270 in series with the winding of either the first select relay R2220 or the second select relay R2240, depending upon the restored positions of the respective first marking relay R2210 and the second marking relay R2230. 65 More particularly, in the event the first trunk of the three constituting the tenth group is idle at this time, the first marking relay R2210 occupies its restored position and the previously mentioned circuit for energizing the winding of the 70 reset relay R2270 in series with the winding of 75

the first select relay R2220 is completed. The last-mentioned circuit extends from ground by way of the contacts 2271, 2264 and 2252, the winding of R2270, the contacts 2211 and the winding of R2220 to battery. When this series circuit is completed the first select relay R2220 operates immediately and the reset relay R2270 operates shortly thereafter, the latter relay being of the slow-to-operate type. Upon operating, the reset relay R2270 interrupts, at the contacts 2271, the previously traced holding circuit, including the contacts 2268, for energizing the winding of the third select relay R2260, thereby to cause the latter relay to restore. Also the reset relay R2270 interrupts, at the contacts 2271, the previously traced series circuit for energizing the winding thereof and the winding of the first select relay R2220, thereby to cause the relays mentioned to restore. Upon restoring, the reset relay R2270 completes, at the contacts 2271, an original operating circuit for energizing the winding of the first select relay R2220; the last-mentioned circuit extending from ground by way of the contacts 2271, 2265, 2245, 2224 and 2211 and the winding of R2220 to battery. When thus energized the first select relay R2220 reoperates to complete, at the contacts 2223 and 2225, the two previously traced holding circuits for energizing the winding thereof. Accordingly, at this time, the first trunk 121 of the three constituting the tenth group is again preselected for use by the switches having access thereto.

In view of the foregoing explanation of the mode of operation of the repeater allotter 13 to reset the first select relay R2220 in the event the first marking relay R2210 occupies its restored position, it will be understood that this apparatus is operative in a substantially identical manner to reset the second select relay R2240, in the event the first marking relay R2210 occupies its operated position and the second marking relay R2230 occupies its restored position. Finally, in this connection, it is pointed out that, in the event both the first marking relay R2210 and the second marking relay R2230 occupy their operated positions when the third trunk of the three constituting the tenth group is taken for use, the reset relay R2270 is not operated and the third select relay R2260 is retained in its operated position. In this event, when all three of the trunks constituting the tenth group are busy, the repeater allotter 13 cannot be reset to preselect an idle trunk of the three constituting the tenth group. Accordingly, the third select relay R2260 is retained in its operated position, whereby the busy third trunk of the three constituting the tenth group is marked for seizure to the automatic switches having access thereto.

Again considering the operation of the by-pass selector 50, it is pointed out that, in the event all three of the trunks constituting the tenth group are busy incident to the restoration of the dial relay R710 therein, the ground potential applied to the group marking conductor C140 is connected in the repeater allotter 13 to one of the individual marking conductors C138, etc., thereby to effect operation of the corresponding trunk select relay R850, etc. In this event, the operating trunk select relay R850, etc., connects the busy preselected trunk of the three constituting the tenth group to the by-pass selector 50, whereby operation of the busy relay R810 is effected, in the manner previously explained. Upon operating, the busy relay R810 causes busy

tone current to be returned to the manual position in the manual exchange 30, thereby to indicate to the operator thereat that all three of the trunks constituting the tenth group are busy at this time.

Again referring to the operation of the repeater allotter 13 it is noted that, when one of the three trunks constituting the tenth group becomes idle, the corresponding marking relay R2210, etc., restores, whereby the reset relay R2270 and the corresponding select relay R2220, etc., are operated in the manner previously described, whereby the repeater allotter 13 is operated to preselect an idle trunk of the three constituting the tenth group for the use of the automatic switches having access thereto.

In connection with the operation of the by-pass selector 50 to select an idle trunk of the three constituting the tenth group, it is again noted that, when all of the trunks in the group mentioned are busy, the busy relay R810 operates. Subsequently, when the dial slave relay R750 restores it completes, at the contacts 753, a path, including the contacts 771, 815 and 913, for applying ground potential to the trunk overflow conductor C172. Also the dial slave relay R750 interrupts, at the contacts 162, the previously mentioned circuit for energizing the winding of the dial slave relay R710, thereby to cause the latter relay to restore shortly thereafter, the dial slave relay R710 being of the slow-to-release type. Upon restoring, the dial slave relay R710 interrupts, at the contacts 771, the previously mentioned path for applying ground potential to the trunk overflow conductor C172. The momentary application of ground potential to the trunk overflow conductor C172 completes a circuit, including either the contacts 1792 or 1897, for operating the trunk overflow meter M1825 in order to indicate the attempted extension of a call by way of a trunk of the three constituting the tenth group when all of the trunks in the group mentioned are busy.

As previously explained, when the trunk 131 and consequently the by-pass selector 50 were seized by the operator at the manual position in the manual exchange 30, the first marking relay R310 in the trunk group allotter 10 operated. Prior to the operation of the first marking relay R310 the first select relay R320 occupied its operated position, the last-mentioned relay being held in its operated position by way of a first holding circuit for energizing the winding thereof, including the contacts 371, 363, 343, 323 and 311, and by way of a second holding circuit for energizing the winding thereof, including the contacts 371, 365, 345 and 325. The operated first select relay R320 remained completed, at the contacts 322, an obvious connection between the group marking conductor C101 and the individual marking conductor C102 extending to the first link 82 in the automatic exchange 35, thereby to preselect the first trunk 105 of the three in the eighth group to the use of the first link 82. Also the operated first select relay R320 retained completed, at the contacts 327, obvious multiple circuits for retaining operated the first select slave relays R410, R440, etc., in the various sets. The operated first select slave relay R410 retained completed, at the contacts 411, an obvious connection between the group marking conductor C151 and the individual marking conductor C158, whereby the trunk group allotter 10 has pre-selected the first trunk 105 of the three in the

eighth group to the use of the incoming selector 53, in the manner previously explained.

Upon operating, the marking relay R310 interrupts, at the contacts 311, one of the previously traced holding circuits for energizing the winding of the first select relay R320; and completes, at the contacts 312, an obvious circuit for energizing the winding of the second select relay R340, thereby to cause the latter relay to operate and effect the restoration of the first select relay R320. Upon restoring, the first select relay R320 effects the restoration of the first select slave relays R410, R440, etc.; and, upon operating, the second select relay R340 effects operation of the second select slave relays R420, R450, etc., in the various sets. Also, upon operating, the second select relay R340 completes, at the contacts 342, an obvious connection between the group marking conductor C101 and the individual marking conductor C103 extending to the first link 92 in the automatic exchange 35, thereby to preselect the second trunk of the three comprising the eighth group to the use of the first link 92. Upon operating, the second select slave relay R420 completes, at the contacts 421, an obvious connection between the group marking conductor C161 and the individual marking conductor C159, thereby to preselect the second trunk of the three comprising the eighth group to the use of the incoming selector 53. Accordingly, at this time, when the trunk 131 is rendered busy the by-pass selector 50 and also the first trunk 105 of the three comprising the eighth group are rendered busy. When the first trunk of the three comprising the eighth group is rendered busy the trunk group allotter 10 operates in order to preselect the next idle trunk of the three comprising the eighth group to the use of the automatic switches having access thereto.

As previously explained, during the operation of the counting relays R1040, etc., incident to the dialing of the first digit into the by-pass selector 50, one of the counting relays operates, then the succeeding counting relay operates in order to effect restoration of the preceding counting relay. Hence, at any time, any two adjacent counting relays may momentarily occupy their operated positions. For example, the counting relays R910 and R920 momentarily occupy operated positions incident to the dialing of the first digit 0 and prior to the restoration of the ninth counting relay R920. In order to prevent the ninth counting relay R920 and the tenth counting relay R910 from momentarily connecting together the corresponding ones of the trunks in the respective ninth and tenth groups, an improved arrangement is provided for isolating the corresponding trunks in adjacent ones of the groups. For example, the first trunk 113 in the ninth group is connected by way of the contacts 924, 925 and 926 by the ninth counting relay R920 to the conductors C881, C882 and C883; while the first trunk 121 in the tenth group is connected by way of the contacts 914, 915 and 916 by the tenth counting relay R910 to the conductors C881', C882' and C883'. Subsequently, the connect slave relay R860 connects the two sets of conductors C881, C882, C883 and C881', C882', C883' together at the contacts 861, 862 and 863. However, at this time, the ninth counting relay R920 has had ample time to restore in order to effect the disconnection of the first trunk 113 in the ninth group from the conductors C881, C882 and C883. Hence, this improved arrangement of the two sets of conductors C881, C882, C883 and

C881', C882', C883' positively prevents corresponding ones of the trunks in adjacent ones of the groups from being momentarily connected together incident to the successive operations of the various counting relays R1040, etc. It will be readily understood that this arrangement positively prevents two corresponding busy trunks in two adjacent groups from being momentarily connected together, incident to the operation of the counting relays R1040, etc., in the by-pass selector 50, and the consequent annoyance to the persons conversing over the corresponding trunks in the two adjacent groups mentioned.

Again continuing with the operation of the by-pass selector 50, assume for convenience that the first-mentioned connection is completed from the manual position in the manual exchange 30 to the single trunk constituting the third group. When the called connection is released the previously traced circuit, including the single trunk in the third group, for energizing the lower winding of the answer relay R650 is interrupted, thereby to cause the latter relay to operate, the answer relay R650 being of the differential type, as previously noted. Upon operating, the answer relay R650 recompletes, at the contacts 651, the previously mentioned circuit for energizing the winding of the supervisory relay R660, thereby to cause the latter relay to reoperate. Upon reoperating, the supervisory relay R660 interrupts, at the contacts 662, the previously traced path for applying battery potential by way of the upper winding of the impulse relay R670 to the dial conductor C568; and recompletes, at the contacts 661, the previously traced path for applying battery potential by way of the upper and lower windings of the impulse relay R670 in series to the dial conductor C568, whereby the resistance of the battery connection to the dial conductors C568 is increased in order to signal the operator at the manual position in the manual exchange 30 indicating that the called connection has been released.

The operator at the manual position in the manual exchange 30 then withdraws the calling plug of the cord circuit from the jack terminating the trunk 131, whereby ground potential is removed from the dial conductor C568 in order to interrupt the previously traced circuit for energizing in series the upper and lower windings of the impulse relay R670. The impulse relay R670 then restores to interrupt, at the contacts 672, the previously mentioned circuit for energizing the winding of the hold relay R630, thereby to cause the latter relay to restore shortly thereafter, the hold relay R630 being of the slow-to-release type. Upon restoring, the hold relay R630 interrupts, at the contacts 631, the previously mentioned circuit for energizing the winding of the reverse battery relay R620, thereby to cause the latter relay to restore. Upon restoring, the reverse battery relay R620 interrupts, at the contacts 625, the previously mentioned circuit for energizing the winding of the lock relay R610 and the previously traced holding circuit for energizing the winding of the switch-through relay R760, thereby to cause the latter relays to restore. Upon restoring, the lock relay R610 interrupts, at the contacts 619, the previously traced multiple circuits for energizing the upper winding of the tone cut-off relay R540 and the winding of the switch relay R640, thereby to cause the latter relays to restore. Also the lock relay R610 interrupts, at the contacts 615, the previously traced holding circuit for energizing the

winding of the test relay R820 in series with the winding of the first trunk select relay R850 and the previously traced holding circuit for energizing the lower winding of the connect relay R870, thereby to cause the latter relays to restore. Further the lock relay R610 interrupts, at the contacts 615, the previously traced holding circuit for energizing the winding of the third cycle relay R1070 in series with the winding of the third counting relay R1020, thereby to cause the latter relays to restore. Further the lock relay R610 interrupts, at the contacts 617, the previously mentioned path for applying ground potential to the control conductor C108 of the first trunk 105 of the three comprising the eighth group, thereby to effect the restoration of the first marking relay R310 in the trunk group allotter 70. The switch-through relay R760, being of the slow-to-release type, restores shortly following the restoration of the reverse battery relay R620; and interrupts, at the contacts 762 and 763, further points in the previously traced connection between the repeater 570 in the single trunk comprising the third group. Upon restoring, the switch relay R640 interrupts, at the contacts 641, the previously mentioned circuit for energizing the upper winding of the answer relay R650, thereby to cause the latter relay to restore. Upon restoring, the answer relay R650 interrupts, at the contacts 651, the previously mentioned circuit for energizing the winding of the supervisory relay R660, thereby to cause the latter relay to restore. Upon restoring, the supervisory relay R660 interrupts, at the contacts 661, the previously traced connection for applying battery potential by way of the upper and lower windings of the impulse relay R670 in series to the dial conductor C568; and recomplete, at the contacts 662, the previously traced connection for applying battery potential by way of the upper winding of the impulse relay R670 to the dial conductor C568. Upon restoring, the third counting relay R1020 interrupts, at the contacts 1024, etc., the previously traced connection between the single trunk comprising the third group and the conductors C881, etc. Upon restoring, the connect relay R870 interrupts, at the contacts 872, the previously mentioned circuit for energizing the winding of the connect slave relay R860, thereby to cause the latter relay to restore. Upon restoring, the connect slave relay R860 interrupts, at the contacts 861, etc., 864, etc., and 867, etc., further connections between the by-pass selector 50 and the conductors to which the various trunks in the different groups are connected by the various counting relays R1040, etc. At this time the connection from the manual position in the manual exchange 30 to the single trunk comprising the third group is completely released; the by-pass selector 50 is completely released and available for further use; the trunk 131 is marked as idle to the manual position in the manual exchange 30; and the first trunk 105 of the three comprising the eighth group is marked as idle to be preselected subsequently by the trunk group allotter 70 to the use of the various automatic switches having access thereto.

Call to the manual exchange 30

Considering the extension of a call to the manual exchange 30, the calling automatic switch is operated to select an idle trunk of the three constituting the eighth group under the control of the trunk group allotter 70, in the manner

previously explained. In the present example, the first select relay R320 in the trunk group allotter 70 occupies its operated position, whereby the first trunk 105 of the three constituting the eighth group is preselected to the use of the calling switch. Hence, the calling switch is governed to seize the first trunk 105 extending to the first by-pass selector 50. When the trunk 105 is thus seized by the calling switch a circuit is completed for energizing the winding of the seizure relay R550, this circuit extending from ground by way of the impedance element I555, the contacts 624 and 644 and the winding 573 of the repeater 570 to the line conductor C107 of the trunk 105 and from battery by way of the winding of R550, the contacts 622 and 642 and the winding 574 of the repeater 570 to the line conductor C106 of the trunk 105, the line conductors C106 and C107 of the trunk 105 being connected together in the calling switch. When thus energized the seizure relay R550 operates to complete, at the contacts 552, an obvious circuit for energizing the winding of the supervisory relay R660, thereby to cause the latter relay to operate. Also the seizure relay R550 completes, at the contacts 551, an obvious circuit for energizing the winding of the ring start relay R530, thereby to cause the latter relay to operate.

Upon operating, the supervisory relay R660 interrupts, at the contacts 662, the previously traced connection including the upper winding of the impulse relay R670 to the dial conductor C568; and completes, at the contacts 661, the previously traced connection including the upper and lower windings of the impulse relay R670 in series to the dial conductor C568. Upon operating, the ring start relay R530 completes, at the contacts 531, an obvious path, including the contacts 613 and 541, for applying ground potential to the motor start conductor C565 extending to the timing and alarm equipment 800, thereby to initiate operation of the latter equipment at this time. Also the ring start relay R530 completes, at the contacts 532, an obvious circuit for energizing the winding of the ring start slave relay R520, thereby to cause the latter relay to operate. Upon operating, the ring start slave relay R520 completes, at the contacts 522, an obvious path for applying ground potential to the timer start conductor C562 extending to the timing and alarm equipment 800, thereby to initiate operation of the timing apparatus in the last-mentioned equipment; and completes, at the contacts 521, an obvious connection including the contacts 611 between the upper winding of the timer relay R510 and the timer conductor C564 extending to the timing and alarm equipment 800, for a purpose more fully explained hereinafter. Also the ring start slave relay R520 completes, at the contacts 523, a circuit, including the contacts 741, for energizing the winding of the ring relay R710; thereby to cause the latter relay to operate shortly thereafter, the ring relay R710 being of the slow-to-operate type. Further the ring start slave relay R520 completes, at the contacts 524, a connection including the contacts 542, the condenser 561, the contacts 616 and 733 between the ring tone conductor C566 and the line conductor C106 of the trunk 105; whereby ring tone is returned over the line conductor C106 of the trunk 105 to the calling switch in order to indicate that the manual position in the manual exchange 30 is being rung. Further the ring start slave relay R520 completes, at the contacts 528, an obvious path, including the contacts 515, for applying

ground potential to the control conductor **C103** of the trunk **105** in order to effect operation of the first marking relay **R310** in the trunk group allotter **10**, for the purpose previously explained.

Upon operating, the ring relay R710 interrupts, at the contacts 714, the previously traced connection including the upper and lower windings of the impulse relay R670 in series and the dial conductor C568; and completes, at the contacts 713, a connection including the resistor 782 between the generator conductor C181 and the dial conductor C568. Also the ring relay R710 completes, at the contacts 711, an obvious circuit for energizing the winding of the shunt relay R720, thereby to cause the latter relay to operate shortly thereafter, the shunt relay R720 being of the slow-to-operate type. Further the ring relay R710 completes, at the contacts 712, a circuit, including the ring conductor C181, the contacts 743 and the condenser 784, for energizing the upper winding of the splash relay R740, thereby to cause the latter relay to operate. Upon operating, the shunt relay R720 completes, at the contacts 721, a path, including the resistors 183 and 665 and the contacts 661, for short-circuiting in series the upper and lower windings of the impulse relay R670. Upon operating, the splash relay R740 completes, at the contacts 742, an obvious holding circuit, including the contacts 523, for energizing the lower winding thereof; interrupts, at the contacts 743, the previously traced original circuit for energizing the upper winding thereof; and interrupts, at the contacts 741, the previously traced circuit for energizing the winding of the ring relay R710, thereby to cause the latter relay to restore. Upon restoring, the ring relay R710 interrupts, at the contacts 711, the previously mentioned circuit for energizing the winding of the shunt relay R720, thereby to cause the latter relay to restore. Also the ring relay R710 interrupts, at the contacts 713, the previously traced connection between the generator conductor C181 and the dial conductor C568; and recompletes, at the contacts 714, the previously traced connection between the upper and lower windings of the impulse relay R670 and the dial conductor C568. Upon restoring, the shunt relay R720 interrupts, at the contacts 721, the previously traced path for short-circuiting in series the upper and lower windings of the impulse relay R670. It is noted that the operation and subsequent restoration of the shunt relay R720 positively prevent operation of the impulse relay R670 during the short time interval in which the generator conductor C181 is connected to the dial conductor C568.

The generator potential projected over the dial conductor C568 and the line conductor C132 of the trunk 131 transmits a called signal to the manual position in the manual exchange 30; and when the operator thereat answers the call by inserting the answering plug of an idle cord circuit into the jack terminating the trunk 131 the previously traced circuit for energizing in series the upper and lower windings of the impulse relay R670 is completed, thereby to effect operation of the latter relay. Upon operating, the impulse relay R670 completes, at the contacts 672, the previously mentioned circuit for energizing the winding of the hold relay R630, thereby to cause the latter relay to operate. Upon operating, the hold relay R630 completes, at the contacts 631, the previously mentioned circuit for energizing the winding of the reverse battery relay R620, thereby to cause the latter relay to operate. Upon operating, the reverse battery

relay R620 completes, at the contacts 625, the previously mentioned circuit for energizing the winding of the lock relay R610, thereby to cause the latter relay to operate. Also the reverse battery relay R620 interrupts, at the contacts 624 and 622, the previously traced original circuit for applying ground and battery potentials by way of the impedance element I555 and the winding of the seizure relay R550 to the line conductors C107 and C106 of the trunk 105; and completes, at the contacts 621 and 623, alternative paths for applying ground and battery potentials by way of the impedance element I555 and the winding of the seizure relay R550 to the conductors C106 and C107 of the trunk 105, whereby the application of battery potential over the line conductors of the trunk 105 is reversed to the calling switch for supervisory purposes.

Upon operating, the lock relay R610 interrupts, at the contacts 611, the previously traced path for applying battery potential by way of the upper winding of the timing relay R510 to the timer conductor C564; interrupts, at the contacts 613, the previously mentioned path for applying ground potential to the motor start conductor C565; and interrupts, at the contacts 616, the previously traced path for projecting ring tone current over the line conductor C106 of the trunk 105. Also the lock relay R610 completes, at the contacts 619, an obvious circuit for energizing the upper winding of the tone cut-off relay R540, thereby to cause the latter relay to operate. Upon operating, the cut-off relay R540 completes, at the contacts 543, an obvious holding circuit, including the contacts 532, for energizing the lower winding thereof; and interrupts, at the contacts 542, a further point in the previously traced path for projecting ring tone over the line conductor C106 of the trunk 105. At this time an operative connection is completed from the calling switch by way of the trunk 105, the by-pass selector 50 and the trunk 131 to the manual position in the manual exchange 30.

45 The release of the established connection from the calling switch to the manual position in the manual exchange 30 may be first initiated by the operator at the manual position in the manual exchange 30 by withdrawing the answer plug of the trunk 131; whereby ground potential is removed from the dial conductor C568 in order to effect the restoration of the impulse relay R670. Upon restoring, the impulse relay R670 interrupts, at the contacts 672, the previously mentioned circuit for energizing the winding of the hold relay R630, thereby to effect the restoration of the latter relay shortly thereafter. Upon restoring, the hold relay R630 interrupts, at the contacts 631, the previously mentioned circuit for energizing the winding of the reverse battery relay R620, thereby to cause the latter relay to restore. Upon restoring, the reverse battery relay R620 interrupts, at the contacts 625, the previously mentioned circuit for energizing the winding of the lock relay R610, thereby to cause the latter relay to restore. Also the reverse battery relay R620 effects the reversal of battery potential over the line conductors of the trunk 105 at the contacts 621, 623 and 622, 624, in the manner previously explained, in order to effect supervision over the calling switch. Upon restoring, the lock relay R610 recompletes, at the contacts 611, the previously traced connection for applying battery potential by way of the upper winding of the timing relay R510 to the timer con-

ductor C564; and interrupts, at the contacts 619, the previously mentioned original operating circuit for energizing the upper winding of the tone cut-off relay R540.

Subsequently, when the calling switch is released the previously traced circuit for energizing the winding of the seizure relay R550 is interrupted, thereby to cause the latter relay to restore. Upon restoring, the seizure relay R550 interrupts, at the contacts 551, the previously mentioned circuit for energizing the winding of the ring start relay R530, thereby to cause the latter relay to restore shortly thereafter, the ring start relay R530 being of the slow-to-release type. Also the seizure relay R550 interrupts, at the contacts 552, the previously mentioned circuit for energizing the winding of the supervisory relay R660, thereby to cause the latter relay to restore. Upon restoring, the supervisory relay R660 interrupts, at the contacts 661, the previously traced path for applying battery potential by way of the upper and lower windings of the impulse relay R670 in series to the dial conductor C568; and recomplete, at the contacts 662, the previously traced path for applying battery potential by way of the upper winding of the impulse relay R670 to the dial conductor C568. Upon restoring, the ring start relay R530 interrupts, at the contacts 531, the previously mentioned path for applying ground potential to the motor start conductor C565; and interrupts, at the contacts 532, the previously mentioned circuit for energizing the winding of the ring start slave relay R520 and the previously mentioned holding circuit for energizing the lower winding of the tone cut-off relay R540, thereby to cause the latter relays to restore. Upon restoring, the ring start slave relay R520 interrupts, at the contacts 523, the previously traced holding circuit for energizing the lower winding of the splash relay R740, thereby to cause the latter relay to restore. Also the ring start slave relay R520 interrupts, at the contacts 521, the previously traced connection for applying battery potential by way of the upper winding of the timing relay R510 to the timer conductor C564; and interrupts, at the contacts 528, the previously traced path for applying ground potential to the control conductor C108 of the trunk 105, thereby to effect the restoration of the first marking relay R310 in the trunk group allotter 70, for the purpose previously explained. Upon restoring, the first marking relay R310 marks the first trunk 105 of the three comprising the eighth group as idle, whereby the last-mentioned trunk may be subsequently pre-selected for allotment by the trunk group allotter 70 to the automatic switches having access thereto.

On the other hand, the release of the established connection from the calling switch to the manual position in the manual exchange 30 may be first initiated by the release of the calling switch, whereby the previously traced circuit for energizing the winding of the seizure relay R550 is interrupted in order to cause the latter relay to restore. Upon restoring, the seizure relay R550 interrupts, at the contacts 551, the previously mentioned original circuit for energizing the winding of the ring start relay R530. Also the seizure relay R550 interrupts, at the contacts 552, the previously mentioned circuit for energizing the winding of the supervisory relay R660, thereby to cause the latter relay to restore. Upon restoring, the supervisory relay R660 effects, at the contacts 661 and 662, the removal

of high resistance battery potential and the application of low resistance battery potential to the dial conductor C568, in the manner previously explained, whereby a supervisory signal is transmitted to the manual position in the manual exchange 30.

Upon receiving the disconnect supervision the operator at the manual position in the manual exchange 30 withdraws the answer plug of the 10 cord circuit from the jack terminating the trunk 131, whereby ground potential is removed from the dial conductor C568 in order to effect the restoration of the impulse relay R670, in the manner previously explained. Upon restoring, the 15 impulse relay R670 effects the restoration of the hold relay R630 shortly thereafter, which latter relay effects the restoration of the reverse battery relay R620, all in the manner previously explained. Upon restoring, the reverse battery relay R620 effects the restoration of the lock relay R610. The lock relay R610 interrupts, at the contacts 614, the previously traced holding circuit for energizing the winding of the ring start relay R530, thereby to cause the latter relay to restore shortly thereafter. Upon restoring, the ring start relay R530 effects the restoration of the ring start slave relay R520 and the tone cut-off relay R540, in the manner previously explained. Upon restoring, the ring start slave 20 relay R520 interrupts, at the contacts 523, the previously traced holding circuit for energizing the lower winding of the splash relay R740, thereby to cause the latter relay to restore. Also the ring start slave relay R520 interrupts, at the contacts 528, the previously traced path for applying ground potential to the control conductor C108 of the trunk 105, thereby to effect the restoration of the first marking relay R310 in the 25 trunk group allotter 70, for the purpose previously explained. Upon restoring, the ring start slave relay R520 interrupts, at the contacts 522, the previously mentioned path for applying ground potential to the timer start conductor C562. At this time the connection from the calling switch 30 to the manual position in the manual exchange 30 is completely released; the by-pass selector 50 is completely released; the trunk 131 is marked as idle; and the first trunk 105 of the three constituting the eighth group is marked as idle subsequently to be allotted by the trunk group allotter 70 to the automatic switches having access thereto.

Reconsidering now the operation of the by-pass selector 50 incident to the seizure of the trunk 105 by the calling switch, it is pointed out that the seizure relay R550 operates and effects operation of the supervisory relay R660 and the ring start relay R530. Upon operating, the ring start relay R530 completes, at the contacts 531, the previously traced path for applying ground potential to the motor start conductor C565 and effects operation of the ring start slave relay R520. Upon operating, the ring start slave relay R520 effects operation of the ring relay R710 and completes, at the contacts 521, the previously traced connection for applying battery potential by way of the upper winding of the timing relay R510 to the timer conductor C564; completes, at the contacts 522, the previously mentioned path for applying ground potential to the timer start conductor C562; completes, at the contacts 524, the previously traced path for connecting ring tone to the line conductor C106 of the trunk 105; and completes, at the contacts 528, the previously traced path for applying ground poten-

tial to the control conductor C108 of the trunk 105. Upon operating, the ring relay R710 effects operation of the shunt relay R720 and the splash relay R740 and causes generator potential to be projected over the dial conductor C568 to the manual position in the manual exchange 30. Upon operating, the splash relay R740 effects the restoration of the ring relay R710 and the latter relay effects the restoration of the shunt relay R720.

When the operator at the manual position in the manual exchange 30 answers the call the impulse relay R670 operates in order to effect operation of the hold relay R630, the hold relay R630 effects operation of the reverse battery relay R620, which latter relay effects operation of the lock relay R610. The lock relay R610 effects operation of the tone cut-off relay R540, all in the manner previously explained. At this time, the previously traced connection between the calling switch and the manual position in the manual exchange 30 is completed and, in the event the operator thereat is unable to converse with a calling party, she surmises that the call was originated on the trunk 105 by the presence of a permanent fault thereon. The operator at the manual position in the manual exchange 30 then withdraws the answer plug of the cord circuit from the jack terminating the trunk 131, thereby to effect the restoration of the impulse relay R670 and the consequent restoration of the hold relay R630. Upon restoring, the hold relay R630 effects the restoration of the reverse battery relay R620 and the latter relay effects the restoration of the lock relay R610, all in the manner previously explained. Upon restoring, the lock relay R610 completes, at the contacts 611, the previously traced connection for applying battery potential by way of the upper winding of the timing relay R510 to the timer conductor C564.

During the course of operation of the timing and alarm equipment 800 ground potential is applied to the timer conductor C564, thereby to complete an obvious circuit, including the contacts 512, 521 and 611, for energizing the upper winding of the timing relay R510 in order to cause the latter relay to operate. Upon operating, the timing relay R510 completes, at the contacts 511, a holding circuit, including the contacts 521 and 611, for energizing the upper winding thereof. Also the timing relay R510 interrupts, at the contacts 515, the previously traced path for applying ground potential to the control conductor C108 of the trunk 105; and completes, at the contacts 514, an alternative path for connecting the grounded control conductor C561 extending from the timing and alarm equipment 800 to the control conductor C108 of the trunk 105, the last-mentioned connection including the contacts 528. Subsequently, during the operation of the timing and alarm equipment 800, ground potential is removed from the control conductor C561 and consequently from the control conductor C108 of the trunk 105 in order to effect the release of the calling switch. When the calling switch is thus released the seizure relay R550 restores in order to effect the release of the supervisory relay R660 and the ring start relay R530; and the latter relay effects the restoration of the ring start slave relay R520 and the tone cut-off relay R540. Upon restoring, the ring start slave relay R520 effects the restoration of the splash relay R740; and interrupts, at the contacts 521, the previously traced holding

circuit for energizing the upper winding of the timing relay R510, thereby to cause the latter relay to restore. At this time the by-pass selector 50 is again completely released, the trunk

5 131 is marked as idle and the first trunk 105 of the three comprising the eighth group is marked as idle for subsequent allotment by the trunk group allotter 70, all in the manner previously explained.

10

Call from the manual exchange 33

Considering the extension of a call from the manual exchange 33, the operator at the toll position therein first selects an idle cord circuit and 15 inserts the call plug thereof into the jack terminating an idle toll line extending to the automatic exchange 35, such, for example, as the toll line 143; whereby ground potential is applied to the line conductor C145 of the toll line 143 and consequently to the dial conductor C1278 extending to the composite equipment 43. The application of ground potential to the dial conductor C1278 completes a circuit, including the resistor 1280 and the contacts 1233 and 1222, for 20 energizing the lower winding of the impulse relay R1240 in the toll line circuit 60, thereby to cause the latter relay to operate. Upon operating, the impulse relay R1240 completes, at the contacts 1242, an obvious circuit for energizing the winding of the hold relay R1250, thereby to cause the latter relay to operate. Also, the impulse relay R1240 completes, at the contacts 1243, a loop circuit for energizing the upper and lower windings 25 of the line relay R1330 in the incoming selector 53 in series with the left-hand winding of the answer relay R1220 in the toll line circuit 60, the incoming selector 53 being individual to the toll line circuit 60 and being connected thereto by way of the trunk 146. The last-mentioned circuit extends from ground by way of the upper winding of the line relay R1330, the contacts 30 1221, the line conductor C148 of the trunk 146, the contacts 1243 and 1235, the winding 1272 of the repeater 1270, the left-hand winding of R1220, 35 the contacts 1231, the winding 1271 of the repeater 1270, the contacts 1231, the line conductor C147 of the trunk 146, the contacts 1225 and the lower winding of R1330 to battery. When this series circuit is completed the line relay R1330 in the incoming selector 53 operates. Upon operating, the hold relay R1250 completes, at the contacts 1251, an obvious circuit for energizing the right-hand winding of the answer relay R1220; however, the latter relay does not operate at this time

40 as it is of the polarized type. Also, the hold relay R1250 completes, at the contacts 1253, a circuit, including the contacts 1261, the control conductor C153 of the trunk 150 and the contacts 1711, for energizing the winding of the busy relay R1720 in the trunk distributor 1700 forming a part of the dial-back repeater 61, the dial-back repeater 61 having access to the trunk 150 individually extending to the toll line circuit 60. When thus energized the busy relay R1720 operates.

45 55 Prior to continuing with the operation of the incoming selector 53, operation of the trunk distributor 1700 forming a part of the dial-back repeater 61 will be considered. In the trunk distributor 1700 the reset relay R1790 operates periodically in order to effect operation of the various select relays R1730, R1770, etc., corresponding to idle ones of the trunks 150, etc. In the present example, the first select relay R1730 and the third select relay R1770 may occupy their operated positions, holding circuits for energizing

the windings thereof being completed. The holding circuit for energizing the winding of the first select relay R1730 extends from ground by way of the contacts 1716 and 1721, the winding of R1730, the contacts 1733 and the resistor 1736 to battery. The operated first select relay R1730 retains completed, at the contacts 1732, a circuit for energizing the lower winding of the first connect relay R1740, this circuit extending from ground by way of the contacts 1753, etc., 1713 and 1732 and the lower winding of R1740 to battery. The operated first connect relay R1740 retains completed, at the contacts 1741 1742 and 1743, an obvious connection between the dial-back repeater 61 and the trunk 150 extending to the toll line circuit 60. Accordingly, at this time the dial back repeater 61 is connected to the trunk 150 and consequently to the toll line circuit 60 and the toll line 143 extending to the manual exchange 33. Hence, the trunk distributor 1700 has operated to preselect the first trunk 150 and consequently the first toll line 143 of the group of three extending to the manual exchange 33.

When the busy relay R1720 operates incident to the seizure of the toll line circuit 60 and the incoming selector 53 over the toll line 143 from the toll position in the manual exchange 33, in the manner explained above, it interrupts, at the contacts 1721, the previously traced holding circuit for energizing the winding of the first select relay R1730, thereby to cause the latter relay to restore. Upon restoring, the first select relay R1730 interrupts, at the contacts 1732, the previously traced operating circuit for energizing the lower winding of the connect relay R1740, thereby to cause the latter relay to restore. Also, the first select relay R1730 completes, at the contacts 1731, a point in a chain circuit traced hereinafter for energizing the winding of the succeeding connect relay; interrupts, at the contacts 1733, a further point in the previously traced holding circuit for energizing the winding thereof; and prepares, at the contacts 1734, a point in an original operating circuit traced hereinafter for energizing the winding thereof. Further, the first select relay R1730 prepares, at the contacts 1735, a point in a chain circuit traced hereinafter for energizing the winding of the reset relay R1790. Upon restoring, the first connect relay R1740 interrupts, at the contacts 1745, a further point in a holding circuit traced hereinafter for energizing the upper winding thereof; and interrupts, at the contacts 1744, an operating circuit traced hereinafter for energizing the winding of the first lockout relay R1710. Further, the first connect relay R1740 interrupts, at the contacts 1741, 1742 and 1743, the previously traced connection between the dial-back repeater 61 and the trunk 150 extending to the toll line circuit 60.

Continuing with the operation of the trunk distributor 1700 and assuming that the third select relay R1770 is the next operated select relay, upon restoring, the first select relay R1730 completes, at the contacts 1731, the previously mentioned chain circuit for energizing the lower winding of the third connect relay R1780. This circuit extends from ground by way of the contacts 1753, etc., 1713, 1731, etc., and 1712 and the lower winding of R1780 to battery. When thus energized the third connect relay R1780 operates to prepare, at the contacts 1785, a holding circuit traced hereinafter for energizing the upper winding thereof; and to prepare, at the contacts 1784, a circuit traced hereinafter for energizing the winding of the third lockout re-

lay R1750. Also, the connect relay R1780 completes, at the contacts 1781, 1782 and 1783, a connection between the dial-back repeater 61 and the third trunk illustrated extending to the third toll line circuit, not shown. Accordingly, at this time the dial-back repeater 61 is operatively connected by way of the third trunk illustrated to the third toll line circuit, not shown, and consequently to the third toll line extending to the manual exchange 33.

Continuing with the operation of the incoming selector 53 which is connected by way of the trunk 146 to the toll line circuit 60 and consequently to the first toll line 143 extending to the manual exchange 33, it is again noted that, when the first toll line 143 is seized by the operator at the toll position in the manual exchange 33, the line relay R1330 in the incoming selector 53 operates. Upon operating, the line relay R1330 completes, at the contacts 1331, a circuit, including the contacts 1311, for energizing the winding of the hold relay R1340, thereby to cause the latter relay to operate. Upon operating, the hold relay R1340 completes, at the contacts 1344, a circuit for returning dial tone current over the toll line 143 to the toll position in the manual exchange 33. The last-mentioned circuit extends from ground by way of the upper winding of the line relay R1330, the contacts 1327, C148, the contacts 1243 and 1235, the winding 1272 of the repeater 1270, the left-hand winding of the answer relay R1220, the contacts 1231, the winding 1271 of the repeater 1270, the contacts 1237, C147, the contacts 1325, 1344 and 1424 to the dial tone conductor C1484. The dial tone current traversing the above-traced circuit, including the windings 1271 and 1272 of the repeater 1270, causes dial tone voltage to be induced into the windings 1273 and 1274 of the repeater 1270, whereby dial tone current is returned over the toll line 143 to the toll position in the manual exchange 33 in order to indicate to the operator therat that she may proceed to dial into the incoming selector 53. At this time the incoming selector 53 is in readiness to receive the first digit.

The operator at the toll position in the manual exchange 33 then proceeds to dial the first digit, whereby the impulse relay R1240 follows the first digit in an obvious manner. Upon the first restoration of the impulse relay R1240 there is interrupted, at the contacts 1242, the previously mentioned circuit for energizing the winding of the hold relay R1250; however, the latter relay does not restore during impulsing as it is of the slow-to-release type. Also, at the contacts 1241, there is completed an obvious circuit, including the contacts 1254, for energizing the winding of the dial relay R1210, thereby to cause the latter relay to operate. Upon operating, the dial relay R1210 prepares, at the contacts 1211, an impulse bridge including the resistor 1279 between the line conductors C147 and C148 of the trunk 146 extending to the incoming selector 53. Further, at the contacts 1243, the previously traced loop circuit for energizing in series the upper and lower windings of the line relay R1330 in the incoming selector 53 is interrupted, thereby to cause the latter relay to restore. Upon the first reoperation of the impulse relay R1240 there is completed, at the contacts 1242, the previously mentioned circuit for energizing the winding of the hold relay R1250; and there is interrupted, at the contacts 1241, the previously traced circuit for energizing the winding of the dial relay R1210; however, the latter relay does not restore

during impulsive as it is of the slow-to-release type. Further, at the contacts 1243, the previously mentioned impulse bridge, including the contacts 1211 and the resistor 1279, is completed between the line conductors of the trunk 146, thereby to cause the line relay R1330 in the incoming selector 53 to reoperate. More particularly, the line conductor C147 of the trunk 146 is connected by way of the contacts 1237 and 1211, the resistor 1279 and the contacts 1235 and 1243 to the line conductor C148 of the trunk 146. Accordingly it will be understood that the impulse relay R1240 in the toll line circuit 60 repeats the impulses of the first digit, at the contacts 1243, to the line relay R1330 in the incoming selector 53, whereby the latter relay follows the impulses of the first digit, in an obvious manner.

Upon the first restoration of the line relay R1330 there is interrupted, at the contacts 1331, the previously traced circuit for energizing the winding of the hold relay R1340; however, the latter relay does not restore during impulsive as it is of the slow-to-release type. Also, at the contacts 1332, there is completed a circuit, including the contacts 1321, 1341 and 1421, for energizing the winding of the dial relay R1350 and a multiple circuit, including the contacts 1671, 1661 and 1651, for energizing the winding of the first counting relay R1640, thereby to cause the relays mentioned to operate. Upon operating, the dial relay R1350 completes, at the contacts 1352, an obvious circuit for energizing the winding of the dial slave relay R1410, thereby to cause the latter relay to operate. Upon operating, the first counting relay R1640 completes, at the contacts 1643, a path for short-circuiting the winding of the first cycle relay R1650, this path extending from ground by way of the contacts 1321, 1332, 1341, 1421, 1671, 1661, 1651 and 1643, the winding of R1650 and the contacts 1663 and 1342 to ground. Also, the first counting relay R1640 prepares, at the contacts 1644, etc., connections to the trunk in the first group in the event the last-mentioned trunk is utilized in the system.

Upon the first reoperation of the line relay R1330 there is completed, at the contacts 1331, the previously traced circuit for energizing the winding of the hold relay R1340; and there is interrupted, at the contacts 1332, the previously traced multiple circuits for energizing the windings of the dial relay R1350 and the first counting relay R1640, and also the previously traced path for short-circuiting the winding of the first cycle relay R1650. At this time a holding circuit is completed for energizing in series the windings of the first counting relay R1640 and the first cycle relay R1650, this circuit extending from ground by way of the contacts 1342 and 1663, the winding of R1650, the contacts 1643 and the winding of R1640 to battery. When this holding circuit is completed the first counting relay R1640 is retained in its operated position and the first cycle relay R1650 operates. Also, it is noted that, when the previously traced circuit for energizing the winding of the dial relay R1350 is thus interrupted, the latter relay does not restore immediately as it is of the slow-to-release type. More particularly, the dial relay R1350 remains operated during impulsive, thereby to retain operated the dial slave relay R1410, in an obvious manner. Upon operating, the first cycle relay R1650 interrupts, at the contacts 1651, a further point in the previously traced original circuit for

energizing the winding of the first counting relay R1640; and prepares, at the contacts 1652, a circuit substantially identical to that previously traced and including the contacts 1642 for energizing the winding of the second counting relay R1630.

The line relay R1330 then restores and reoperates following the second impulse of the first digit, whereby the second counting relay R1630 is operated in an obvious manner and a holding circuit is completed, at the contacts 1633, for energizing the winding thereof in series with the winding of the second cycle relay R1660. This circuit extends from ground by way of the contacts 1342 and 1673, the winding of R1660, the contacts 1633 and the winding of R1630 to battery. When this holding circuit is completed the second counting relay R1630 is retained in its operated position and the second cycle relay R1660 operates. Upon operating, the second cycle relay R1660 interrupts, at the contacts 1661, a further point in the previously mentioned original circuit for energizing the winding of the second counting relay R1630; and prepares, at the contacts 1662, a circuit substantially identical to that previously traced and including the contacts 1632 for energizing the winding of the third counting relay R1620. Also, the second cycle relay R1660 interrupts, at the contacts 1663, the previously traced holding circuit for energizing the winding of the first counting relay R1640 in series with the winding of the first cycle relay R1650, thereby to cause the latter relays to restore.

In view of the foregoing explanation of the mode of operation of the counting relays R1640 and R1630 in conjunction with the cycle relays R1650 and R1660, it will be understood that the counting relays R1640, R1630, R1620, R1610, etc., are operated successively in accordance with the number of impulses included in the first digit; that, as each counting relay operates, a holding circuit is completed for energizing the winding thereof in series with the winding of the corresponding one of the cycle relays; and that, as each cycle relay operates, it effects the restoration of the preceding cycle relay and the counting relay preceding the last operated counting relay.

At the conclusion of the first digit the impulse relay R1240 in the toll line circuit 60 is retained in its operated position, thereby to retain completed, at the contacts 1242, the previously mentioned circuit for energizing the winding of the hold relay R1250 and to retain interrupted, at the contacts 1241, the previously traced circuit for energizing the winding of the dial relay R1210. Shortly thereafter the dial relay R1210 restores, the latter relay being of the slow-to-release type, as previously noted. Upon restoring, the dial relay R1210 interrupts, at the contacts 1211, the previously traced impulse bridge between the line conductors C147 and C148 of the trunk 146. However, at this time the previously traced original circuit for energizing the line relay R1330 in the incoming selector 53 is retained completed, at the contacts 1243, due to the operated position of the impulse relay R1240.

Accordingly, at the conclusion of the first digit, the line relay R1330 in the incoming selector 53 is retained in its operated position, thereby to retain completed, at the contacts 1331, the previously mentioned circuit for energizing the winding of the hold relay R1340 and to retain interrupted, at the contacts 1332, the previously traced circuit for energizing the winding of the dial relay R1350. Shortly thereafter the dial relay

R1350 restores, the latter relay being of the slow-to-release type, as previously noted. Upon restoring, the dial relay R1350 interrupts, at the contacts 1352, the previously mentioned circuit for energizing the winding of the dial slave relay R1410; however, the latter relay does not immediately restore as it is of the slow-to-release type. Also, the dial relay R1350 completes, at the contacts 1351, an obvious circuit, including the contacts 1411, for energizing the upper winding of the connect relay R1480, thereby to cause the latter relay to operate. Further, the dial relay R1350 completes, at the contacts 1351, a circuit for energizing one of the trunk select relays R1460, R1450 or R1460, depending upon the numerical value of the first digit and whether the corresponding group of trunks selected comprises one or three trunks, in a manner more fully explained hereinafter.

For purpose of illustration, assume that the first digit was 3, whereby the third counting relay R1620 and the third cycle relay R1670 occupy their operated positions. In this event, upon restoring, the dial relay R1350 completes, at the contacts 1351, a circuit for energizing the winding of the first trunk select relay R1460; the third group of trunks comprising only one trunk. The last-mentioned circuit extends from ground by way of the contacts 1351, 1411 and 1621, C158 and the winding of the first counting relay R1460 to battery, whereby the latter relay operates. Upon operating, the connect relay R1480 completes, at the contacts 1482, an obvious holding circuit, including the contacts 1342, for energizing the lower winding thereof; and completes, at the contacts 1481, an obvious circuit for energizing the winding of the connect slave relay R1470, thereby to cause the latter relay to operate. Upon operating, the first trunk select relay R1460 prepares, at the contacts 1462, 1463 and 1464, a connection traced hereinafter to the single trunk in the third group; and completes, at the contacts 1461, a path for short-circuiting the winding of the test relay R1430. The last-mentioned path extends from ground by way of the contacts 1351, 1411 and 1621, C158, the contacts 1461, the winding of R1430, the contacts 1422 and 1343 to ground.

Shortly following the restoration of the dial relay R1350 the dial slave relay R1410 restores in order to interrupt, at the contacts 1411, the previously traced path for short-circuiting the winding of the test relay R1430; whereupon a holding circuit is completed for energizing the winding of the first select relay R1460 in series with the winding of the test relay R1430. This circuit extends from ground by way of the contacts 1343 and 1422, the winding of R1430, the contacts 1461 and the winding of R1460 to battery. When this holding circuit is completed the first trunk select relay R1460 is retained in its operated position and the test relay R1430 operates.

During the time interval following the restoration of the dial relay R1350 and prior to the restoration of the dial slave relay R1410 and the consequent operation of the test relay R1430, the idle or busy condition of the single trunk in the third group is tested. More particularly, during this time interval, battery potential is connected by way of the upper winding of the busy relay R1420, the contacts 1432, 1464 and 1473, C1493 and the contacts 1628 to the control conductor of the single trunk in the third group. In the event the last-mentioned trunk is busy,

ground potential appears upon the control conductor thereof; and in the event the last-mentioned trunk is idle, battery potential appears upon the control conductor thereof. First assuming that the single trunk in the third group is busy, the presence of ground potential upon the control conductor thereof completes an obvious circuit substantially identical to that traced above for energizing the upper winding of the busy relay R1420, thereby to cause the latter relay to operate. Upon operating, the busy relay R1420 completes, at the contacts 1423, a holding circuit, including the contacts 1342, for energizing the lower winding thereof. Also, the busy relay R1420 interrupts, at the contacts 1422, a circuit traced hereinafter for energizing the winding of the switch-through relay R1320; and interrupts, at the contacts 1421, a further point in the previously traced pulsing circuit for operating the counting relays R1640, R1630, etc. Further, the busy relay R1420 interrupts, at the contacts 1424, the previously traced path for returning dial tone current over the toll line 143 to the toll position in the manual exchange 33; and completes, at the contacts 1425, a circuit for returning busy tone current over the toll line 143 extending to the toll position in the manual exchange 33. The last-mentioned circuit extends from the busy tone conductor C1483 by way of the contacts 1425, the condenser 1353, the contacts 1327 to the line conductor C148 of the trunk 146 and from the line conductor C147 of the trunk 146 by way of the contacts 1325 and the lower winding of the line relay R1330 to battery; the line conductors C147 and C148 of the trunk 146 being connected together by way of the previously traced circuit including the windings 1271 and 1272 of the repeater 1270. The busy tone current traversing the windings 1271 and 1272 of the repeater 1270 induces busy tone voltage in the windings 1273 and 1274 thereof; whereby busy tone current is returned from the windings 1273 and 1274 of the repeater 1270 by way of the condensers 1276 and 1277 and the line conductors C144 and C145 of the toll line 143 to the toll position in the manual exchange 33 in order to indicate to the operator thereat that the single trunk in the third group is busy at this time. Upon receiving busy tone the operator at the toll position in the manual exchange 33 effects the release of the incoming selector 53, in a manner more fully explained hereinafter.

Now assuming that the single trunk in the third group is idle, battery potential appearing upon the control conductor thereof completes a path substantially identical to that previously traced for short-circuiting the upper winding of the busy relay R1420, thereby positively to prevent operation of the latter relay at this time. Shortly thereafter the test relay R1430 operates in order to arrest the testing of the idle or busy condition of the single trunk in the third group, in the manner previously explained. Upon operating, the test relay R1430 interrupts, at the contacts 1432, the previously traced connection between the upper winding of the busy relay R1420 and the control conductor of the single trunk in the third group. Also, the test relay R1430 completes, at the contacts 1433, the previously mentioned circuit for energizing the winding of the switch-through relay R1320, this circuit extending from ground by way of the contacts 1343, 1422, 1433, 1315 and 1329 and the winding of R1320 to battery. When thus energized the switch-through relay R1320 operates to com-

plete, at the contacts 1328, an obvious holding circuit, including the contacts 1343, for energizing the winding thereof. Also the switch-through relay R1320 completes, at the contacts 1323, an obvious circuit, including the contacts 1637, for energizing the winding of the control relay R1310, thereby to cause the latter relay to operate. Further the switch-through relay R1320 completes, at the contacts 1322, an obvious multiple holding circuit for energizing the lower winding of the connect relay R1480 and an obvious multiple holding circuit for energizing in series the winding of the third cycle relay R1670 and the third counting relay R1620. Further the switch-through relay R1320 interrupts, at the contacts 1325 and 1327, the previously traced loop circuit for energizing in series the upper and lower windings of the line relay R1330, thereby to cause the latter relay to restore. Also the switch-through relay R1320 completes, at the contacts 1324 and 1326, a connection between the line conductors C147 and C148 of the trunk 146 and the line conductors of the single trunk in the third group; and completes, at the contacts 1320, an obvious path for applying ground potential to the control conductor C149 of the trunk 146. The application of ground potential to the control conductor C149 of the trunk 146 completes an obvious circuit for energizing the winding of the busy relay R1260 in the toll line circuit 60, thereby to cause the latter relay to operate. Upon operating, the busy relay R1260 interrupts, at the contacts 1261, the previously traced original path for applying ground potential to the control conductor C153 of the trunk 150; and completes, at the contacts 1262, an obvious alternative path for applying ground potential to the control conductor C153 of the trunk 150, thereby to retain operated the busy relay R1720 in the trunk distributor 1700 comprising a portion of the dial-back repeater 61.

At this time ground potential is applied by way of the contacts 1343, 1422, 1431, 1464 and 1473, C1493 and the contacts 1626 to the control conductor of the single trunk in the third group, whereby the apparatus associated therewith operates in order to cause ground potential to be returned over the control conductor of the last-mentioned trunk. The application of ground potential returned over the control conductor of the single trunk in the third group completes an obvious multiple holding circuit for energizing the winding of the switch-through relay R1320 and an obvious multiple holding circuit for energizing the winding of the test relay R1430 in series with the winding of the first trunk select relay R1460.

Upon operating, the control relay R1310 completes, at the contacts 1312, an obvious holding circuit, including the contacts 1331, for energizing the winding thereof; and interrupts, at the contacts 1311, the previously traced circuit for energizing the winding of the hold relay R1340, thereby to cause the latter relay to restore shortly thereafter. Upon restoring, the hold relay R1340 interrupts, at the contacts 1344, the previously traced circuit for returning dial tone current over the toll line 143 to the toll position in the manual exchange 33. At this time an operative connection is completed between the repeater 1270 and the single trunk in the third group, as previously noted. More particularly, one of the line conductors of the single trunk in the third group is connected by way of the contacts 1624, C1491, the contacts 1471, 1462 and 1324, C147, the contacts 1237, the winding 1271 of the repeater 1270, the

contacts 1231, the left-hand winding of the answer relay R1220, the winding 1272 of the repeater 1270, the contacts 1235 and 1243, C148, the contacts 1326, 1463 and 1472, C1492 and the contacts 1625 to the other line conductor of the single trunk in the third group.

The operator at the toll position in the manual exchange 33 proceeds to dial the second and subsequent digits over the toll line 143, whereby the impulse relay R1240 in the toll line circuit 60 follows the digits mentioned, in the manner previously explained, repeating the digits mentioned, at the contacts 1243, over the single trunk in the third group to the succeeding switching stages.

15 When the call on the single trunk in the third group is answered the apparatus associated therewith reverses battery potential over the line conductors thereof, whereby the left-hand winding of the answer relay R1220 in the toll line circuit 20 60 is energized over the above-traced circuit in the opposite direction. When the left-hand winding of the answer relay R1220 is thus energized the latter relay operates as it is of the polarized type, as previously noted. Upon operating, 25 the answer relay R1220 interrupts, at the contacts 1222, the previously traced path for applying battery potential by way of the lower winding of the impulse relay R1240 to the dial conductor C1278; and completes, at the contacts 30 1221, an obvious path for applying battery potential by way of the upper and lower windings of the impulse relay R1240 in series to the dial conductor C1278. The consequent increase in the 35 resistance interposed between battery and the dial conductor C1278 is effective to signal the operator at the toll position in the manual exchange 33 that the desired connection is now completed to the single trunk in the third group.

In the foregoing explanation of the mode of 40 operation of the incoming selector 53, it was assumed that the connection was to be extended to the single trunk in the third group; however, the connection might have been extended to the single trunk in the second group. For example, 45 in extending the connection to the single trunk in the second group, the first digit 2 is dialed by the operator at the toll position in the manual exchange 33 into the incoming selector 53 after seizure thereof, in the manner previously explained. Now assuming that the operator at the toll position in the manual exchange 33 has seized the incoming selector 53 and that the first digit 2 has been dialed therewith, in the manner previously explained, the second counting relay 55 R1630 and the second cycle relay R1660 occupy their operated positions. In the present example, the single trunk 158 in the second group is individual to the incoming selector 53 and terminates in a line circuit, not shown, individual thereto. Accordingly the single trunk 156 in the second group comprises no control conductor and is always tested as idle when the incoming selector 53 is operated to seize it. Accordingly, in the present example, upon operating, the switch-through relay R1320 does not complete, at the contacts 1323, the previously traced operating 60 circuit for energizing the winding of the control relay R1310 due to the operated position of the second counting relay R1630. However, when 65 the switch-through relay R1320 operates it completes, at the contacts 1324 and 1326, a connection between the repeater 1270 and the single trunk 156 in the second group, including the winding of the series relay R1680. More particularly, the above-mentioned connection ex-

tends from one of the line conductors of the trunk 156 by way of the contacts 1634, the winding of R1880, C1481', the contacts 1471, 1462 and 1324 to the line conductor C147 of the trunk 148, and from the other line conductor of the trunk 156 by way of the contacts 1635, C1482', the contacts 1472, 1463 and 1326 to the line conductor C148 of the trunk 148. The line conductors C147 and C148 of the trunk 148 are connected together by way of the previously traced circuit including the left-hand winding of the answer relay R1220.

When thus energized the series relay R1880 operates to complete, at the contacts 1681, an obvious alternative circuit for energizing the winding of the control relay R1310, thereby to cause the latter relay to operate. Upon operating, the control relay R1310 completes, at the contacts 1314, an alternative holding circuit for energizing the winding of the switch-through relay R1320 and an alternative holding circuit for energizing the winding of the test relay R1430 in series with the winding of the first trunk select relay R1460. The last-mentioned circuit extends from ground by way of the contacts 1636, 1314 and 1328 and the winding of R1320 to battery and from the grounded contacts 1314 by way of the contacts 1422, the winding of R1430, the contacts 1461 and the winding of R1460 to battery. Upon restoring, the line relay R1330 effects restoration of the hold relay R1340 shortly thereafter, in the manner previously explained.

As previously noted, the single trunk 156 in the second group terminates in a line circuit individual thereto which is accessible to the finder of each of the links in the automatic exchange 35; and the finder of an idle one of the links operates to seize the trunk extending to the line circuit mentioned. The operator at the toll position in the manual exchange 33 then proceeds to dial the second and subsequent digits over the toll line 143, whereby the impulse relay R1240 in the toll line circuit 60 repeats the digits mentioned at the contacts 1243 over the single trunk 156 in the second group to the link utilized in the automatic exchange 35, thereby to effect operation of the last-mentioned link in an entirely conventional manner. More particularly, the link utilized in the automatic exchange 35 extends the call and when the call is answered it operates in order to cause battery potential to be reversed over the single trunk 156 in the second group; whereby the answer relay R1220 in the toll line circuit 60 is operated, in the manner previously explained, in order to effect the transmission of a signal to the operator at the toll position in the manual exchange 33 indicating that the call has been answered.

In the foregoing explanation of the mode of operation of the incoming selector 53, it was assumed that the connection was to be extended to the single trunk in the third group or to the single trunk in the second group; however, the connection might have been extended to the single trunk in any other group or to an idle trunk in any group comprising three trunks. For example, the connection might have been extended to an idle one of the three trunks in the eighth group; in which event the first digit 8 would have been dialed by the operator at the toll position in the manual exchange 33 into the incoming selector 53 after seizure thereof, in the manner previously explained. Now assuming that the operator at the toll position in the manual exchange 33 has seized the incoming selector 53 and that the first digit 8 has been dialed

thereinto, in the manner previously explained, the eighth counting relay R1530 and the second cycle relay R1660 occupy their operated positions. In the present example, shortly following the first digit 8, the dial relay R1360 restores in the manner previously explained, thereby to complete, at the contacts 1351, a path, including the contacts 1411 and 1531, for applying ground potential to the group marking conductor C161 extending to the trunk group allotter 70; the trunk group allotter 70 being associated with the three by-pass selectors 50, etc., accessible to the incoming trunks 105, etc., in the eighth group.

Before continuing with the detailed operation of the incoming selector 53, reference is had to the trunk group allotter 70 and it is pointed out that, when the first by-pass selector 50 and the incoming trunk 105 extending thereto are idle, the first marking relay R310 in the trunk group allotter 70 occupies its restored position; the incoming trunk 105 being the first of the three comprising the eighth group. The restored first marking relay R310 in the trunk group allotter 70 originally completed, at the contacts 311, a circuit, including the contacts 311, 363, 343 and 323, for energizing the winding of the first select relay R320; whereby the latter relay operated to complete, at the contacts 325, a holding circuit, including the contacts 345, 365 and 371, for energizing the winding thereof. The operated first select relay R320 marks the first incoming trunk 105 of the three constituting the eighth group as idle to the switches having access thereto. More particularly, the operated first select relay R320 completes, at the contacts 322, a connection between the group marking conductor C101 and the individual marking conductor C102 extending to the first link 92 in the automatic exchange 35, for a purpose more fully explained hereinafter. Also the first select relay R320 completes, at the contacts 327, obvious multiple circuits for energizing the first select slave relays R410, R440, etc., in the various sets of three, whereby the latter relays are retained in their operated positions. The operated first select slave relay R410 retains completed, at the contacts 411, an obvious connection between the group marking conductor C161 and the individual marking conductor C158. Accordingly, at this time, the trunk group allotter 70 has preselected the first incoming trunk 105 of the three constituting the eighth group as the next trunk selectable by the various switches having access thereto.

Continuing now with the operation of the incoming selector 53 it is pointed out that the application of ground potential to the group marking conductor C161 causes ground potential to be returned over the individual marking conductor C158 due to the operated position of the first select slave relay R410 in the trunk group allotter 70, as previously noted. The application of ground potential to the individual marking conductor C158 completes the previously traced circuit for energizing the winding of the first trunk select relay R1460, thereby to cause the latter relay to operate in the manner previously explained; whereby an operative connection is ultimately completed between the repeater 1270 and the first incoming trunk 105 of the three constituting the eighth group. More particularly, in the present example, ground potential is applied by way of the impedance element 1555 in the by-pass selector 50, the contacts 624 and 644 and the winding 573 of the repeater 570 to

the line conductor C107 of the trunk 105; and battery potential is applied by way of the winding of the seizure relay R550 in the by-pass selector 50, the contacts 622 and 642 and the winding 574 of the repeater 570 to the line conductor C106 of the trunk 105. One of the line conductors of the trunk 105 is connected by way of the contacts 1534, C1491', the contacts 1471, 1462 and 1324 to the line conductor C147 of the trunk 146; and the other line conductor of the trunk 105 is connected by way of the contacts 1535, C1492', the contacts 1472, 1463 and 1326 to the line conductor C148 of the trunk 146. The line conductors C147 and C148 of the trunk 146 are connected together by way of the previously traced circuit including the left-hand winding of the answer relay R1220 in the toll line circuit 60. Hence, at this time, an operative connection is completed between the toll position in the manual exchange 33 and the first trunk 105 of the three constituting the eighth group.

Furthermore, at this time, ground potential is applied in the by-pass selector 50 to the control conductor C108 of the trunk 105, thereby to complete the previously traced holding circuit for energizing the winding of the switch-through relay R1320 and the previously traced holding circuit for energizing the winding of the test relay R1430 in series with the winding of the first trunk select relay R1460 in the incoming selector 53, in the manner previously explained. Also the application of ground potential in the by-pass selector 50 to the control conductor C108 of the trunk 105 completes an obvious circuit for energizing the winding of the first marking relay R310 in the trunk group allotter 70, thereby to cause the latter relay to operate. Upon operating, the first marking relay R310 interrupts, at the contacts 311, the previously traced original circuit for energizing the winding of the first select relay R320; and completes, at the contacts 312, a circuit, including the contacts 371, 363, 343, 323 and 331, for energizing the winding of the second select relay R340 in the event the second by-pass selector, not shown, is idle at this time, whereby the latter relay operates. Upon operating, the second select relay R340 completes, at the contacts 346, a holding circuit, including the contacts 365 and 371, for energizing the winding thereof; interrupts, at the contacts 343, a further point in the previously traced original circuit for energizing the winding of the first select relay R320; and prepares, at the contacts 344, a circuit substantially identical to that previously traced for energizing the winding of the third select relay R360 upon the subsequent operation of the second marking relay R330. Further the second select relay R340 interrupts, at the contacts 345, the previously traced holding circuit for energizing the winding of the first select relay R320, thereby to cause the latter relay to restore. Upon restoring, the first select relay R320 interrupts, at the contacts 322, the previously traced connection between the group marking conductor C101 and the individual marking conductor C102 extending to the first link 92 in the automatic exchange 35. Also the first select relay R320 interrupts, at the contacts 327, the previously traced multiple circuits for energizing the windings of the first select slave relays R410, R440 etc. in the various sets, thereby to cause the latter relays to restore. Upon restoring, the first select slave relay R410 interrupts, at the contacts 411, the previously

5 mentioned connection between the group marking conductor C101 and the individual marking conductor C102; whereby the first trunk 105 of the three in the eighth group is marked as busy to the subsequent use of the incoming selector 53.

10 Also, upon operating, the second select relay R340 completes, at the contacts 347, obvious multiple circuits for energizing the windings of the second select slave relays R420, R450 etc. in the different sets, thereby to effect operation of the relays mentioned. Upon operating, the second select slave relay R420 completes, at the contacts 421, an obvious connection between the group marking conductor C101 and the individual marking conductor C102, thereby to mark the second trunk of the three in the eighth group as idle to the subsequent use of the incoming selector 53.

15 Again referring to the operation of the incoming selector 53 it is noted that, in the event the second trunk of the three constituting the eighth group had been preselected by the trunk group allotter 70, the incoming selector 53 would have operated to select the last-mentioned trunk instead of the first trunk 105 in this group. More particularly, in this event, the group marking conductor C101 would have been connected by way of the contacts 421 to the individual marking conductor C102 in the trunk group allotter 70, in the manner explained above. Accordingly, 20 in this event, the application of ground potential to the group marking conductor C101 would have been effective to cause ground potential to be applied to the individual marking conductor C102, whereby the second trunk select relay R1460 in the incoming selector 53 would have operated in order to effect the seizure of the second trunk of the three constituting the eighth group, in an obvious manner.

25 Continuing now with the operation of the trunk group allotter 70, it is pointed out that subsequently, when the second trunk of the three constituting the eighth group is taken for use, the second marking relay R330 operates in order to effect the restoration of the second select relay R340 and the second select slave relays R420, R450 etc. and to effect operation of the third select relay R360 and the third select slave relays R430, R460 etc., all in the manner previously explained. 30 When the third select relay R360 and the third select slave relays R430, R460 etc. occupy their operated positions, the third trunk of the three constituting the eighth group is preselected to the use of the switches having access thereto. Subsequently, when the third trunk of the three constituting the eighth group is taken for use, the third marking relay R350 is operated in the manner previously explained. Upon operating, the third marking relay R350 interrupts, at the contacts 351, a previously completed holding circuit, including the contacts 364 and 371, for energizing the winding of the third select relay R360; however, the latter relay does not restore at this time due to the previous completion of an alternative holding circuit for energizing the winding thereof including the contacts 371 and 386. Further the third marking relay R350 prepares, at the contacts 352, a circuit for energizing the winding of the reset relay R370 in series with the winding of either the first select relay R320 or the second select relay R340, depending upon the restored positions of the respective first marking relay R310 and the second marking relay R330. More particularly, in the event the first trunk of the three constituting the eighth

group is idle at this time, the first marking relay R310 occupies its restored position and the previously mentioned circuit for energizing the winding of the reset relay R370 in series with the winding of the first select relay R320 is completed. The last-mentioned circuit extends from ground by way of the contacts 371, 364 and 352, the winding of R370, the contacts 311 and the winding of R320 to battery. When this series circuit is completed the first select relay R320 operates immediately and the reset relay R370 operates shortly thereafter, the latter relay being of the slow-to-operate type. Upon operating, the reset relay R370 interrupts, at the contacts 371, the previously traced holding circuit, including the contacts 366, for energizing the winding of the third select relay R360, thereby to cause the latter relay to restore. Also the reset relay R370 interrupts, at the contacts 371, the previously traced series circuit for energizing the winding thereof and the winding of the first select relay R320, thereby to cause the relays mentioned to restore. Upon restoring, the reset relay R370 completes, at the contacts 371, an original operating circuit for energizing the winding of the first select relay R320; the last-mentioned circuit extending from ground by way of the contacts 371, 365, 345, 324 and 311 and the winding of R320 to battery. When thus energized the first select relay R320 reoperates to complete, at the contacts 323 and 325, the two previously traced holding circuits for energizing the winding thereof. Accordingly, at this time, the first trunk 105 of the three constituting the eighth group is again preselected for use by the switches having access thereto.

In view of the foregoing explanation of the mode of operation of the trunk group allotter 70 to reset the first select relay R320, in the event the first marking relay R310 occupies its restored position, it will be understood that this apparatus is operative in a substantially identical manner to reset the second select relay R340, in the event the first marking relay R310 occupies its operated position and the second marking relay R330 occupies its restored position. Finally, in this connection, it is pointed out that, in the event both the first marking relay R310 and the second marking relay R330 occupy their operated positions, when the third trunk of the three constituting the eighth group is taken for use the reset relay R370 is not operated and the third select relay R360 is retained in its operated position. In this event, when all three of the trunks constituting the eighth group are busy, the trunk group allotter 70 cannot be reset to preselect an idle trunk of the three constituting the eighth group. Accordingly, the third select relay R360 is retained in its operated position, whereby the busy third trunk of the three constituting the eighth group is marked for seizure to the automatic switches having access thereto.

Again considering the operation of the incoming selector 53, it is pointed out that, in the event all three of the trunks constituting the eighth group are busy incident to the restoration of the dial relay R1350 therein, the ground potential applied to the group marking conductor C161 is connected in the trunk group allotter 70 to one of the individual marking conductors C158 etc., thereby to effect operation of the corresponding trunk select relay R1460 etc. In this event, the operating trunk select relay R1460 etc. connects the busy preselected trunk of the three constituting the eighth group to the in-

coming selector 53, whereby operation of the busy relay R1420 is effected in the manner previously explained. Upon operating, the busy relay R1420 causes busy tone current to be returned to the toll position in the manual exchange 33, thereby to indicate to the operator thereof that all three of the trunks constituting the eighth group are busy at this time.

Again referring to the operation of the trunk group allotter 70 it is noted that, when one of the three trunks constituting the eighth group becomes idle, the corresponding marking relay R310 etc. restores, whereby the reset relay R370 and the corresponding select relay R320 etc. are operated in the manner previously described; whereby the trunk group allotter 70 is operated to preselect an idle trunk of the three constituting the eighth group for the use of the automatic switches having access thereto.

As previously explained, during the operation of the counting relays R1640 etc. incident to the dialing of the first digit into the incoming selector 53, one of the counting relays operates; then the succeeding counting relay operates in order to effect restoration of the preceding counting relay. Hence, at any time, any two adjacent counting relays may momentarily occupy their operated positions. For example, the counting relays R1530 and R1540 momentarily occupy operated positions incident to the dialing of the first digit 8 and prior to the restoration of the seventh counting relay R1540. In order to prevent the seventh counting relay R1540 and the eighth counting relay R1530 from momentarily connecting together the single trunk 125 comprising the seventh group and the first trunk 105 of the three comprising the eighth group, an improved arrangement is provided for isolating the corresponding trunks in adjacent ones of the groups. For example, the single trunk 125 comprising the seventh group is connected by way of the contacts 1544, 1545 and 1546 by the seventh counting relay R1540 to the conductors C1491, C1492 and C1493; while the first trunk 105 in the eighth group is connected by way of the contacts 1534, 1535 and 1536 by the eighth counting relay R1530 to the conductors C1491', C1492' and C1493'. Subsequently the connect slave relay R1470 connects the two sets of conductors C1491, C1492, C1493 and C1491', C1492', C1493' together at the contacts 1471, 1472 and 1473. However, at this time, the seventh counting relay R1540 has had ample time to restore in order to effect the disconnection of the single trunk 125 constituting the seventh group from the conductors C1491, C1492 and C1493. Hence, this improved arrangement of the two sets of conductors C1491, C1492, C1493 and C1491', C1492', C1493' positively prevents corresponding ones of the trunks in adjacent ones of the groups from being momentarily connected together incident to the successive operation of the various counting relays R1640 etc. It will be readily understood that this arrangement positively prevents two corresponding busy trunks in two adjacent groups from being momentarily connected together incident to the operation of the counting relays R1640 etc. in the incoming selector 53, and the consequent annoyance to the persons conversing over the corresponding trunks in the two adjacent groups mentioned.

Again continuing with the operation of the incoming selector 53, assume, for convenience, that the first-mentioned connection is completed from the toll position in the manual exchange

33 to the single trunk constituting the third group. When the called connection is released, the previously traced path for applying ground potential to the control conductor of the single trunk comprising the third group is interrupted, thereby to interrupt the previously traced holding circuit for energizing the winding of the switch-through relay R1320 and the previously traced multiple holding circuit for energizing the winding of the test relay R1430 in series with the winding of the first trunk select relay R1460, whereby the relays mentioned restore. Upon restoring, the switch-through relay R1320 interrupts, at the contacts 1324 and 1326, the previously traced connection between the line conductors of the trunk 146 and the line conductors of the single trunk comprising the third group; and recomplete, at the contacts 1325 and 1327, the previously traced loop circuit for energizing in series the upper and lower windings of the line relay R1330 and the left-hand winding of the answer relay R1220. Accordingly, battery potential is reversed over the line conductors of the trunk 146; whereby the answer relay R1220 in the toll line circuit 60 restores, the latter relay being of the polarized type, as previously noted. Also, at this time, the line relay R1330 in the incoming selector 53 reoperates, thereby to complete, at the contacts 1331, an obvious holding circuit, including the contacts 1312, for energizing the winding of the control relay R1310. Also, upon restoring, the switch-through relay R1320 interrupts, at the contacts 1322, the previously traced holding circuit for energizing the lower winding of the connect relay R1480 and the previously traced multiple holding circuit for energizing the winding of the third cycle relay R1670 in series with the winding of the third counting relay R1620, whereby the relays mentioned restore. Further the switch-through relay R1320 interrupts, at the contacts 1320, the previously mentioned path for applying ground potential to the control conductor C149 of the trunk 146, thereby to interrupt the previously mentioned circuit for energizing the winding of the busy relay R1260 in the toll line circuit 60, whereupon the latter relay restores. Upon restoring, the busy relay R1260 interrupts, at the contacts 1262, the previously traced alternative path for applying ground potential to the control conductor C153 of the trunk 150; and completes, at the contacts 1261, the previously traced original path for applying ground potential to the last-mentioned control conductor, whereby the busy relay R1720 in the trunk distributor 1700 forming a part of the dial-back repeater 61 is retained in its operated position.

Upon restoring, the answer relay R1220 interrupts, at the contacts 1221, the previously traced path for applying battery potential by way of the upper and lower windings of the impulse relay R1240 in series to the dial conductor C1278; and completes, at the contacts 1222, the previously traced original path for applying battery potential by way of the lower winding of the impulse relay R1240 to the dial conductor C1278. The consequent reduction in the resistance interposed between battery and the dial conductor C1278 is effective to signal the operator at the toll position in the manual exchange 33 that the called connection has been released.

The operator at the toll position in the manual exchange 33 then withdraws the call plug of the cord circuit from the jack terminating the toll line 143, thereby to interrupt the previously

traced circuit for energizing the lower winding of the impulse relay R1240 in the toll line circuit 60, whereupon the latter relay restores. Upon restoring, the impulse relay R1240 interrupts, at the contacts 1243, the previously traced loop circuit for energizing the windings of the line relay R1330 in the incoming selector 53, thereby to cause the latter relay to restore. Also the impulse relay R1240 interrupts, at the contacts 1242, the previously mentioned circuit for energizing the winding of the hold relay R1250, thereby to cause the latter relay to restore shortly thereafter, the hold relay R1250 being of the slow-to-release type. Upon restoring, the hold relay R1250 interrupts, at the contacts 1251, the previously mentioned circuit for energizing the right-hand winding of the answer relay R1220. Further, the hold relay R1250 interrupts, at the contacts 1253, the previously traced path for applying ground potential to the control conductor C153 of the trunk 150; and completes, at the contacts 1252, the previously traced path for applying battery potential by way of the winding of the switching relay R1230 to the last-mentioned control conductor. 25 When ground potential is removed from the control conductor C153 of the trunk 150 the previously traced circuit for energizing the winding of the busy relay R1720 in the trunk distributor 1700 forming a part of the dial-back repeater 61 is interrupted, thereby to cause the latter relay to restore. Upon restoring, the busy relay R1720 reprepares, at the contacts 1721, an original operating circuit traced hereinafter for energizing the winding of the first select relay R1730, thereby to 30 mark the trunk 150 extending to the toll line circuit 60 as idle to be selected subsequently during the cycle of operation of the trunk distributor 1700.

Continuing now with the operation of the incoming selector 53, upon restoring, the line relay R1330 interrupts, at the contacts 1331, the previously traced holding circuit for energizing the winding of the control relay R1310, thereby to cause the latter relay to restore shortly thereafter, the control relay R1310 being of the slow-to-release type. Upon restoring, the connect relay R1480 interrupts, at the contacts 1481, the previously mentioned circuit for energizing the winding of the connect slave relay R1470, thereby to 45 cause the latter relay to restore. At this time the incoming selector 53 is completely released and available for further use. The single trunk comprising the third group is marked as idle to the switches having access thereto; the trunk 150 extending to the toll line circuit 60 is marked as idle to the trunk distributor 1700 forming a part of the dial-back repeater 61 and to the distributors forming parts of the other dial-back repeaters, not shown; and the toll line 143 is rendered idle 50 and available for further use.

In the foregoing explanation of the release of the incoming selector 53, it was assumed that the connection was completed to the single trunk comprising the third group. However, the connection might have been completed to the single trunk 156 comprising the second group. In the last-mentioned event, when the called connection is released, the previously traced circuit for energizing the winding of the series relay R1680 is interrupted, thereby to cause the latter relay to restore. Upon restoring, the series relay R1680 interrupts, at the contacts 1681, the previously traced circuit for energizing the winding of the control relay R1310, thereby to cause the latter 70 relay to restore shortly thereafter. Upon restor- 75

ing, the control relay R1310 interrupts, at the contacts 1314, the previously traced holding circuits, including the contacts 1638, for energizing the winding of the switch-through relay R1320 and for energizing the winding of the test relay R1438 in series with the winding of the first trunk select relay R1460, thereby to cause the relays mentioned to restore. Upon restoring, the switch-through relay R1320 effects the re-operation of the line relay R1330 in the incoming selector 53 and the restoration of the answer relay R1220 in the toll line circuit 60; whereby a release signal is rendered the operator at the toll position in the manual exchange 33, all in the manner previously explained. The complete release of the toll line circuit 60 and the incoming selector 53 is then effected under the control of the operator at the toll position in the manual exchange 33, in the manner previously explained.

In the foregoing explanation of the mode of releasing the incoming selector 53, it was assumed that the release occurred subsequent to the completion of an actual connection extended by way of the incoming selector 53. However, it may occur that the single trunk comprising one of the groups or each of the three trunks comprising one of the groups which is called by the operator at the toll position in the manual exchange 33 is busy; whereby the busy relay R1420 operates in order to cause busy tone current to be returned over the toll line 143 to the toll position in the manual exchange 33, in the manner previously explained. In this event, the operator at the toll position in the manual exchange 33 initiates the release of the incoming selector 53 by withdrawing the call plug of the cord circuit in use from the jack terminating the toll line 143, whereby the previously traced circuit for energizing the winding of the impulse relay R1240 is interrupted in order to cause the latter relay to restore. Upon restoring, the impulse relay R1240 interrupts, at the contacts 1243, the previously traced loop circuit for energizing the windings of the line relay R1330 in the incoming selector 53, thereby to cause the latter relay to restore. Also the impulse relay R1240 interrupts, at the contacts 1242, the previously mentioned circuit for energizing the winding of the hold relay R1250, thereby to cause the latter relay to restore shortly thereafter. Upon restoring, the hold relay R1250 interrupts, at the contacts 1253, the previously traced path for applying ground potential to the control conductor C153 of the trunk 150; and completes, at the contacts 1252, the previously mentioned path for applying battery potential by way of the winding of the switching relay R1230 to the last-mentioned conductor, whereby the previously traced circuit for energizing the winding of the busy relay R1720 in the trunk distributor 1700 is interrupted in order to cause the latter relay to restore, for the purpose previously explained.

Upon restoring, the line relay R1330 in the incoming selector 53 recompletes, at the contacts 1332, the previously traced circuit for energizing the winding of the dial relay R1350, thereby to cause the latter relay to reoperate; and interrupts, at the contacts 1331, the previously traced circuit for energizing the winding of the hold relay R1340, thereby to cause the latter relay to restore shortly thereafter. Upon reoperating, the dial relay R1350 recompletes, at the contacts 1352, the previously mentioned circuit for energizing the winding of the dial slave relay R1410, thereby to cause the latter relay to reop-

erate. Upon restoring, the hold relay R1340 interrupts, at the contacts 1341, the previously traced circuit for energizing the winding of the dial relay R1350, thereby to cause the latter relay to restore shortly thereafter and effect the restoration of the dial slave relay R1410 further shortly thereafter. Also the hold relay R1340 interrupts, at the contacts 1342, the previously traced multiple holding circuits for energizing the lower windings of the busy relay R1420 and the connect relay R1430 and for energizing the winding of one of the cycle relays R1560, etc., in series with the winding of one of the counting relays R1640, etc., thereby to cause the relays mentioned to restore. At this time the incoming selector 53 is completely released and available for further use; the trunk 150 is marked as idle; and the toll line 143 is in readiness for subsequent use.

20 *Call to the manual exchange 33*

Considering now the extension of a call to the manual exchange 33, the calling automatic switch is first operated to select an idle trunk of the three constituting the tenth group under the control of the repeater allotter 13, in the manner previously explained. In the present example, the first select relay R2220 in the repeater allotter 13 occupies its operated position, whereby the first trunk 121 of the three constituting the tenth group is preselected to the use of the calling switch. Hence, the calling switch is governed to seize the first trunk 121 of the three constituting the tenth group and extending to the first dial-back repeater 11. When the trunk 121 is thus seized by the calling switch a circuit is completed for energizing the winding of the seizure relay R2050, this circuit extending from ground by way of the impedance element I2040, the winding 1919 of the repeater 1915 and the contacts 2014 to the line conductor C123 of the trunk 121 and from battery by way of the winding of R2050, the winding 1918 of the repeater 1915 and the contacts 2072 to the line conductor C122 of the trunk 121, the line conductors C122 and C123 of the trunk 121 being connected together in the calling switch. When thus energized the seizure relay R2050 operates to complete, at the contacts 2053, an obvious circuit for energizing the winding of the hold relay R2020, thereby to cause the latter relay to operate. Also the seizure relay R2050 completes, at the contacts 2054, an obvious circuit, including the contacts 1932, for energizing the winding of the supervisory relay R1850, thereby to cause the latter relay to operate. Also when the calling switch seizes the trunk 121 ground potential therein is applied to the control conductor C124 of the trunk 121, whereupon an obvious circuit is completed for energizing the winding of the first marking relay R2210 in the repeater allotter 13. When thus energized the first marking relay R2210 in the repeater allotter 13 operates, for the purpose previously explained.

65 Upon operating, the supervisory relay R1850 interrupts, at the contacts 1852, a further point in a path traced hereinafter for applying battery potential by way of the upper winding of the impulse relay R1870 to the dial conductor C154 of the trunk 150; and prepares, at the contacts 1851, a path traced hereinafter for applying battery potential by way of the upper and lower windings of the impulse relay R1870 in series to the dial conductor C154 of the trunk 150. Upon operating, the hold relay R2020 completes, at

the contacts 2021, a path, including the interrupted generator conductor C2042, the condenser 2041 and the contacts 2011 and 2072, for applying interrupted generator potential to the line conductor C122 of the trunk 121, thereby to give the calling switch ring-back tone indication. Also the hold relay R2020 completes, at the contacts 2022, an obvious path for applying ground potential to the tone start conductor C2044 extending to the timing and alarm equipment 2100 in order to initiate operation of the latter equipment at this time. Further the hold relay R2020 completes, at the contacts 2023, an obvious circuit for energizing the winding of the lock relay R1990, thereby to cause the latter relay to operate.

Upon operating, the lock relay R1990 completes, at the contacts 1993, an obvious circuit for energizing the right-hand winding of the answer relay R1940; however, the latter relay does not operate at this time as it is of the polarized type. Also the lock relay R1990 completes, at the contacts 1993, a circuit, including the contacts 1814, for energizing the winding of the signal relay R1830, thereby to cause the latter relay to operate shortly thereafter, the signal relay R1830 being of the slow-to-operate type. Further the lock relay R1990 completes, at the contacts 1994, a holding circuit, including the contacts 1924 and 1745, for energizing the upper winding of the first connect relay R1740, and a multiple circuit, including the contacts 1924 and 1744, for energizing the winding of the lockout relay R1710. When the above-traced holding circuit for energizing the upper winding of the first connect relay R1740 is energized the latter relay is retained in its operated position, thereby to retain the trunk 150 connected to the dial-back repeater 61, the trunk 150 extending to the toll line circuit 60 individually associated with the idle toll line 143 extending to the toll position in the manual exchange 33. As previously explained, the trunk distributor 1700 has operated prior to the seizure of the dial-back repeater 61 to connect an idle trunk thereto; such, for example, as the trunk 150 illustrated. When thus energized the first lockout relay R1710 operates to complete, at the contacts 1712, a circuit, including the contacts 1994, 1924 and 1744, C153 and the contacts 1281 and 1252, for energizing the winding of the switching relay R1230 in the toll line circuit 60, thereby to cause the latter relay to operate. Also, upon operating, the first lockout relay R1710 in the trunk distributor 1700 interrupts, at the contacts 1715, the previously traced holding circuit for energizing the winding of the first select relay R1730, thereby to cause the latter relay to restore. Further the first lockout relay R1710 interrupts, at the contacts 1718, the previously traced original circuit for energizing the lower winding of the first connect relay R1740; however, the latter relay is retained in its operated position due to the above-traced holding circuit for energizing the upper winding thereof.

Upon operating, the switching relay R1230 interrupts, at the contacts 1233, the previously traced path for applying battery potential by way of the lower winding of the impulse relay R1240 to the dial conductor C1278; and completes, at the contacts 1232, an obvious connection including the resistor 1280 between the dial conductor C1278 and the dial conductor C154 in the trunk 150. Also the switching relay R1230 interrupts, at the contacts 1235 and 1237, further points in

the previously traced connection between the line conductors C147 and C148 of the trunk 148 and the repeater 1270; and completes, at the contacts 1234 and 1236, an obvious connection between the line conductors C151 and C152 of the trunk 150 and the repeater 1270. Further the switching relay R1230 interrupts, at the contacts 1231, the normally completed connection between the left-hand winding of the answer relay R1220 and the repeater 1270.

Further the lock relay R1990 completes, at the contacts 1992, a test circuit between the control conductor C124 of the trunk 121 and the lower winding of the local call relay R1960. More particularly, in the event the present call from the calling switch constitutes a trunk call originating from the manual position in the manual exchange 30, 31 or 32, ground potential is applied to the control conductor C124 of the trunk 121, thereby to complete a path, including the contacts 1992 and 2083, for short-circuiting the lower winding of the local call relay R1960. On the other hand, in the event the present call from the calling switch constitutes a local call originating in the automatic exchange 35, battery potential is applied to the control conductor C124 of the trunk 121, thereby to complete a circuit substantially identical to that traced above for energizing the lower winding of the local call relay R1960; whereupon the latter relay operates. Further the lock relay R1990 completes, at the contacts 1995, an obvious path, including the contacts 2037, for applying ground potential to the motor start conductor C2048 extending to the timing and alarm equipment 2100, thereby to initiate operation of the latter equipment at this time. Also the lock relay R1990 prepares, at the contacts 1997, an obvious connection between the overflow meter M1825 and the overflow conductor C172; whereby the meter M1825 is operated at this time, in the event ground potential appears upon the last-mentioned conductor, as previously explained. Further the lock relay R1990 completes, at the contacts 1993, an obvious circuit for energizing the winding of the control relay R1970, thereby to cause the latter relay to operate. In the event the local call relay R1960 operates in the manner explained above, it interrupts, at the contacts 1961, a further point in a circuit traced hereinafter for energizing the lower winding of the trunk call relay R2060.

Upon operating the signal relay R1830 completes, at the contacts 1834, an obvious circuit for energizing the winding of the signal slave relay R1820, thereby to cause the latter relay to operate; and completes, at the contacts 1833, an obvious circuit, including the contacts 1811, for energizing the upper winding of the toll connect relay R1810, thereby to cause the latter relay to operate partially. Further the signal relay R1830 completes, at the contacts 1832, a circuit, including the generator conductor C1896, the resistor 1892, the contacts 1743, the dial conductor C154 of the trunk 150, the contacts 1332 and the resistor 1280, for projecting generator current over the dial conductor C1278 and consequently the toll line 143 extending to the manual exchange 33; whereby the operator at the toll position in the manual exchange 33 is signaled that a call is waiting to be answered on the toll line 143. Upon operating partially, the toll connect relay R1810 completes, at the contacts 1813, an obvious circuit, including the contacts 1833, for energizing the lower winding

thereof; whereby the latter relay operates fully, the toll connect relay R1810 being of the two-step type. Upon operating fully, the toll connect relay R1810 interrupts, at the contacts 1814, the previously traced circuit for energizing the winding of the signal relay R1820, thereby to cause the latter relay to restore. Upon restoring, the signal relay R1820 interrupts, at the contacts 1832, the previously traced circuit for projecting generator current over the dial conductor C1278; and completes, at the contacts 1831, a connection for applying battery potential by way of the upper and lower windings of the impulse relay R1870 in series to the dial conductor C1278. The last-mentioned connection extends from battery by way of the upper and lower windings of the impulse relay R1870, the resistor 1895, the contacts 1863, 1851, 1812, 1831 and 1743, C154, the contacts 1232 and the resistor 1280 to the dial conductor C1278. Further the signal relay R1820 interrupts, at the contacts 1834, the previously mentioned circuit for energizing the winding of the signal slave relay R1820, thereby to cause the latter relay to restore shortly thereafter, the signal slave relay R1820 being of the slow-to-release type. Upon restoring, the signal slave relay R1820 interrupts, at the contacts 1821, a previously completed path, including the resistor 1891, the contacts 1812, 1851 and 1863 and the resistor 1895, for short-circuiting the upper and lower windings of the impulse relay R1870 in series. The above-traced circuit, when completed, prevents the possible application of generator potential by way of the above-traced path to the dial conductor C1278 from effecting operation of the impulse relay R1870.

The operator at the toll position in the manual exchange 33 answers the call by inserting the answer plug of an idle cord circuit into the jack terminating the toll line 143, whereby ground potential is applied to the dial conductor C1278 in order to complete a circuit substantially identical to that previously traced for energizing in series the upper and lower windings of the impulse relay R1870, whereupon the latter relay operates. Upon operating, the impulse relay R1870 completes, at the contacts 1873, an obvious circuit for energizing the winding of the hold relay R1840, thereby to cause the latter relay to operate. Upon operating, the hold relay R1840 completes, at the contacts 1844, an obvious circuit for energizing the upper winding of the control relay R2010, thereby to cause the latter relay to operate; and completes, at the contacts 1845, a circuit, including the contacts 2036, for energizing the winding of the timer relay R1980, thereby to cause the latter relay to operate. Further the hold relay R1840 completes, at the contacts 1846, an obvious multiple point in the previously traced holding circuit for energizing the upper winding of the first connect relay R1740, for energizing the winding of the first lockout relay R1710 and for energizing the winding of the switching relay R1230, thereby to retain the relays mentioned in their operated positions. Further the hold relay R1840 completes, at the contacts 1841 and 1842, a communication connection between the trunk 121 and the repeater 1270. More particularly, the line conductors C122 and C123 of the trunk 121 are connected by way of the previously traced path to the windings 1918 and 1919 of the repeater 1915; and the winding 1918 of the repeater 1915 is connected by way of the contacts 75

1881, 1841 and 1741, C152, the contacts 1238, the winding 1271 of the repeater 1270, the condenser 1275, the winding 1272 of the repeater 1270, the contacts 1234, C151, the contacts 1742, 1842 and 1884 to the winding 1919 of the repeater 1915.

Upon operating, the control relay R2010 completes, at the contacts 2013, an obvious holding circuit, including the contacts 1993, for energizing the lower winding thereof; and interrupts, at the contacts 2011, the previously traced path for returning ring-back tone current over the line conductor C122 of the trunk 121. Upon operating, the timer relay R1980 vibrates its armature, thereby to complete intermittently, at the contacts 1985, an obvious circuit for energizing the winding of the tone stop relay R2030, whereby the latter relay operates an appreciable time interval thereafter due both to the vibration of the armature of the timer relay R1980 for a short time interval and the slow-to-operate characteristic of the tone stop relay R2030. Also the timer relay R1980 completes, at the contacts 1981, an obvious path for applying ground potential to the tone start conductor C2043 extending to the timing and alarm equipment 2100; and completes, at the contacts 1982, a connection, including the condenser 1936 and the contacts 2072 and 2074 between the upper winding of the local call relay R1960 and the line conductors C122 and C123 of the trunk 121. Also the timer relay R1980 prepares, at the contacts 1983, the previously mentioned circuit for energizing the lower winding of the trunk call relay R2060; which last-mentioned circuit is completed at this time in the event the local call relay R1960 occupies its restored position in order to cause the trunk call relay R2060 to operate.

In the event the present call over the calling switch to the trunk 121 constitutes a trunk call, the local call relay R1960 occupies its restored position; whereupon the trunk call relay R2060 operates at this time in order to complete, at the contacts 2061, an obvious holding circuit, including the contacts 1993, for energizing the upper winding thereof. Also the trunk call relay R2060 completes, at the contacts 2062, an obvious circuit, including the contacts 1843, for energizing the winding of the reverse battery relay R2070, thereby to cause the latter relay to operate. Upon operating, the reverse battery relay R2070 interrupts, at the contacts 2072 and 2074, the previously traced connection between the seizure relay R2050 and the impedance element I2040 and the line conductors C122 and C123 of the trunk 121; and completes, at the contacts 2071 and 2073, obvious connections between the impedance element I2040 and the seizure relay R2050 and the line conductors C122 and C123 of the trunk 121, whereby battery potential is reversed over the trunk 121 in order to render the calling operator at the manual position in one of the manual exchanges mentioned answer supervision, in an obvious manner.

On the other hand, in the event the present call over the calling switch to the trunk 121 constitutes a local call, the local call relay R1960 occupies its operated position in order to prevent operation of the trunk call relay R2060 and the consequent operation of the reverse battery relay R2070, in the manner explained above. Hence, in this event, battery potential is not reversed over the trunk 121. Moreover, in this event, tone current indicative of the class of the calling subscriber substation in the automatic exchange 33 is applied to the control conductor

C124 of the trunk 121 and is conducted through the lower winding of the local call relay R1960 to ground at the contacts 2083, as previously noted. The class tone current traversing the lower winding of the local call relay R1960 induces a corresponding tone voltage in the upper winding thereof which is connected by way of the previously traced path across the line conductors of the trunk 121 and, consequently, across the windings 1918 and 1919 of the repeater 1915; whereby class tone current traverses the windings 1271 and 1272 of the repeater 1270. The class tone current traversing the windings 1271 and 1272 of the repeater 1270 induces class tone voltage in the windings 1273 and 1274 thereof; whereby class tone current is returned over the toll line 143 to the toll position in the manual exchange 33 in order to indicate to the operator thereat the class of the calling subscriber substation in the automatic exchange 35 originating the present call.

Upon operating, the tone stop relay R2030 completes, at the contacts 2035, an obvious holding circuit, including the contacts 1845, for energizing the winding thereof; interrupts, at the contacts 2036, the previously traced circuit for energizing the winding of the timer relay R1980, thereby to cause the latter relay to restore; and completes, at the contacts 2031, an obvious path, including the contacts 1992, for short-circuiting the lower winding of the local call relay R1960, thereby to arrest the projection of class tone current over the toll line 143 to the toll position in the manual exchange 33. Also the tone stop relay R2030 completes, at the contacts 2033, an obvious multiple holding circuit for energizing the winding of the lock relay R1990; and interrupts, at the contacts 2037, the previously mentioned path for applying ground potential to the motor start conductor C2048 extending to the timing and alarm equipment 2100. Upon restoring, the timer relay R1980 interrupts, at the contacts 1982, the previously traced connection between the upper winding of the local call relay R1960 and the windings 1918 and 1919 of the repeater 1915; and interrupts, at the contacts 1981, the previously mentioned path for applying ground potential to the tone start conductor C2043 extending to the timing and alarm equipment 2100. When the lower winding of the local call relay R1960 is thus short-circuited incident to the operation of the tone stop relay R2030 the local call relay R1960 restores.

In view of the foregoing explanation of the mode of operation of the apparatus incorporated in the dial-back repeater 61, it will be understood that the class tone current is returned over the toll line 143 to the toll position in the manual exchange 33 only for a short time interval after the operator thereat answers the call. In the event the operator wishes to verify the class of service rendered the calling subscriber substation in the automatic exchange 35, she may do so by withdrawing the answer plug of the cord circuit from the jack terminating the toll line 143 for a short time interval and then reinserting the same into the jack mentioned. When the answer plug of the cord circuit is withdrawn from the jack terminating the toll line 143 the previously traced circuit for energizing in series the upper and lower windings of the impulse relay R1870 is interrupted; thereby to cause the latter relay to restore and effect the restoration of the hold relay R1840 shortly thereafter, the hold relay R1840 being of the slow-to-release type, in an obvious

manner. Upon restoring, the hold relay R1840 interrupts, at the contacts 1845, the previously traced holding circuit for energizing the winding of the tone stop relay R2030, thereby to cause the latter relay to restore and interrupt, at the contacts 2031, the previously traced path for short-circuiting the lower winding of the local call relay R1960. When the operator again inserts the answer plug of the cord circuit into the jack terminating the toll line 143 the impulse relay R1870 again operates to effect operation of the hold relay R1840. Upon operating the hold relay R1840 completes, at the contacts 1845, the previously traced circuit for energizing the winding of the timer relay R1850; whereby the latter relay operates in order to cause the class tone current to be returned over the toll line 143 to the toll position in the manual exchange 33, in the manner previously explained, and to effect operation of the tone stop relay R2030 shortly thereafter. Upon operating, the tone stop relay R2030 again completes, at the contacts 2031, the previously traced path for short-circuiting the lower winding of the local call relay R1960 and effects restoration of the timer relay R1850, whereby the return of the class tone current over the toll line 143 to the toll position in the manual exchange 33 is arrested. The operator at the toll position in the manual exchange 33 may verify or check the class of service rendered the calling subscriber in the automatic exchange 35 as many times as she sees fit, in the manner explained above.

At this time an operative connection is completed from the calling switch by way of the trunk 121, the dial-back repeater 61, the trunk 150, the toll line circuit 60 and the toll line 143 to the toll position in the manual exchange 33. This call may be extended by the operator at the toll position in the manual exchange 33 forwardly to a called circuit not included in the system illustrated or backwardly over the dial-back repeater 61 and the associated incoming selector 54 to a called circuit included in the system illustrated. First assuming that the call is to be extended forwardly to a called circuit not included in the system illustrated, the operator at the toll position in the manual exchange 33 extends the call by way of the call plug of the cord circuit utilized and completes the ultimate connection, all in accordance with conventional practice.

Considering now the release of the call completed by way of the dial-back repeater 61 and extended forwardly through the toll position in the manual exchange 33, when the calling switch is released the trunk 121 is disengaged, thereby to interrupt the previously traced circuit for energizing the winding of the seizure relay R2050, whereupon the latter relay restores. Upon restoring, the seizure relay R2050 interrupts, at the contacts 2053, the previously mentioned circuit for energizing the winding of the hold relay R2020; thereby to cause the latter relay to restore shortly thereafter, the hold relay R2020 being of the slow-to-release type. Also the seizure relay R2050 interrupts, at the contacts 2054, the previously traced circuit for energizing the winding of the supervisory relay R1850, thereby to cause the latter relay to restore. Upon restoring, the supervisory relay R1850 interrupts, at the contacts 1851, the previously traced path for applying battery potential by way of the upper and lower windings of the impulse relay R1870 in series to the dial conductor C1278; and com-

plete, at the contacts 1852, the previously traced path for applying battery potential by way of the upper winding of the impulse relay R1870 to the dial conductor C1278. The consequent decrease in the resistance interposed between battery and the dial conductor C1278 is effective to signal the operator at the toll position in the manual exchange 33 that the established connection, including the toll line 143, has been released by the calling switch. Upon restoring, the hold relay R2020 interrupts, at the contacts 2022, the previously mentioned path for applying ground potential to the tone start conductor C2044 extending to the timing and alarm equipment 2100; and interrupts, at the contacts 2023, one of the multiple holding circuits for energizing the winding of the lock relay R1990; however, the latter relay remains in its operated position at this time due to the operated position of the tone stop relay R2030.

Upon receiving disconnect supervision the operator at the toll position in the manual exchange 33 withdraws the answer plug of the cord circuit in use from the jack terminating the toll line 143, thereby to interrupt the previously traced circuit for energizing the upper winding of the impulse relay R1870, whereupon the latter relay restores. Upon restoring, the impulse relay R1870 interrupts, at the contacts 1873, the previously mentioned circuit for energizing the winding of the hold relay R1840, thereby to cause the latter relay to restore shortly thereafter, the hold relay R1840 being of the slow-to-release type. Upon restoring, the hold relay R1840 interrupts, at the contacts 1845, the previously mentioned circuit for energizing the winding of the reverse battery relay R2070, thereby to cause the latter relay to restore, in the event it was previously operated. Also the hold relay R1840 interrupts, at the contacts 1845, the previously traced holding circuit for energizing the winding of the tone stop relay R2030, thereby to cause the latter relay to restore. Upon restoring, the tone stop relay R2030 interrupts, at the contacts 1933, the previously mentioned holding circuit for energizing the winding of the lock relay R1990, thereby to cause the latter relay to restore.

Upon restoring, the lock relay R1990 interrupts, at the contacts 1993, the previously traced multiple holding circuits for energizing the lower winding of the control relay R2010 and the lower winding of the toll connect relay R1810, thereby to cause the relays mentioned to restore. Also the lock relay R1990 interrupts, at the contacts 1993, the previously traced circuit for energizing the right-hand winding of the answer relay R1940 and the previously traced holding circuit for energizing the upper winding of the trunk call relay R2060, in the event the last-mentioned relay is operated, thereby to cause the relays mentioned to restore. Further the lock relay R1990 interrupts, at the contacts 1993, the previously mentioned circuit for energizing the winding of the control relay R1970, thereby to cause the latter relay to restore shortly thereafter, the control relay R1970 being of the slow-to-release type. Also the lock relay R1990 interrupts, at the contacts 1994, the previously traced multiple holding circuits for energizing the upper winding of the first connect relay R1740 and the winding of the first lockout relay R1710 in the trunk distributor 1700 and the winding of the switching relay R1230 in the toll line circuit 60, thereby to cause the relays mentioned

to restore. Upon restoring, the first connect relay R1740 interrupts, at the contacts 1741, etc., the connections between the dial-back repeater 61 and the trunk 150 extending to the toll line circuit 60.

Upon restoring, the lockout relay R1710 completes, at the contacts 1713, the previously mentioned chain circuit for energizing the connect relay corresponding to the next operated select relay. For example, the lockout relay R1710 may complete, at the contacts 1713, a circuit for energizing the lower winding of the third connect relay R1780, this circuit extending from ground by way of the contacts 1783, etc., 1713, 1731, etc., and 1712 and the lower winding of R1780 to battery. When thus energized the third connect relay R1780 operates to complete, at the contacts 1781, etc., obvious connections between the third trunk extending to the third toll line circuit, not shown, and the dial-back repeater 61. Also the first lockout relay R1710 completes, at the contacts 1711, the previously mentioned path for applying battery potential by way of the winding of the busy relay R1720 to the control conductor C153 of the trunk 150 extending to the toll line circuit 60, for the purpose previously explained.

Upon restoring, the switching relay R1230 interrupts, at the contacts 1234 and 1236, the previously traced connection between the trunk 150 and the repeater 1270; and reprepares, at the contacts 1235 and 1237, the previously traced connection between the trunk 146 extending to the incoming selector 53 and the repeater 1270. Further the switching relay R1230 interrupts, at the contacts 1232, the previously traced connection between the dial conductor C1278 and the dial conductor C154 of the trunk 150; and re-completes, at the contacts 1233, the previously traced path for applying battery potential by way of the lower winding of the impulse relay R1240 to the dial conductor C1278.

Finally the tone stop relay R2030 interrupts, at the contacts 2031, the previously mentioned path for applying ground potential to the control conductor C124 of the trunk 121, whereby the previously traced circuit for energizing the winding of the first marking relay R2210 in the repeater allotter 13 is interrupted in order to cause the latter relay to restore.

Upon restoring, the first marking relay R2210 marks the first trunk 121 of the three constituting the tenth group as idle for subsequent pre-selection by the repeater allotter 13 to the use of the automatic switches having access thereto. At this time the dial-back repeater 61 is completely released; the trunks 121 and 150 are marked as idle; the dial-back repeater 61 is operatively connected to the third trunk illustrated extending to the third toll line circuit, not shown; and the toll line 143 is marked as idle and connected by way of the trunk 146 to the incoming selector 53.

In the foregoing explanation of the mode of operation of the dial-back repeater 61 incident to the seizure of the trunk 121 by a calling switch, it was assumed that the calling switch was governed from a manual operator position in one of the exchanges 30, 31 or 32 or from a subscriber substation in the automatic exchange 35. However, it may occur that the trunk 121 is seized due to a faulty operation of the calling switch as the result of a permanent fault therein. In this event, when the trunk 121 is seized the dial-back repeater 61 operates in order to cause the call to be routed by way of the trunk preselected by the

trunk distributor 1700 and the corresponding toll line circuit and toll line to the toll position in the manual exchange 33, in the manner explained above. The operator at the toll position in the manual exchange 33 then answers the call and endeavors to converse over the toll line, the dial-back repeater 61, the trunk 121 and the calling switch, all in the manner previously explained. In the event the operator at the toll position in the manual exchange 33 is unable to converse over the connection, she assumes that the connection was routed to her position due to a fault and then withdraws the answer plug of the cord circuit in use from the jack terminating the associated toll line, whereby the impulse relay R1870 restores in order to cause the restoration of the hold relay R1840 in the dial-back repeater 61, all in the manner previously explained. Upon restoring, the hold relay R1840 interrupts, at the contacts 1845, the previously traced holding circuit for energizing the winding of the tone stop relay R2030, thereby to cause the latter relay to restore. Upon restoring, the tone stop relay R2030 completes, at the contacts 2037, the previously mentioned path for applying ground potential to the motor start conductor C2048 extending to the timing and alarm equipment 2100; whereby operation of the last-mentioned equipment is initiated and ground potential is applied to the timer conductor C2046. The application of ground potential to the timer conductor C2046 completes a circuit, including the contacts 2085, 2034, 1984 and 1996, for energizing the upper winding of the alarm relay R2080, thereby to cause the latter relay to operate. Upon operating, the alarm relay R2080 completes, at the contacts 2084, an obvious holding circuit substantially identical to that previously traced for energizing the upper winding thereof; and interrupts, at the contacts 2085, the previously traced original circuit for energizing the upper winding thereof. Also the alarm relay R2080 completes, the contacts 2082, an alternative path, including the grounded timer conductor C2045, the lower winding of the local call relay R1960 and the contacts 1992, for applying ground potential to the control conductor C124 of the trunk 121; and interrupts, at the contacts 2083, the previously traced original path for applying ground potential to the control conductor C124 of the trunk mentioned.

After a predetermined time interval the timing and alarm equipment 2100 operates in order to cause ground potential to be removed from the timer conductor C2045 and consequently from the connected control conductor C124 of the trunk 121, whereby the calling switch is released in order to effect the restoration of the seizure relay R2050. Upon restoring, the seizure relay R2050 effects the complete release of the dial-back repeater 61, in the manner previously explained.

Reconsidering now the operation of the trunk distributor 1700 forming a part of the dial-back repeater 61 in greater detail, it is pointed out that, when the operator at the toll position in the manual exchange 33 initiates a call over the first toll line 143 and the associated incoming selector 53, the first busy relay R1720 is operated, thereby to effect the restoration of the first select relay R1730 and the first connect relay R1740, all in the manner previously explained, whereby the trunk 150 extending to the toll line circuit 60 individual to the first toll line 143 is disconnected from the dial-back repeater 61. Upon restoring, the first select relay R1730 effects the op-

eration of the next preceding select relay and the associated connect relay, whereby the dial-back repeater 61 is connected to an idle one of the trunks, all in the manner previously explained.

Also when a call is extended to the dial-back repeater 61 the first lockout relay R1710 operates in order to effect the restoration of the first select relay R1730 and to prevent further operation of the other select relays; and the first connect relay R1740 is retained in its operated position, whereby the call extended to the dial-back repeater 61 is routed by way of the trunk 150, the toll line circuit 60 and the first toll line 143 to the toll position in the manual exchange 33 to be answered. Subsequently, when the above-mentioned connection is released the first connect relay R1740 and the first lock-out relay R1710 restore, whereby the next select relay and the associated connect relay are operated, all in the manner previously explained; whereby the next idle trunk is connected to the dial-back repeater 61.

In view of the foregoing explanation of the mode of operation of the trunk distributor 1700, it will be understood that the three trunks 150, etc., are utilized in rotation. When each of the trunks mentioned has been utilized in turn in conjunction with the dial-back repeater 61, all of the select relays R1730, etc., occupy their restored positions and, when all of the lockout relays R1710, etc., occupy their operated positions, a circuit is completed for energizing the winding of the reset relay R1790. The last-mentioned circuit extends from ground by way of the contacts 1735, etc., 1775 and the winding of R1790 to battery. When thus energized the reset relay R1790 operates to complete, at the contacts 1791, multiple circuits for energizing the windings of the various select relays R1730, etc. For example, the circuit for energizing the winding of the first select relay R1730 extends from ground by way of the contacts 1715 and 1721, the winding of R1730, the contacts 1734, 1714, etc., 1755 and 1791 and the resistor 1794 to battery. When thus energized the first select relay R1730 operates to complete, at the contacts 1733, the previously traced holding circuit for energizing the winding thereof; and to interrupt, at the contacts 1734, the above-traced original operating circuit for energizing the winding thereof. The other select relays R1710, etc., operate and complete holding circuits for energizing the windings thereof in a similar manner. The first select relay R1730 completes, at the contacts 1732, the previously traced circuit for energizing the lower winding of the first connect relay R1740; thereby to cause the latter relay to operate and connect the first trunk 150 to the dial-back repeater 61, in the manner previously explained. Also the first select relay R1730 interrupts, at the contacts 1735, the previously traced chain circuit for energizing the winding of the reset relay R1790; thereby to cause the latter relay to restore shortly thereafter, the reset relay R1790 being of the slow-to-release type. Also it is noted that, upon operating, the reset relay R1790 completes, at the contacts 1793, a path, including the contacts 1871 and 1981, for applying ground potential to the control conductor C124 of the trunk 121 in the event the dial-back repeater 61 is idle at this time, the control relay R1870 and the lock relay R1990 occupying their restored positions; whereby the dial-back repeater 61 is marked against seizure for the short time interval while the

trunk distributor 1700 is recycling the select relays R1730, etc., in the manner explained above. Further, while the reset relay R1790 occupies its operated position, there is completed, at the contacts 1792, an obvious connection between the trunk overflow conductor C172 and the overflow meter M1825; whereby the meter mentioned may be operated at this time in the event ground potential appears upon the trunk overflow conductor C172, all in the manner previously explained.

Dial-back call from the manual exchange 33

As explained above, the call which was routed from the calling switch by way of the trunk 121, the dial-back repeater 61, the trunk 150 and the toll line 143 to the toll position in the manual exchange 33 may be extended after the operator thereat answers it either forwardly to a called circuit not included in the system illustrated or backwardly over the dial-back repeater 61 to a called circuit included in the system illustrated. For purpose of illustration, assuming that the above-traced call extending from the calling switch by way of the dial-back repeater 61 and the toll line 143 and answered at the toll position in the manual exchange 33 is to be extended backwardly via the dial-back repeater 61, the trunk 155 and the incoming selector 54 to a called circuit included in the system illustrated, the operator first obtains the information concerning the extension of the call and then dials the preliminary digit 1 over the toll line 143. The impulse relay R1870 follows the single impulse of the preliminary digit 1, restoring and reoperating in the manner previously explained. Upon restoring, the impulse relay R1870 interrupts, at the contacts 1873, the previously mentioned circuit for energizing the winding of the hold relay R1840; however, the latter relay does not restore during impulsing as it is of the slow-to-release type. Also the impulse relay R1870 completes, at the contacts 1872, an obvious multiple circuit, including the contacts 1823 and 1843, for energizing the winding of the dial relay R1860 and the upper winding of the bridge relay R1880, thereby to cause the relays mentioned to operate. Upon operating, the dial relay R1860 completes, at the contacts 1864, an obvious holding circuit for energizing the lower winding of the bridge relay R1880; and interrupts, at the contacts 1861, a path traced hereinafter for connecting the condenser 1893 across the impulsing contacts 1871 of the impulse relay R1870. Also the dial relay R1860 completes, at the contacts 1862, an obvious alternative path, including the contacts 1851, for applying battery potential by way of the upper winding of the impulse relay R1870 to the dial conductor C1278; and interrupts, at the contacts 1863, the previously traced path, including the contacts 1851, for applying battery potential by way of the upper and lower windings of the impulse relay R1870 in series to the dial conductor C1278.

Upon operating, the bridge relay R1880 interrupts, at the contacts 1881 and 1884, the previously traced connection between the repeater 1270 and the windings 1918 and 1919 of the repeater 1915; and completes, at the contacts 1882, an obvious path, including the contacts 2024, for short-circuiting the winding 1916 of the repeater 1915. Also, the bridge relay R1880 prepares, at the contacts 1883, an impulse circuit traced hereinafter, including the winding 1917 of the repeater 1915, which is ultimately completed between the line conductors of the trunk 155 extending

5 to the incoming selector 54. Upon reoperating, the impulse relay R1870 recompletes, at the contacts 1873, the previously mentioned circuit for energizing the winding of the hold relay R1840; and prepares, at the impulsing contacts 1871, the impulsing circuit previously mentioned. Also the impulse relay R1870 interrupts, at the contacts 1872, the previously traced multiple circuits for energizing the winding of the dial relay R1860 and the upper winding of the bridge relay R1880. However, the dial relay R1860 does not immediately restore as it is of the slow-to-release type; and the bridge relay R1880 does not restore due to the completed holding circuit for energizing the lower winding thereof by the operated dial relay R1860. Further the impulse relay R1870 completes, at the contacts 1873, a circuit, including the contacts 1885, 2032 and 1954, for energizing the upper winding of the selector connect relay R1850, thereby to cause the latter relay to operate. Upon operating, the selector connect relay R1850 completes, at the contacts 1955, an obvious holding circuit, including the contacts 1893, for energizing in series the upper and lower windings thereof; and interrupts, at the contacts 1854, the previously traced operating circuit for energizing the upper winding thereof. Also the selector connect relay R1850 completes, at the contacts 1853, an obvious circuit for energizing the winding of the control relay R1930, thereby to cause the latter relay to operate. Further the selector connect relay R1850 completes, at the contacts 1951 and 1952, a loop circuit including the previously mentioned impulsing contacts 1871 between the line conductors of the trunk 155 extending to the incoming selector 54. More particularly, one of the line conductors of the trunk 155 is connected by way of the contacts 1952, the winding 1917 of the repeater 1915, the contacts 1871 and 1883, the resistor 1894, the contacts 1882 and 1851 to the other line conductor of the trunk 155.

Upon operating, the control relay R1930 interrupts, at the contacts 1832, the previously traced circuit for energizing the winding of the supervisory relay R1850, thereby to cause the latter relay to restore. Upon restoring, the supervisory relay R1850 interrupts, at the contacts 1851, the previously traced circuit, including the contacts 1862, for energizing the upper winding of the impulse relay R1870; and completes, at the contacts 1852, the previously traced original circuit for energizing the upper winding of the impulse relay R1870. Upon restoring, the dial relay R1860 interrupts, at the contacts 1864, the previously mentioned holding circuit for energizing the lower winding of the bridge relay R1880, thereby to cause the latter relay to restore. Upon restoring, the bridge relay R1880 recompletes, at the contacts 1881 and 1884, the previously traced connection between the repeater 1270 and the windings 1918 and 1919 of the repeater 1915; and interrupts, at the contacts 1882 and 1883, the previously traced impulsing circuit extending between the line conductors of the trunk 155. However, at this time, a holding circuit is completed between the line conductors of the trunk 155 which extends from one of the line conductors thereof by way of the contacts 1952, the winding 1917 of the repeater 1915, the contacts 1871, the left-hand winding of the answer relay R1940, the contacts 2024, the winding 1916 of the repeater 1915 and the contacts 1951 to the other line conductor of the trunk 155. At this time the incoming selector 54 is seized due to the

completed holding circuit between the line conductors of the trunk 155 and causes dial tone current to be returned over the previously traced holding circuit including the windings 1916 and 1917 of the repeater 1915. The dial tone current traversing the windings 1916 and 1917 of the repeater 1915 induces dial tone voltage into the windings 1918 and 1919 thereof, whereby dial tone current is returned over the previously traced circuit including the windings 1271 and 1272 of the repeater 1270. The dial tone current traversing the windings 1271 and 1272 of the repeater 1270 induces dial tone voltage in the windings 1273 and 1274 thereof, whereby dial tone current is returned over the toll line 143 to the toll position in the manual exchange 33.

The operator at the toll position in the manual exchange 33 then proceeds to dial the first digit over the toll line 143, whereby the impulse relay R1870 again follows the digit mentioned, in the manner previously explained. Upon the first restoration of the impulse relay R1870 the previously traced circuits for energizing the winding of the dial relay R1860 and the upper winding of the bridge relay R1880 are completed, thereby to cause the latter relays to reoperate. Upon reoperating, the dial relay R1860 completes, at the contacts 1884, the previously mentioned holding circuit for energizing the lower winding of the bridge relay R1880. Upon reoperating, the bridge relay R1880 interrupts, at the contacts 1881 and 1884, the previously traced connection between the windings 1918 and 1919 of the repeater 1915 and the repeater 1270; and prepares, at the contacts 1882 and 1883, the previously traced impulsive circuit connected across the line conductors of the trunk 155. Upon the first reoperation of the impulse relay R1870 the previously traced circuit for energizing the winding of the dial relay R1860 is interrupted at the contacts 1872; and the previously traced impulsive circuit between the line conductors of the trunk 155 is completed at the contacts 1871. Both the hold relay R1840 and the dial relay R1860 are of the slow-to-release type and remain operated during impulsive, the dial relay R1860 retaining operated the bridge relay R1880. Accordingly the impulse relay R1870 repeats, at the impulsive contacts 1871, the impulses of the first digit over the trunk 155 to the incoming selector 54, whereby the last-mentioned selector is operated in a manner entirely identical to the operation of the incoming selector 53, previously explained.

At the conclusion of the first digit the impulse relay R1870 reoperates, thereby to effect the restoration of the dial relay R1860 shortly thereafter and the consequent restoration of the bridge relay R1880, all in the manner previously explained. The operator then dials second and following digits over the toll line 143, whereby the impulse relay R1870 in the dial-back repeater 61 repeats the second digit and subsequent digits over the incoming selector 54 to the ultimately called circuit, in the event this is necessary. The called circuit is then rung and, when the call is answered thereon, battery potential is reversed over the trunk 155; whereby the current traversing the previously traced holding circuit, including the left-hand winding of the answer relay R1940, is reversed in order to cause the latter relay to operate, the answer relay R1940 being of the polarized type. Upon operating, the answer relay R1940 completes, at the contacts 1941, an obvious circuit for energizing the lower winding of the shunt relay R1920, thereby to cause the

latter relay to operate; and completes, at the contacts 1942, an alternative circuit, including the contacts 1933 and 2054, for energizing the winding of the supervisory relay R1850, thereby to cause the latter relay to operate. Also the answer relay R1940 completes, at the contacts 1943, a multiple holding circuit for energizing the winding of the reverse battery relay R2070 in the event the last-mentioned relay occupies its operated position, as previously explained. Further the answer relay R1940 completes, at the contacts 1943, a multiple holding circuit substantially identical to that previously traced for energizing the winding of the tone stop relay R2030.

Upon operating, the supervisory relay R1850 completes, at the contacts 1851, the previously traced circuit for energizing in series the upper and lower windings of the impulse relay R1870; and interrupts, at the contacts 1852, the previously traced circuit for energizing the upper winding of the impulse relay R1870. The consequent increase in the resistance of battery potential applied to the dial conductor C1278 is effective to signal the operator at the toll position in the manual exchange 33 that the called circuit has answered. Upon operating, the shunt relay R1920 completes, at the contacts 1921, an obvious path for short-circuiting the impulsive contacts 1871 in order to complete a holding circuit between the line conductors of the trunk 155 exclusive of the impulsive contacts 1871. The operator at the toll position in the manual exchange 33 is operatively connected to the windings 1918 and 1919 of the repeater 1915 by way of the previously traced circuit; the calling switch is connected by way of the previously traced circuit, including the trunk 121, to the windings 1918 and 1919 of the repeater 1915; and the called circuit is connected by way of the previously traced circuit, including the incoming selector 54 and the trunk 155, to the windings 1916 and 1917 of the repeater 1915. Accordingly, at this time, a three-way communication connection is completed, including the calling switch, the called circuit and the toll position in the manual exchange 33. After the operator at the toll position in the manual exchange 33 verifies the completion of the call between the calling switch and the called circuit, she releases the connection between her position and the toll line 143 by withdrawing the answer plug of the cord circuit in use from the jack terminating the toll line 143; whereby the previously traced circuit for energizing in series the upper and lower windings of the impulse relay R1870 in the dial-back repeater 61 is interrupted. The impulse relay R1870 then restores, thereby to interrupt, at the contacts 1813, the previously mentioned circuit for energizing the winding of the hold relay R1840, whereupon the latter relay restores shortly thereafter. Also the impulse relay R1870 completes, at the contacts 1812, a holding circuit, including the contacts 1831 and 1825, for energizing the upper winding of the shunt relay R1920. Upon restoring, the hold relay R1840 interrupts, at the contacts 1846, the previously traced holding circuit for energizing the upper winding of the first connect relay R1740 and the winding of the lock-out relay R1710 in the trunk distributor 1700 and the winding of the switching relay R1230 in the toll line circuit 60, thereby to cause the latter relays to restore, all in the manner previously explained.

Considering now the release of the established connection between the calling switch and the

called circuit, including the trunk 121, the dial-back repeater 81, the trunk 155 and the incoming selector 54, when the calling switch is released the previously traced circuit for energizing the winding of the seizure relay R2050 is interrupted, thereby to cause the latter relay to restore. Upon restoring, the seizure relay R2050 interrupts, at the contacts 2051, a multiple point in the previously traced connection between the trunk 155 and the windings 1916 and 1917 of the repeater 1915, including the left-hand winding of the answer relay R1940; and interrupts, at the contacts 2053, the previously mentioned circuit for energizing the winding of the hold relay R2020, thereby to cause the latter relay to restore shortly thereafter, the hold relay R2020 being of the slow-to-release type. Also the seizure relay R2050 interrupts, at the contacts 2054, the previously traced circuit for energizing the winding of the supervisory relay R1850, thereby to cause the latter relay to restore. Further the seizure relay R2050 completes, at the contacts 2052, a circuit, including the contacts 1922 and 1952, the winding 1917 of the repeater 1915 and one of the line conductors of the trunk 155, for energizing the winding of the release relay R1910, thereby to cause the latter relay to operate. Upon operating, the release relay R1910 completes, at the contacts 1911, an obvious multiple holding circuit for energizing the winding of the tone stop relay R2030. Upon restoring, the hold relay R2020 interrupts, at the contacts 2024, the previously traced connection between the line conductors of the trunk 155 and the windings 1916 and 1917 of the repeater 1915, thereby to effect the transmission of a release signal over the called circuit including the incoming selector 54. Also, when the previously traced connection between the windings 1916 and 1917 of the repeater 1915 and the line conductors of the trunk 155 is interrupted, the left-hand winding of the answer relay R1940 is interrupted, thereby to cause the latter relay to restore. When the called circuit is released battery potential is reversed over the trunk 155; whereby a path substantially identical to that previously traced is completed for short-circuiting the winding of the release relay R1910 in order to cause the latter relay to restore.

Upon restoring, the release relay R1910 interrupts, at the contacts 1911, the previously traced holding circuit for energizing the winding of the tone stop relay R2030, thereby to cause the latter relay to restore and interrupt, at the contacts 2033, the previously mentioned holding circuit for energizing the winding of the lock relay R1990 in order to cause the latter relay to restore. Upon restoring, the lock relay R1990 interrupts, at the contacts 1992, the previously traced path for applying ground potential by way of the lower winding of the local call relay R1960 to the control conductor C124 of the trunk 121; and interrupts, at the contacts 1993, the previously mentioned holding circuits for energizing the lower winding of the control relay R1910 and for energizing the lower winding of the toll connect relay R1810, whereupon the relays mentioned restore. Also the lock relay R1990 interrupts, at the contacts 1993, the previously mentioned circuit for energizing the right-hand winding of the answer relay R1940 and the previously mentioned holding circuit for energizing the upper winding of the trunk call relay R2060, in the event the last-mentioned relay occupies its operated position; whereupon the trunk call relay R2060 restores. Further, the

lock relay R1990 interrupts, at the contacts 1993, the previously mentioned circuit for energizing the winding of the control relay R1970; whereupon the latter relay restores shortly thereafter, the control relay R1970 being of the slow-to-release type. Further, the lock relay R1990 interrupts, at the contacts 1993, the previously mentioned holding circuit for energizing in series the upper and lower windings of the selector connect relay R1950, thereby to cause the latter relay to restore. Upon restoring, the selector connect relay R1950 interrupts, at the contacts 1953, the previously mentioned circuit for energizing the winding of the control relay R1930, thereby to cause the latter relay to restore; and interrupts, at the contacts 1951 and 1952, further points in the previously traced connection between the repeater 1915 and the trunk 155. Also, upon restoring, the answer relay R1940 interrupts, at the contacts 1943, the previously mentioned circuit for energizing the winding of the reverse battery relay R2070, thereby to cause the latter relay to restore, in the event it was previously operated. At this time, the dial-back repeater 81 and the incoming selector 54 are completely released.

In the foregoing explanation of the release of the dial-back repeater 81 it was assumed that the calling switch was released prior to the release of the called circuit; however, it may occur that the called circuit is released first. In the last-mentioned event, the previously traced circuit for energizing the left-hand winding of the answer relay R1940 is interrupted when the called circuit is released, thereby to restore and interrupt, at the contacts 1942, the previously traced circuit for energizing the winding of the supervisory relay R1850, whereupon the latter relay restores. Also the answer relay R1940 interrupts, at the contacts 1943, the previously traced holding circuit for energizing the winding of the tone stop relay R2030, whereupon the latter relay restores. Further the answer relay R1940 interrupts, at the contacts 1943, the previously traced circuit for energizing the winding of the reverse battery relay R2070, thereby to cause the latter relay to restore in the event it was operated. Upon restoring, the reverse battery relay R2070 causes battery potential to be reversed over the line conductors C122 and C123 of the trunk 121, in the event it was operated, in the manner previously explained, in order to render the calling switch disconnect supervision.

When the calling switch is then released the previously traced circuit for energizing the winding of the seizure relay R2050 is interrupted, thereby to cause the latter relay to restore and effect the restoration of the hold relay R2020 shortly thereafter, in the manner previously explained. Upon restoring, the hold relay R2020 interrupts, at the contacts 2023, the previously mentioned circuit for energizing the winding of the lock relay R1990, thereby to cause the latter relay to restore. Upon restoring, the lock relay R1990 interrupts, at the contacts 1993, the previously traced circuit for energizing the right-hand winding of the answer relay R1940; and effects the restoration of the control relays R1910 and R2010, the selector connect relay R1950, the toll connect relay R1810 and the trunk call relay R2060, in the event the latter relay occupies its operated position, all in the manner previously explained. At this time the dial-back repeater 81 is completely released and available for further use.

Call from the automatic exchange 34

Considering the extension of a call from the automatic exchange 34, the calling subscriber therein initiates the call and dials the required digits to cause the automatic switching apparatus in the automatic exchange 34 to seize the composite equipment associated with an idle trunk, such, for example, as the trunk 165. When the trunk 165 is thus seized the automatic switching apparatus applies battery potential thereto over the dial conductor C2414, thereby to complete a circuit, including the contacts 2448, 2171, 2762, 2641 and 2662, for energizing the lower winding of the impulse relay R2410, whereupon the latter relay operates. Upon operating, the impulse relay R2410 completes, at the contacts 2413, a circuit, including the contacts 2734, for energizing the winding of the hold relay R2430, thereby to cause the latter relay to operate. Upon operating, the hold relay R2430 completes, at the contacts 2432, an obvious path for applying ground potential to the control conductor C169 of the trunk 166, thereby to cause the trunk group allotter 74 to operate and mark the trunk 166 as busy to the switches having access thereto, in the manner previously explained.

Also, the hold relay R2430 interrupts, at the contacts 2435, a path, including the contacts 2644, 2653 and 2745, for applying battery potential by way of the winding of the busy relay R2760 to the control conductor C118 of the trunk 113, for a purpose more fully explained hereinafter. Further the hold relay R2430 completes, at the contacts 2434, an obvious circuit for energizing the winding of the hold slave relay R2420, thereby to cause the latter relay to operate shortly thereafter, the hold slave relay R2420 being of the slow-to-operate type. The application of ground potential to the control conductor C169 also completes an obvious circuit for energizing the upper winding of the answer relay R2620, thereby to prepare the latter relay to operate subsequently, the answer relay R2620 being of the polarized type. Further, the hold relay R2430 completes, at the contacts 2431, a loop circuit including the winding of the control relay R2610 and the lower winding of the answer relay R2620 between the line conductors C114 and C115 of the trunk 113. The last-mentioned circuit extends from the line conductor C114 of the trunk 113 by way of the contacts 2441 and 2431, the winding 2473 of the repeater 2470, the contacts 2443, the winding of R2810, the lower winding of R2620, the contacts 2445, the winding 2474 of the repeater 2470, the contacts 2411 and 2442 to the line conductor C115 of the trunk 113. When the above-traced loop circuit is completed between the line conductors C114 and C115 of the trunk 113 the control relay R2610 in the automatic repeater 62 operates and the line circuit 81 terminating the trunk 113 operates; thereby to mark the trunk 113 as a calling trunk by way of the control conductors C170 extending to the call allotter 90. The call allotter 90 then operates in order to mark the trunk 113 as a calling trunk through the link allotter 91 and the cable 95 to the link preselected by the link allotter 91, such, for example, as the first link 92. When the trunk 113 is thus marked through the link allotter 91 by way of the cable 95 to the first link 92 the finder 93 thereof operates to seize the trunk 113; whereby the first link 92 is operatively connected to the trunk 113 and the connector 94 is rendered responsive to digits dialed thereinto.

The calling subscriber in the automatic ex-

change 34 then dials the next digit which is transmitted over the dial conductor C2414 and followed by the impulse relay R2410, in an obvious manner. The impulse relay R2410 repeats 5 the impulses of the digit mentioned, at the contacts 2411, over the trunk 113 to the first link 92. Upon the first restoration of the impulse relay R2410 there is interrupted, at the contacts 2413, the previously traced circuit for energizing 10 the winding of the hold relay R2430; and there is completed, at the contacts 2412, a circuit, including the contacts 2421 and 2734, for energizing the winding of the bridge relay R2510; whereupon the latter relay operates. The hold relay 15 R2430 and the bridge relay R2510, being of the slow-to-release type, do not restore during impulsion. Upon operating, the bridge relay R2510 completes, at the contacts 2514, an obvious circuit for energizing the winding of the control 20 relay R2650; and completes, at the contacts 2515, an obvious circuit for energizing the winding of the shunt relay R2550, whereupon the relays mentioned operate. Upon operating, the shunt relay R2550 completes, at the contacts 2554, an obvious circuit for energizing the winding of the shunt relay R2540, thereby to cause the latter relay to operate. Also, upon operating, the bridge relay R2510 prepares, at the contacts 2511, a direct impulsion bridge between the line conductors C114 and C115 of the trunk 113; completes, 30 at the contacts 2512, an obvious path for short-circuiting the winding 2474 of the repeater 2470; completes, at the contacts 2511, an obvious path for short-circuiting the winding of the control relay R2610 and the lower winding of the answer relay R2620; and completes, at the contacts 2513, an obvious path for short-circuiting the winding of the seizure relay R2570. At this time, the 35 impulsion bridge between the line conductors of the trunk 113 extends, when completed, from the line conductor C114 by way of the contacts 2441, 2511, 2411 and 2442 to the line conductor C115. At the conclusion of the digit mentioned the 40 impulse relay R2410 reoperates, thereby to retain the hold relay R2430 in its operated position and to cause the bridge relay R2510 to restore shortly thereafter; the last-mentioned relay being of the slow-to-release type, as previously noted. Upon 45 restoring, the bridge relay R2510 interrupts, at the contacts 2511, the previously traced impulsion bridge between the line conductors of the trunk 113; interrupts, at the contacts 2512, the previously traced direct path for short-circuiting the 50 winding 2474 of the repeater 2470; interrupts, at the contacts 2513, the previously traced direct path for short-circuiting the winding of the seizure relay R2570; interrupts, at the contacts 2514, the previously mentioned circuit for energizing 55 the winding of the control relay R2650; and interrupts, at the contacts 2515, the previously mentioned circuit for energizing the winding of the shunt relay R2550. Shortly thereafter the control relay R2650 and the shunt relay R2550 60 restore, these relays being of the slow-to-release type. Upon restoring, the shunt relay R2550 interrupts, at the contacts 2554, the previously mentioned circuit for energizing the winding of the shunt relay R2540; thereby to cause the latter 65 relay to restore shortly thereafter, the shunt relay R2540 being of the slow-to-release type. When the bridge relay R2510 restores to interrupt, at the contacts 2512, the previously mentioned direct path for short-circuiting the winding 70 2474 of the repeater 2470, multiple paths. 75

respectively including the contacts 2541 and 2551 and the resistors 2581 and 2582, are completed for short-circuiting the last-mentioned winding. When the bridge relay R2510 restores to interrupt, at the contacts 2513, the previously traced direct path for short-circuiting the winding of the seizure relay R2570, there are completed obvious multiple paths, respectively including the contacts 2542 and 2552 and the resistors 2583 and 2584, for short-circuiting the winding of the last-mentioned relay. Shortly thereafter the shunt relay R2550 restores to interrupt, at the contacts 2551, one of the previously mentioned paths for short-circuiting the winding 2474 of the repeater 2470; and to interrupt, at the contacts 2552, one of the previously mentioned paths for short-circuiting the winding of the seizure relay R2570. Further, shortly thereafter the shunt relay R2540 restores to interrupt, at the contacts 2541, the second mentioned path for short-circuiting the winding 2474 of the repeater 2470; and to interrupt, at the contacts 2542, the second mentioned path for short-circuiting the winding of the seizure relay R2570. The arrangement described above for successively short-circuiting the winding 2474 of the repeater 2470 through successively higher resistance paths positively prevents any inductive voltage kick in the winding 2474 of the repeater 2470 from disturbing the first link 92 operatively connected to the trunk 113. Also the arrangement for successively short-circuiting the winding of the seizure relay R2570 through higher resistances positively prevents operation of the last-mentioned relay at this time. Upon restoring, the control relay R2650 prepares, at the contacts 2651, a circuit traced hereinafter for energizing the winding of the supervisory relay R2660. At this time, at the conclusion of the first digit transmitted by way of the automatic repeater 62, the line conductors of the trunk 113 are again operatively connected by way of the previously traced circuit to the windings 2473 and 2474 of the repeater 2470, to the winding of the control relay R2610 and to the lower winding of the answer relay R2620.

The subscriber at the calling subscriber substation in the automatic exchange 34 then dials the next digit over the trunk 165; whereby the automatic repeater 62 operates to repeat the digit mentioned over the trunk 113 to the connector 94 of the first link 92, in the manner previously explained. The connector 94 of the first link 92 then operates to seize the subscriber line extending to the called subscriber substation in the automatic exchange 35, such, for example, as the subscriber line 163 extending to the called subscriber substation T. The connector 94 then operates to test the idle or busy condition of the subscriber line 163 under the control of the individually associated line circuit 82; whereby busy tone current is returned therefrom over the trunk 113 in the event the called subscriber substation T is busy or ringing current is projected over the subscriber line 163 to the called subscriber substation T in the event the subscriber substation T is idle, all in accordance with conventional practice.

Assuming that the called subscriber substation T is idle when the subscriber thereat answers the call, the connector 94 of the first link 92 operates in order to cause battery potential to be reversed over the associated finder 83 and the trunk 113; whereby the lower winding of the answer relay R2620 in the automatic repeater 62 is energized

in the opposite direction over the previously traced circuit. Accordingly the answer relay R2620 operates at this time; thereby to complete, at the contacts 2621, an obvious circuit for energizing the winding of the supervisory relay R2770, whereupon the latter relay operates. Upon operating, the supervisory relay R2770 completes, at the contacts 2773, an obvious circuit for energizing the winding of the control relay R2650, thereby to cause the latter relay to operate. Also the supervisory relay R2770 completes, at the contacts 2774, a holding circuit, including the contacts 2633, for energizing the upper winding of the impulse relay R2410. Further, the supervisory relay R2770 interrupts, at the contacts 2771, the previously traced circuit, including the dial conductor C2414, for energizing the lower winding of the impulse relay R2410; and completes, at the contacts 2772, a path for applying battery potential by way of the upper winding of the answer relay R2630 and the contacts 2448 to the dial conductor C2414. The removal of ground potential by way of the lower winding of the impulse relay R2410 from the dial conductor C2414 and the application of battery potential by way of the upper winding of the answer relay R2630 to the dial conductor C2414 constitutes an answer supervisory control which serves no useful purpose in the present embodiment of the system, but which would be utilized for supervisory control purposes in the event the calling connection included a manual operator position, in an obvious manner.

Further, it is pointed out that the automatic repeater 62 embodies another feature which may be utilized in the present embodiment of the system pertaining to paystation tone supervision. For example, in the event the present call had originated at a paystation in the automatic exchange 34 and had been extended by the connector 94 of the first link 92 via an automatic-to-manual repeater to a manual operator position, the automatic-to-manual repeater would not have operated to reverse battery potential over the connector 94 and the finder 83 of the first link 92 and the trunk 113. Hence, the answer relay R2620 in the automatic repeater 62 would not have operated. In this event, when the operator at the manual position answered the call the automatic-to-manual repeater would have opened the loop momentarily, including the trunk 113, causing the control relay R2610 to restore. In this event, upon restoring, the control relay R2610 would have completed, at the contacts 2611, an obvious circuit, including the contacts 2422 and 2651, for energizing the winding of the supervisory relay R2660 in order to cause the latter relay to operate. Upon operating, the supervisory relay R2660 would have completed, at the contacts 2663, an obvious alternative circuit for energizing the upper winding of the impulse relay R2410; interrupted, at the contacts 2662, the previously traced path for applying ground potential by way of the lower winding of the impulse relay R2410 to the dial conductor C2414; and completed, at the contacts 2661, a path, including the resistor 2681, the contacts 2641, 2782, 2771 and 2448, for applying battery potential to the dial conductor C2414, thereby giving the operator at the manual position a supervisory signal indicating that the call was originated at a paystation in the automatic exchange 34.

Again assuming that the above-mentioned connection is completed between the calling subscriber substation in the automatic exchange 34

and the called subscriber substation T in the automatic exchange 35, the calling subscriber substation in the automatic exchange 34 is operationally connected by way of the automatic switching apparatus therein, the trunk 165 and the condensers 2475 and 2476 to the windings 2471 and 2472 of the repeater 2470; and the called subscriber substation T in the automatic exchange 35 is connected by way of the subscriber line 163, the line circuit 82, the first link 92 and the trunk 113 to the windings 2473 and 2474 of the repeater 2470. Now assuming that the above-mentioned connection is first released at the called subscriber substation T in the automatic exchange 35, the connector 94 of the first link 82 operates to cause battery potential to be reversed over the trunk 113; whereby the answer relay R2620 in the automatic repeater 62 restores, the answer relay R2620 being of the polarized type, as previously noted. Upon restoring, the answer relay R2620 interrupts, at the contacts 2621, the previously mentioned circuit for energizing the winding of the supervisory relay R2770, thereby to cause the latter relay to restore. Upon restoring, the supervisory relay R2770 interrupts, at the contacts 2773, the previously mentioned circuit for energizing the winding of the control relay R2650; whereupon the latter relay restores shortly thereafter, the control relay R2650 being of the slow-to-release type. Also, the supervisory relay R2770 interrupts, at the contacts 2774, the previously traced holding circuit for energizing the upper winding of the impulse relay R2410. Further, the supervisory relay R2770 interrupts, at the contacts 2772, the previously traced path for applying battery potential by way of the upper winding of the answer relay R2630 to the dial conductor C2414; and completes, at the contacts 2771, the previously traced path for applying ground potential by way of the lower winding of the impulse relay R2410 to the dial conductor C2414; whereby the lower winding of the impulse relay R2410 is short-circuited, causing the latter relay to restore. Upon restoring, the impulse relay R2410 interrupts, at the contacts 2411, the previously traced loop circuit extending by way of the trunk 113 to the first link 92; whereby this link is released, effecting the restoration of the control relay R2610. Also, upon restoring, the impulse relay R2410 interrupts, at the contacts 2413, the previously traced circuit for energizing the winding of the hold relay R2430; thereby to cause the latter relay to restore shortly thereafter, the hold relay R2430 being of the slow-to-release type. Upon restoring, the hold relay R2430 interrupts, at the contacts 2434, the previously mentioned circuit for energizing the winding of the hold slave relay R2420, thereby to cause the latter relay to restore. Also, upon restoring, the hold relay R2430 interrupts, at the contacts 2432, the previously mentioned path for applying ground potential to the control conductor C169 of the trunk 166, whereby the automatic repeater 62 is marked as idle to the trunk group allotter 74. At this time the automatic repeater 62 is completely released and available for further use.

Further, the application of ground potential by way of the lower winding of the impulse relay R2410 to the dial conductor C2414, incident to the restoration of the supervisory relay R2770, not only effects the short-circuiting and the consequent restoration of the impulse relay R2410 but also the release of the automatic switching apparatus in the automatic exchange 34.

Again assuming that the above-mentioned connection is completed between the calling subscriber substation in the automatic exchange 34 and the called subscriber substation T in the automatic exchange 35, and that this connection is first released at the calling subscriber substation in the automatic exchange 34, in this event the automatic switching apparatus in the automatic exchange 34 is released, causing ground potential to be applied to the dial conductor C2414; whereby a circuit substantially identical to that previously traced is completed for energizing the upper winding of the answer relay R2630. When thus energized the answer relay R2630 operates to interrupt, at the contacts 2633, the previously traced holding circuit for energizing the upper winding of the impulse relay R2410; and to complete, at the contacts 2632, a circuit, including the contacts 2432 and 2783, for energizing the winding of the control relay R2640, thereby to cause the latter relay to operate. Upon operating, the control relay R2640 interrupts, at the contacts 2641, a further point in the previously traced path for applying ground potential by way of the lower winding of the impulse relay R2410 to the dial conductor C2414; and completes, at the contacts 2643, an obvious multiple holding circuit for energizing the winding thereof. The impulse relay R2410 then restores in order to effect the restoration of the hold relay R2430 shortly thereafter and the consequent restoration of the hold slave relay R2420, in the manner previously explained. Also, the impulse relay R2410 interrupts, at the contacts 2411, the previously traced loop circuit extending by way of the trunk 113 to the first link 92, whereby the first link 92 is released. Incident to the restoration of the impulse relay R2410 the bridge relay R2510, the control relay R2650 and the shunt relays R2550 and R2540 operate in the manner previously explained.

When the above-traced loop circuit, including the trunk 113, is interrupted the control relay R2610 and the answer relay R2620 restore, in the manner previously explained. Upon restoring, the answer relay R2620 interrupts, at the contacts 2621, the previously traced circuit for energizing the winding of the supervisory relay R2770, thereby to cause the latter relay to restore. Upon restoring, the hold relay R2430 interrupts, at the contact 2432, the previously mentioned path for applying ground potential to the control conductor C169 of the trunk 166, thereby to cause the trunk group allotter 74 to mark the trunk 166 as idle. Also when ground potential is removed from the control conductor C169 of the trunk 166 the previously traced holding circuit for energizing the winding of the control relay R2640 is interrupted, thereby to cause the latter relay to restore. Upon restoring, the hold slave relay R2420 effects the restoration of the bridge relay R2510 shortly thereafter; whereupon the control relay R2650 and the shunt relays R2550 and R2540 restore shortly thereafter, all in the manner previously explained. Upon restoring, the supervisory relay R2770 interrupts, at the contacts 2772, the previously traced circuit for energizing the upper winding of the answer relay R2630, thereby to cause the latter relay to restore; and completes, at the contacts 2771, the previously traced path for connecting ground potential by way of the lower winding of the impulse relay R2410 to the dial conductor C2414. At this time the automatic repeater 62 is completely released.

In the event the above-mentioned connection extending from the calling subscriber substation in the automatic exchange 34 by way of the automatic repeater 62 and the first link 92 had included an automatic-to-manual operator position, in the manner previously explained, the release of the automatic repeater 62 under the control of the calling subscriber substation in the automatic exchange 34 would have taken place, as described above. However, in this event, upon restoring, the control relay R2680 would have completed, at the contacts 2653, a circuit, including the contacts 2435, 2644 and 2745 and the control conductor C116 of the trunk 113, for energizing the winding of the busy relay R2760, thereby to cause the latter relay to operate. This operating circuit for energizing the winding of the busy relay R2760 is completed in the event mentioned, due to the fact that the automatic-to-manual repeater retains the first link 92 in its operated position and ground potential upon the control conductor C116 until the operator at the manual position releases the connection. Upon operating, the busy relay R2760 interrupts, at the contacts 2762, the previously traced path for applying ground potential by way of the lower winding of the impulse relay R2410 to the dial conductor C2414; and completes, at the contacts 2761, an alternative path for applying battery potential by way of the upper winding of the answer relay R2630 to the dial conductor C2414. This application of battery potential to the dial conductor C2414 marks the trunk 165 as busy to the automatic switching apparatus in the automatic exchange 34. Subsequently, when the operator at the manual position releases the automatic-to-manual repeater mentioned, the first link 92 is released and ground potential is removed from the control conductor C116 of the trunk 113, thereby to effect the restoration of the busy relay R2760. Upon restoring, the busy relay R2760 interrupts, at the contacts 2761, the above-traced alternative path for applying battery potential by way of the upper winding of the answer relay R2630 to the dial conductor C2414; and completes, at the contacts 2762, the previously traced path for applying ground potential by way of the lower winding of the impulse relay R2410 to the dial conductor C2414, whereby the trunk 165 is marked as idle to the automatic switching apparatus in the automatic exchange 34 having access thereto. At this time the automatic repeater 62 is completely released.

Call to the automatic exchange 34

Considering now the extension of a call to the automatic exchange 34, the calling automatic switch is first operated to select an idle trunk of the three constituting the ninth group under the control of the trunk group allotter 14, in the manner previously explained, such, for example, as the first trunk 166, extending to the automatic repeater 62. When the calling automatic switch seizes the trunk 166 ground potential is applied to the control conductor C169 thereof; whereby the trunk group allotter 14 operates in order to mark the trunk 166 as busy to the other switches having access thereto. Also the application of ground potential to the control conductor C169 of the trunk 166 completes an obvious circuit, including the contacts 2433, for energizing the winding of the cutoff relay R2440 and an obvious multiple circuit for energizing the upper winding of the answer relay R2620. When thus energized the cutoff relay R2440 operates to complete, at

the contacts 2449, an obvious holding circuit for energizing the winding thereof. However, when the upper winding of the answer relay R2620 is thus energized the latter relay does not operate as it is of the polarized type, as previously noted. Also the cutoff relay R2440 interrupts, at the contacts 2441 and 2442, the previously traced connection between the line conductors of the trunk 113 and the repeater 2470; and completes, at the contacts 2444 and 2446, the loop circuit traced hereinafter for energizing the winding of the impulse relay R2520 in series with the winding of the seizure relay R2510. The above-mentioned loop circuit extends from ground by way of the winding of R2510, the contacts 2454 and 2446 and the winding 2474 of the repeater 2470 to the line conductor C167 of the trunk 166, and from battery by way of the winding of R2520, the contacts 2452 and 2444 and the winding 2473 of the repeater 2470 to the line conductor C168 of the trunk 166; the line conductors of the trunk 166 being connected together in the calling switch. When thus energized the impulse relay R2520 and the seizure relay R2510 operate. Upon operating, the impulse relay R2520 completes, at the contacts 2521, an obvious circuit, including the contacts 2743, for energizing the winding of the pulse relay R2720, thereby to cause the latter relay to operate. Upon operating, the pulse relay R2720 completes, at the contacts 2725, an obvious multiple holding circuit, including the resistor 2784, for energizing the winding thereof; and completes, at the contacts 2721, an obvious circuit for energizing the winding of the hold relay R2730, whereupon the latter relay operates. Upon operating, the hold relay R2730 completes, at the contacts 2731, a path for applying battery potential by way of the lower winding of the answer relay R2630 to the dial conductor C2414, the last-mentioned path including the contacts 2731, 2672 and 2441. This application of battery potential to the dial conductor C2414 causes the automatic switching apparatus in the automatic exchange 34 to seize the trunk 165 in a well-known manner. Also the hold relay R2730 completes, at the contacts 2732, an obvious circuit for energizing the winding of the control relay R2740, thereby to cause the latter relay to operate. Furthermore, when battery potential is applied by way of the lower winding of the answer relay R2630 to the dial conductor C2414 the lower winding of the latter relay is energized. When the answer relay R2630 is thus energized it operates to complete, at the contacts 2632, the previously traced circuit for energizing the winding of the control relay R2640, thereby to cause the latter relay to operate.

A digit is then dialed over the calling switch seizing the trunk 166, whereby the impulses of the digit mentioned are transmitted over the previously traced loop circuit, causing the impulse relay R2520 to follow the impulses of the digit mentioned. Upon the first restoration of the impulse relay R2520 it interrupts, at the contacts 2521, the previously mentioned holding circuit for energizing the winding of the pulse relay R2720, thereby to cause the latter relay to restore. Upon restoring, the pulse relay R2720 interrupts, at the contacts 2721, the previously mentioned circuit for energizing the winding of the hold relay R2730; and completes, at the contacts 2724, a circuit, including the contacts 2742 and 2713, for energizing the winding of the repeat relay R2670, thereby to cause the latter relay to operate. Upon operating, the repeat relay R2670 completes, at the contacts 2671, an obvious alternative circuit for energizing the winding of the hold relay R2730,

thereby to retain the last-mentioned relay in its operated position. The hold relay R2730, being of the slow-to-release type, does not restore during impulsing. Also, upon restoring, the pulse relay R2720 completes, at the contacts 2723, a circuit, including the contacts 2741 and 2455, for energizing the winding of the bridge relay R2510, thereby to cause the latter relay to operate. Upon operating, the bridge relay R2510 completes, at the contacts 2514, the previously traced circuit for energizing the winding of the control relay R2650; and completes, at the contacts 2515, the previously mentioned circuit for energizing the winding of the shunt relay R2550, whereby the relays mentioned operate. Upon operating, the shunt relay R2550 effects operation of the shunt relay R2540, in the manner previously explained. Also the bridge relay R2510 completes, at the contacts 2513, the previously mentioned path for short-circuiting the winding of the seizure relay R2570, thereby to cause the latter relay to remain in its restored position during impulsing. Further the bridge relay R2510 completes, at the contacts 2512, the previously traced path for short-circuiting the winding 2474 of the repeater 2470, whereby an impulsing bridge is completed for energizing the winding of the impulse relay R2520. The above-mentioned impulsing bridge extends from ground by way of the contacts 2513, 2454, 2446 and 2512 to the line conductor C167 of the trunk 166, and from battery by way of the winding of the impulse relay R2520, the contacts 2452 and 2444 and the winding 2473 of the repeater 2470 to the line conductor C168 of the trunk 166.

Also, upon operating, the repeat relay R2670 completes, at the contacts 2674, an obvious path for short-circuiting the lower winding thereof, thereby to render the last-mentioned relay slow to release when the above-traced circuit for energizing the upper winding thereof is subsequently interrupted. Further the repeat relay R2670 completes, at the contacts 2673, a circuit, including the contacts 2742 and 2722, for energizing the upper winding of the pulse relay R2710; thereby to cause the latter relay to operate shortly thereafter. The pulse relay R2710 is rendered slow to release due to the obvious normally completed path for short-circuiting the lower winding thereof. Upon operating, the pulse relay R2710 interrupts, at the contacts 2711, the previously mentioned path for short-circuiting the lower winding thereof; completes, at the contacts 2712, a holding circuit substantially identical to that previously traced for energizing the winding thereof; and interrupts, at the contacts 2713, the previously traced circuit for energizing the winding of the repeat relay R2670; thereby to cause the latter relay to restore shortly thereafter, the repeat relay R2670 being rendered slow to release due to the previously mentioned completed path for short-circuiting the lower winding thereof. Also the pulse relay R2710 completes, at the contacts 2714, a priming circuit, including the contacts 2722 and 2733 and the resistor 2783, for energizing the winding of the impulse relay R2520; thereby to render the last-mentioned relay fast to operate when the previously traced impulsing circuit, including the line conductors of the trunk 166, is subsequently completed. Upon restoring, the repeat relay R2670 interrupts, at the contacts 2674, the previously mentioned path for short-circuiting the lower winding thereof. Accordingly the repeat relay R2670 operates and restores, interrupting and then recompleteing, at the contacts 2672, the

previously traced path for applying battery potential by way of the lower winding of the answer relay R2630 to the dial conductor C2414; thereby effectively causing the first impulse of 5 the digit mentioned to be transmitted to the automatic switching apparatus in the automatic exchange 34.

Subsequently, at the conclusion of the first impulse of the digit mentioned, the previously 10 traced impulsing circuit, including the line conductors of the trunk 166, is completed for energizing the winding of the impulse relay R2520, whereby the latter relay operates exceedingly fast to interrupt, at the contacts 2522, the previously 15 traced priming circuit for energizing the winding thereof; and to complete, at the contacts 2521, the previously mentioned circuit for energizing the winding of the pulse relay R2720, thereby to cause the latter relay to reoperate. 20 Upon reoperating, the pulse relay R2720 completes, at the contacts 2721, the previously mentioned circuit for energizing the winding of the hold relay R2730, thereby to retain the latter relay in its operated position. Also the pulse relay R2720 completes, at the contacts 2725, the previously 25 traced holding circuit for energizing the winding thereof; and interrupts, at the contacts 2722, the previously traced circuit for energizing the upper winding of the pulse relay R2710, thereby to cause the latter relay to restore. 30 Also the pulse relay R2720 interrupts, at the contacts 2723, the previously traced circuit for energizing the winding of the bridge relay R2510; however, the latter relay does not immediately 35 restore as it is of the slow-to-release type.

Upon the next restoration of the impulsing relay R2520 incident to the transmission of the second impulse of the digit mentioned over the 40 trunk 166, the pulse relays R2720 and R2710 and the repeat relay R2670 operate, in the manner explained above; whereby the repeat relay R2670 repeats the second impulse of the digit over the dial conductor C2414, in the manner noted. Accordingly the impulse relay R2520 follows the digit, causing the repeat relay R2670 to repeat the impulses thereof over the dial conductor C2414 to the automatic switching apparatus in the automatic exchange 34, in the manner explained 50 above.

At the conclusion of the first digit the impulse relay R2520 remains in its operated position and, shortly thereafter, the bridge relay R2510 restores to interrupt, at the contacts 2511, the previously 55 traced path for short-circuiting the winding 2474 of the repeater 2470; and to interrupt, at the contacts 2515, the previously mentioned circuit for energizing the winding of the shunt relay R2550. The shunt relay R2550 restores shortly thereafter and effects the restoration of the shunt relay R2540 subsequently. Also, upon restoring, the bridge relay R2510 interrupts, at the contacts 2514, the previously mentioned circuit for energizing the winding of the control relay R2650; thereby to cause the latter relay to restore shortly thereafter, the control relay R2650 being of the slow-to-release type. Upon 60 restoring, the shunt relays R2550 and R2540 successively interrupt, at the contacts 2551 and 2541, obvious resistance paths, respectively including the resistors 2582 and 2581, for short-circuiting the winding 2474 of the repeater 2470; and successively interrupt, at the contacts 2552 and 2542, obvious paths, respectively including the resistors 2584 and 2583, for short-circuiting the 65 70 75

winding of the seizure relay R2570. This arrangement positively prevents any inductive kick voltage induced in the winding 2474 of the repeater 2470 from effecting momentary restoration of the impulse relay R2520. At this time the previously traced original loop circuit for energizing the winding of the seizure relay R2570 in series with the winding of the impulse relay R2520 is recompleted, whereupon the seizure relay R2570 reoperates.

One or more digits are dialed over the trunk 166 to the automatic repeater 62 and are repeated therefrom over the dial conductor C2414 and the trunk 165 to the automatic switching apparatus in the automatic exchange 34; whereby the last-mentioned automatic switching apparatus operates to seize the line extending to the called subscriber substation in the automatic exchange 34. The automatic switching apparatus then tests the idle or busy condition of the called subscriber substation, whereby ringing current is projected over the subscriber line to the called subscriber substation or busy tone current is returned over the trunk 165, respectively, in the event the called subscriber substation is idle or busy in accordance with conventional practice. Assuming that the called subscriber substation in the automatic exchange 34 is idle, when the call is answered thereat the automatic switching apparatus in the automatic exchange 34 operates in order to cause battery potential instead of ground potential to be returned over the dial conductor C2414; thereby to complete an obvious path for short-circuiting the lower winding of the answer relay R2630. The answer relay R2630 then restores, thereby to complete, at the contacts 2631, a circuit for energizing the winding of the control relay R2750; this circuit including the grounded control conductor C169 of the trunk 166, the contacts 2433, 2553, 2571, 2631 and 2642. When thus energized the control relay R2750 operates to complete, at the contacts 2751, an obvious circuit for energizing the winding of the control relay R2560 and an obvious multiple circuit, including the contacts 2561 and 2752, for energizing the winding of the control relay R2650. The control relay R2650 operates immediately while the control relay R2560 operates shortly thereafter, the control relay R2560 being of the slow-to-operate type. Upon operating, the control relay R2650 completes, at the contacts 2652, an obvious circuit, including the contacts 2751, for energizing the winding of the tone relay R2530, thereby to cause the latter relay to operate. Upon operating, the control relay R2560 interrupts, at the contacts 2561, the previously traced circuit for energizing the winding of the control relay R2650; thereby to cause the latter relay to restore shortly thereafter, the control relay R2650 being of the slow-to-release type. Upon restoring, the control relay R2650 interrupts, at the contacts 2652, the previously traced circuit for energizing the winding of the tone relay R2530; thereby to cause the latter relay to restore shortly thereafter, the tone relay R2530 being of the slow-to-release type. Upon restoring, the tone relay R2530 completes, at the contacts 2531, a circuit, including the grounded control conductor C169 of the trunk 166, the contacts 2433, 2553, 2571, 2631, 2642, 2753 and 2562, for energizing the winding of the reverse battery relay R2450, thereby to cause the latter relay to operate. Upon operating, the reverse battery relay R2450 interrupts, at the contacts 2452 and 2454, the previously traced application of battery

and ground potentials by way of the windings of the impulse relay R2520 and the seizure relay R2570 to the line conductors of the trunk 166; and completes, at the contacts 2451 and 2453, obvious alternative paths for applying ground and battery potentials by way of the windings of the seizure relay R2570 and the impulse relay R2520 to the line conductors of the trunk 166. Accordingly, battery potential is reversed over the trunk 166 to the calling switch for supervisory purposes. At this time an operative connection is completed from the calling switch by way of the trunk 166 and the previously traced loop circuit to the windings 2473 and 2474 of the repeater 2470; while the windings 2471 and 2472 of the repeater 2470 are operatively connected by way of the condensers 2475 and 2476, the trunk 166 and the automatic switching apparatus in the automatic exchange 34 to the called subscriber substation.

Now assuming that the above-mentioned connection is completed and that the calling automatic switch is first released, the previously traced loop circuit for energizing in series the windings of the impulse relay R2520 and the seizure relay R2570 are interrupted, thereby to cause these relays to restore. Upon restoring, the impulse relay R2520 interrupts, at the contacts 2521, the previously mentioned holding circuit for energizing the winding of the pulse relay R2720; thereby to cause the latter relay to restore and effect the restoration of the hold relay R2730 shortly thereafter, the hold relay R2730 being of the slow-to-release type. Upon restoring, the hold relay R2730 interrupts, at the contacts 2732, the previously mentioned circuit for energizing the winding of the control relay R2740, thereby to cause the latter relay to restore. Upon restoring, the control relay R2740 interrupts, at the contacts 2744, a previously completed path, including the contacts 2535 and 2433, for applying ground potential to the control conductor C169 of the trunk 166; whereby the calling switch is released. When ground potential is removed from the control conductor C169 of the trunk 166 the cutoff relay R2440, the control relay R2640 and the control relay R2750 restore, in an obvious manner. Upon restoring, the control relay R2640 completes, at the contacts 2641, the previously traced path for applying ground potential by way of the lower winding of the impulse relay R2410 to the dial conductor C2414; the previously traced path for applying battery potential by way of the lower winding of the answer relay R2630 to the dial conductor C2414 being interrupted, at the contacts 2731, incident to the restoration of the hold relay R2730. This application of ground potential to the dial conductor C2414 effects the restoration of the automatic switching apparatus in the automatic exchange 34 and operation of the impulse relay R2410. Upon operating, the impulse relay R2410 completes, at the contacts 2413, the previously traced circuit for energizing the winding of the hold relay R2430, thereby to cause the latter relay to operate. Upon operating, the hold relay R2430 effects operation of the hold slave relay R2420; and completes, at the contacts 2432, the previously mentioned path for applying ground potential to the control conductor C169 of the trunk 166; whereby the trunk group allotter 74 is operated in order to mark the trunk 166 as busy at this time. Further the impulse relay R2410 completes, at the contacts 2411, the previously traced loop circuit for energizing the winding of the

control relay R2610 and the lower winding of the answer relay R2620 in series by way of the line conductors of the trunk 113, whereupon the control relay R2610 operates; however, the answer relay R2620 does not operate due to the fact that it is of the polarized type, as previously noted.

When the automatic switching apparatus in the automatic exchange 34 is completely released battery potential is removed from the dial conductor C2414 and ground potential is applied thereto, whereby the lower winding of the impulse relay R2410 is short-circuited in order to cause the latter relay to restore. Upon restoring, the impulse relay R2410 effects the restoration of the hold relay R2430 and the consequent restoration of the hold slave relay R2420; and interrupts, at the contacts 2411, the previously traced loop circuit between the line conductors of the trunk 113; whereby the control relay R2610 restores, all in the manner previously explained. Upon restoring, the hold relay R2430 interrupts, at the contacts 2432, the application of ground potential to the control conductor C169 of the trunk 166; whereby the trunk group allotter 74 operates in order to mark the trunk 166 as idle to the switches having access thereto.

Again assuming that the above-mentioned connection is completed by way of the automatic repeater 62 and that the release thereof is initiated at the called subscriber substation in the automatic exchange 34, the automatic switching apparatus in the automatic exchange 34 operates in order to cause ground potential to be applied to the dial conductor C2414, thereby to complete the previously traced circuit for energizing the lower winding of the answer relay R2630; whereupon the latter relay operates to interrupt, at the contacts 2631, the previously traced circuit for energizing the winding of the control relay R2750. The control relay R2750 then restores and interrupts, at the contacts 2751, the previously traced circuit for energizing the winding of the control relay R2660; and interrupts, at the contacts 2663, the previously traced circuit for energizing the winding of the reverse battery relay R2450, whereupon the relays mentioned restore. Upon restoring, the reverse battery relay R2450 reverses the application of ground and battery potentials by way of the windings of the seizure relay R2570 and the impulse relay R2520 to the line conductors of the trunk 166 for supervisory purposes. When the calling switch is then released the previously traced loop circuit for energizing in series the windings of the seizure relay R2570 and the impulse relay R2520 are interrupted, thereby to cause the latter relays to restore. Upon restoring, the impulse relay R2520 effects the restoration of the pulse relay R2720, which latter relay effects the restoration of the hold relay R2730 and the operation of the bridge relay R2510, all in the manner previously explained. Upon operating, the bridge relay R2510 effects the operation of the control relay R2650 and the shunt relays R2550 and R2540, in the manner previously explained. Upon restoring, the hold relay R2730 effects the restoration of the control relay R2740, whereby ground potential is removed from the control conductor C169 in order to effect the final release of the calling switch and the restoration of the control relay R2640 and the cutoff relay R2440. Also the control relay R2740 effects the restoration of the bridge relay R2510 and the consequent restora-

tion of the control relay R2650 and the shunt relays R2550 and R2540, all in the manner previously explained. Upon restoring, the hold relay R2730 interrupts, at the contacts 2731, the previously traced path for applying battery potential by way of the lower winding of the answer relay R2630 to the dial conductor C2414; and, upon restoring, the cutoff relay R2440 recompletes, at the contacts 2448, the previously traced path for applying ground potential by way of the lower winding of the impulse relay R2410 to the dial conductor C2414, thereby to effect the ultimate release of the automatic switching apparatus in the automatic exchange 34. At this time the automatic repeater 62 is completely released.

Further it is noted that the automatic repeater 62 embodies a feature which may be utilized in the illustrated embodiment of the system pertaining to the supervisory arrangement incorporated therein, whereby a call might be extended from a calling switch by way of the trunk 166, the automatic repeater 62 and the trunk 165, and further by way of the automatic repeater, the automatic switching apparatus and an automatic-to-manual repeater to a manual position in the automatic exchange 34. In the event a call were extended by way of the connection mentioned, when the operator at the manual position answered, the associated automatic-to-manual repeater would operate in order momentarily to interrupt the application of ground potential to the dial conductor C2414; whereby the answer relay R2630 in the automatic repeater 62 would restore and then reoperate momentarily. In this event, upon restoring, the answer relay R2630 effects operation of the control relay R2750, whereby the latter relay effects operation of the control relay R2660 and the control relay R2650, in the manner previously explained. Upon operating, the control relay R2660 effects restoration of the control relay R2650 shortly thereafter, in the manner previously explained. While the control relay R2650 occupies its operated position and a short time interval thereafter the tone relay R2530 occupies its operated position, as previously pointed out. While the tone relay R2530 occupies its operated position it completes, at the contacts 2532, an obvious path, including the condenser 2481, for energizing the left-hand winding of the transformer 2460 across the line conductors C167 and C168 of the trunk 166; and interrupts, at the contacts 2535, an obvious normally completed path for short-circuiting the right-hand winding of the transformer 2460. At this time, in the event a paystation is connected to the calling switch, the paystation tone current applied to the control conductor C168 completes a circuit, including the contacts 2433 and 2744, for energizing the right-hand winding of the transformer 2460; whereby paystation tone voltage is induced in the left-hand winding of the transformer 2460. The paystation tone voltage induced in the left-hand winding of the transformer 2460 causes paystation tone current to traverse an obvious circuit, including the windings 2473 and 2474 of the repeater 2470, whereby paystation tone current is projected over the trunk 165 to the answering manual position in order to indicate to the operator thereat that the call was originated at a paystation.

Shortly thereafter the tone relay R2530 restores, thereby to recomplete, at the contacts 2535, the previously mentioned path for short-circuiting the right-hand winding of the transformer 2460 in order effectively to interrupt the

projection of paystation tone current to the manual position mentioned. Also the tone relay R2530 interrupts, at the contacts 2532, the previously traced connection between the left-hand winding of the transformer 2460 and the line conductors of the trunk 166. The answer relay R2630 immediately reoperates in order to effect the restoration of the control relay R2750 and the consequent restoration of the control relay R2560, all in the manner previously explained. Further it is noted that the control relay R2750 restores prior to the restoration of the tone relay R2530, thereby positively to prevent operation of the reverse battery relay R2550. The subsequent release of the established connection and the automatic repeater 62 is the same as that previously explained.

Operation of the local switch train in the automatic exchange 35

In view of the foregoing explanation of the mode of operation of the by-pass selector 50, it will be understood that a call initiated at the manual position in the manual exchange 30 may be extended by way of the by-pass selector 50 and the trunk 134 individual thereto to the line circuit 80. Similarly, a call initiated at the manual position in the manual exchange 31 may be extended by way of the by-pass selector 51 and the trunk individual thereto to the line circuit, not shown; a call initiated at the manual position in the manual exchange 32 may be extended by way of the by-pass selector 52 and the trunk individual thereto to the line circuit, not shown; a call initiated at the manual position in the manual exchange 33 may be extended by way of the incoming selector 53 and the trunk 156 individual thereto to the line circuit, not shown; and a dial-back call extended back from the manual position in the manual exchange 33 may be extended by way of the incoming selector 54 and the trunk individual thereto to the line circuit, not shown. Furthermore, a call initiated in the automatic exchange 34 may be extended by way of the repeater 62 to the line circuit 81; and a call initiated at the subscriber substation T in the automatic exchange 35 may be extended to the line circuit 82, all in an obvious manner. When a call is extended to any one of the line circuits, 80, 81, 82 etc., the call allotter 90 is controlled in order to effect the control of the link allotter 91; whereby an idle link, such, for example, as the first link 92, which has been preselected, is marked in order to cause the finder 93 thereof to seize the trunk extending to the associated line circuit mentioned. The connector 94 of the first link 92 may then be controlled in order to extend the connection. In the event the call mentioned was originated in the manual exchange 30, the manual exchange 31, the manual exchange 32 or the manual exchange 33, the connector 94 of the first link 92 will be operated to extend the call to a subscriber substation in the automatic exchange 35 in view of the fact that interexchange calls between the exchanges mentioned do not include a local link in the automatic exchange 35, as previously explained.

As previously noted, the first link 92 comprises restricted service facilities which are so connected and arranged that, in the event the call was initiated in the automatic exchange 34, the connector 94 is blocked against access to other than a subscriber substation in the automatic exchange 35. Finally the first link 92 comprises restricted service facilities which are so con-

nected and arranged that, in the event the call was initiated at a subscriber substation in the automatic exchange 35, the connector 94 is blocked against access to the three trunks in the eighth group and does not have access to the three trunks in the sixth group. Accordingly it will be understood that, in the event a call initiated at a subscriber substation in the automatic exchange 35 is to be extended to the manual exchange 30 or to the manual exchange 32, it is necessary for the call first to be extended by way of one of the three trunks in the tenth group over one of the dial-back repeaters 61 etc. to the manual exchange 33; and when the operator at the manual position in the manual exchange 33 answers the call she will control, through the associated dial-back repeater, the individual incoming selector in order to extend the call either to the manual exchange 30 or to the manual exchange 32, in the manner previously explained.

Conclusions

From the foregoing it is apparent that a telephone system is provided which comprises a C. A. X including improved automatic switching apparatus of the all-relay type for setting up local calls, incoming and outgoing central exchange trunk calls and inter-central exchange trunk calls.

While one embodiment of the invention has been disclosed it will be understood that various modifications may be made therein, which are within the true spirit and scope of the invention.

What is claimed is:

1. In a telephone system comprising a plurality of remote exchanges, a local exchange, a plurality of trunk lines extending between said remote exchanges and said local exchange, a plurality of selectors in said local exchange individually terminating said trunk lines, a plurality of by-pass trunks individually extending to said selectors, and switching apparatus in said local exchange; each of said selectors being of the all-relay type including a group of counting relays selectively operative in accordance with the number of impulses of a digit transmitted over the terminated trunk line, group and unit contact sets selectively operative to connect the terminated trunk line directly to different ones of said by-pass trunks and to said switching apparatus, means governed by said counting relays for operating said group and unit contact sets, and means for operatively connecting the by-pass trunk extending thereto to the terminated trunk.

2. In a telephone system comprising a plurality of remote exchanges, a local exchange, a plurality of trunk lines extending between said remote exchanges and said local exchange, a plurality of selectors in said local exchange individually terminating said trunk lines, a plurality of by-pass trunks individually extending to said selectors, and switching apparatus in said local exchange; each of said selectors being of the all-relay type including a group of counting relays selectively operative in accordance with the number of impulses of a digit transmitted over the terminated trunk line, group and unit contact sets selectively operative to connect the terminated trunk line directly to different ones of said by-pass trunks and to said switching apparatus, means governed by said counting relays for operating said group and unit contact sets, means for operatively connecting the by-

pass trunk extending thereto to the terminated trunk, and means responsive to the connections of another selector to the by-pass trunk extending thereto for transmitting a signal over the terminated trunk.

3. In a telephone system comprising a plurality of remote exchanges, a local exchange, a plurality of groups of trunk lines individually extending between said remote exchanges and said local exchange, a plurality of groups of selectors in said local exchange individually terminating the trunk lines in said groups, a plurality of groups of by-pass trunks individually extending to the selectors in said groups, and switching apparatus in said local exchange; each of said selectors being of the all-relay type including a group of counting relays selectively operative in accordance with the number of impulses of a digit transmitted over the terminated trunk line, group and unit contact sets selectively operative to connect the terminated trunk line directly to corresponding ones of the by-pass trunks in corresponding ones of said groups and to said switching apparatus, means governed by said counting relays for operating the one of said group contact sets corresponding to any one of said groups of by-pass trunks and for effecting operation of one of said unit contact sets corresponding to an idle one of the by-pass trunks in said one group, and means for operatively connecting the by-pass trunk extending thereto to the terminated trunk.

4. In a telephone system comprising a plurality of remote exchanges, a local exchange, a plurality of trunk lines extending between said remote exchanges and said local exchange, an operator position in each of said remote exchanges having access to the trunk line extending thereto, a plurality of selectors in said local exchange individually terminating said trunk lines, a plurality of by-pass trunks individually extending to said selectors, and switching apparatus in said local exchange; each of said selectors being of the all-relay type including means responsive to the seizure of the terminated trunk line at the operator position in the associated remote exchange for returning a ready signal over the terminated trunk line, a group of counting relays selectively operative in accordance with the number of impulses of a digit transmitted from the operator position in the associated remote exchange over the terminated trunk, group and unit contact sets selectively operative to connect the terminated trunk line directly to different ones of said by-pass trunks and to said switching apparatus, means governed by said counting relays for operating said group and unit contact sets, means responsive to the completion of the connection for arresting the return of said ready signal over the terminated trunk line and for returning an answer signal thereover, and means for operatively connecting the by-pass trunk extending thereto to the terminated trunk.

5. In a telephone system comprising a plurality of remote exchanges, a local exchange, a plurality of trunk lines extending between said remote exchanges and said local exchange, an operator position in each of said remote exchanges having access to the trunk line extending thereto, a plurality of selectors in said local exchange individually terminating said trunk lines, a plurality of by-pass trunks individually extending to said selectors, and switching apparatus in said local exchange; each of said selectors being of the all-relay type including a group

of counting relays selectively operative in accordance with the number of impulses of a digit transmitted from the operator position in the associated remote exchange over the terminated trunk after seizure thereof, group and unit contact sets selectively operative to connect the terminated trunk line directly to different ones of said by-pass trunks and to said switching apparatus, means governed by said counting relays for operating said group and unit contact sets, means for operatively connecting the by-pass trunk extending thereto to the terminated trunk, means responsive to the connection of another selector to the by-pass trunk extending thereto for transmitting a call signal over the terminated trunk and for returning a ring signal over the by-pass trunk, and means responsive to the completion of the connection to the operator position in the associated remote exchange for arresting the return of said ring signal over the by-pass trunk extending thereto and for returning an answer signal thereover.

6. In a telephone system comprising a plurality of remote exchanges, a plurality of trunks individually extending to said remote exchanges, a control exchange including an operator position, a control trunk extending to said control exchange, a dial back repeater associated with said control trunk, a selector associated with said repeater and having access to said trunks, means for extending a call from a first of said remote exchanges by way of the associated trunk and said repeater and said control trunk to said control exchange, and means controllable from said operator position for extending the call reverberatively over said control trunk and said repeater to said selector; said selector being of the all-relay type including a group of counting relays selectively operative in accordance with the number of impulses of a digit transmitted thereto from said repeater, group and unit contact sets selectively operative further to extend the call to any second of said remote exchanges by way of the associated trunk, and means governed by said counting relays for operating said group and unit contact sets.

7. In a telephone system comprising a local exchange, a remote exchange, a trunk extending to said remote exchange, a control exchange including an operator position, a control trunk extending to said control exchange, a dial back repeater associated with said control trunk, a selector associated with said repeater and having access to said trunk, means for extending a call from said local exchange by way of said repeater and said control trunk to said control exchange, and means controllable from said operator position for extending the call reverberatively over said control trunk and said repeater to said selector; said selector being of the all-relay type including a group of counting relays selectively operative in accordance with the number of impulses of a digit transmitted thereto from said repeater, group and unit contact sets operative further to extend the call by way of said trunk to said remote exchange, and means governed by said counting relays for operating said group and unit contact sets.

8. In a telephone system comprising a local exchange, a remote exchange, a trunk extending to said remote exchange, a control exchange including an operator position, a control trunk extending to said control exchange, a dial back repeater associated with said control trunk, a selector associated with said repeater, means for

extending a call from said remote exchange by way of said trunk and said repeater and said control trunk to said control exchange, and means controllable from said operator position or extending the call revertively over said control trunk and said repeater to said selector; said selector being of the all-relay type including a group of counting relays selectively operative in accordance with the number of impulses of a digit transmitted thereto from said repeater, group and unit contact sets operative further to extend the call in said local exchange, and means governed by said counting relays for operating said group and unit contact sets.

9. In a telephone system, an operator position, a plurality of control trunks extending to said operator position, a plurality of selectors normally individually connected to said control trunks, a plurality of dial back repeaters, a distributor operative to preselect idle ones of said control trunks in a predetermined order, means controllable from said operator position for routing a call therefrom over any one of said control trunks and the connected selector, means for extending a call to an idle one of said repeaters, means controlled when a call is extended to any one of said repeaters for connecting said repeater to the one of said control trunks reselected by said distributor and for disconnecting said one control trunk from the connected selector, thereby to route the call from said one repeater over said one control trunk to said operator position, means controlled when a call is routed over any one of said control trunks for marking said one control trunk as busy to said distributor, and means controllable from said operator position for extending a call thereto over any one of said control trunks revertively over said one control trunk and the connected repeater.

10. In a telephone system, an operator position, a plurality of control trunks extending to said operator position, a plurality of selectors normally individually connected to said control trunks, a plurality of dial back repeaters, each of said repeaters including an incoming trunk and an outgoing trunk, a distributor operative to preselect idle ones of said control trunks in a predetermined order, means controllable from said operator position for routing a call therefrom over any one of said control trunks and the connected selector, means for extending a call to an idle one of said repeaters over the associated incoming trunk, means controlled when a call is extended to any one of said repeaters for connecting said repeater to the one of said control trunks reselected by said distributor and for disconnecting said one control trunk from the connected selector, thereby to route the call from said one repeater over said one control trunk to said operator position, means controlled when a call is routed over any one of said control trunks for marking said one control trunk as busy to said distributor, and means controllable from said operator position for extending a call thereto over any one of said control trunks revertively over said one control trunk and the outgoing trunk of the connected repeater.

11. In a telephone system, an operator position, a plurality of control trunks extending to said operator position, a plurality of selectors normally individually connected to said control trunks, a plurality of dial back repeaters, each of said repeaters including an incoming trunk and an outgoing trunk, a distributor operative to

preselect idle ones of said control trunks in a predetermined order, means controllable from said operator position for routing a call therefrom over any one of said control trunks and the connected selector, means for extending a call to an idle one of said repeaters over the associated incoming trunk, means controlled when a call is extended to any one of said repeaters for connecting said one repeater to the one of said control trunks preselected by said distributor and for disconnecting said one control trunk from the connected selector, thereby to route the call from said one repeater over said one control trunk to said operator position, means controlled when a call is routed over any one of said control trunks for marking said one control trunk as busy to said distributor, means controllable from said operator position for extending a call thereto over any one of said control trunks revertively over said one control trunk and the outgoing trunk of the connected repeater, thereby to set up a connection in said last-mentioned repeater including the incoming and outgoing trunks thereof and said one control trunk, means controllable from said operator position for releasing said one control trunk, and means controlled when said one control trunk is released for reconnecting said one control trunk to the associated selector and for marking said one control trunk as idle to said distributor.

12. In a telephone system, a first exchange including a paystation and a first repeater and first automatic switching apparatus, a second exchange including a subscriber substation and an operator position and a second repeater and second automatic switching apparatus, a trunk extending between said repeaters, means for routing a call from said paystation over said first and second switching apparatus and said first and second repeaters and said trunk either to said substation or to said operator position, means governed in response to the answering of the call at said substation for controlling said second repeater, whereby said second repeater is operated to return a first control over said trunk, means governed in response to the answering of the call at said operator position for controlling said second repeater, whereby said second repeater is operated to return a second control over said trunk, and means included in said first repeater and responsive only to the return of said first control over said trunk for effecting the reversal of battery potentials over said first switching apparatus, said paystation including normally operative telephone equipment which is rendered ineffective in response to the reversal of battery potentials over said first switching apparatus unless a coin or the like is deposited therein.

13. In a telephone system, a first exchange including a first repeater and first automatic switching apparatus, a second exchange including a second repeater and second automatic switching apparatus, a trunk extending between said repeaters, means for routing a call initiated in said first exchange over said first and second switching apparatus and said first and second repeaters and said trunk to said second exchange, means governed in response to the answering of the call in said second exchange and in accordance with the destination thereof for selectively controlling said second repeater, whereby said second repeater is operated to return either first or second controls over said trunk, and means included in said first repeater and responsive only to the return of said first control over said trunk

for effecting the reversal of battery potentials over said first switching apparatus.

14. In a telephone system, a first exchange including a first repeater and first automatic switching apparatus, a second exchange including a second repeater and second automatic switching apparatus, a trunk extending between said repeaters, means for routing a call initiated in said first exchange over said first and second switching apparatus and said first and second repeaters and said trunk to said second exchange, means governed in response to the answering of the call in said second exchange and in accordance with the destination thereof for selectively controlling said second repeater, whereby said second repeater is operated either to reverse battery potentials or to transmit an impulse over said trunk, and means included in said first repeater and responsive only to the reversal of battery potentials over said trunk for effecting the reversal of battery potentials over said first switching apparatus.

15. In a telephone system, a first exchange including a first repeater and first automatic switching apparatus, a second exchange including a second repeater and second automatic switching apparatus, a trunk extending between said repeaters, means for routing a call initiated in said first exchange over said first and second switching apparatus and said first and second repeaters and said trunk to said second exchange, means governed in response to the answering of the call in said second exchange and in accordance with the destination thereof for selectively controlling said second repeater, whereby said second repeater is operated either to reverse battery potentials or to transmit an impulse over said trunk, said first repeater including an answer relay operatively connected to said trunk, whereby said answer relay is restored in response to the reversal of battery potentials over said trunk and is restored and reoperated in response to the transmission of an impulse over said trunk, a reverse battery relay operative to effect the reversal of battery potentials over said switching apparatus, and means responsive to the restoration of

said answer relay throughout a fixed time interval for operating said reverse battery relay.

16. In a telephone system, a first exchange including a first repeater and first automatic switching apparatus, a first loop circuit extending between said first repeater and said first switching apparatus, a second exchange including a second repeater and second automatic switching apparatus, a second loop circuit extending between said second repeater and said second switching apparatus, a trunk interconnecting said exchanges, a dial circuit including said trunk extending between said repeaters, the two terminals of a source of current supply being respectively connected to said dial circuit in said first and second repeaters, means included in said first repeater and responsive to impulses received over said first loop circuit for correcting the received impulses to a predetermined standard and for transmitting the corrected impulses over said dial circuit, and means included in said second repeater and responsive to the impulses received over said dial circuit for repeating the impulses over said second loop circuit.

17. In a telephone system, a repeater comprising an incoming trunk, an outgoing trunk, a repeater coil including a primary winding connected to said incoming trunk and a secondary winding connected to said outgoing trunk, means including an impulse relay operative intermittently in response to impulses received over said incoming trunk for repeating the impulses over said outgoing trunk, means including a slow-acting bridge relay operative in response to the intermittent operation of said impulse relay for short-circuiting said primary winding during impulsion, and means including a plurality of slow-acting shunt relays controlled by said bridge relay for successively shunting said primary winding through successively higher resistance elements following the restoration of said bridge relay after impulsion, thereby to prevent inductive surge voltages in said primary winding and the consequent momentary restoration of said impulse relay.

EDWARD S. PETERSON.
